UNITED STATES PATENT OFFICE.

HUBERT S. TURNER, OF WASHINGTON, DISTRICT OF COLUMBIA.

TELEPHONY.

Application filed December 4, 1915. Serial No. 64,967.

To all whom it may concern:

Be it known that I, HUBERT S. TURNER, a citizen of the United States, residing at Washington, in the District of Columbia, 5 have invented certain new and useful Improvements in Telephony, of which the following is a specification.

The present invention has for one of its principal objects the provision of means whereby the simplicity and advantages obtained by the use of an old and well known form of link connector or cord circuit together with the improved service obtained by using link connectors comprising features 15 such as automatic "disconnect", automatic "recall," automatic ringing, automatic listening and "secret service," etc., are combined in a new link connector circuit which is the subject of the present invention, in which 20 the disadvantages inherent in both the cited link connector circuits are eliminated. The link connector circuit of this invention is adaptable for use with any of the well known forms of central office apparatus. I have 25 chosen for illustrating the same a well known type of such apparatus and a well known type of link connector to which types, however, the invention is not to be restricted as it will be clear that the new features 30 described may be adapted for use with other well known forms of apparatus and for use with other well known forms of link connector circuits, without departing from the principles involved.

35 In my invention, I add but one, two, three or four simple relays of a well known type to each link connector and by providing audible signal means for the operator, am enabled to approximate the advantages 40 obtained by the use of the more complicated link connector comprising the automatic features mentioned.

In my invention when a calling or called party replaces the substation receiver on 45 its switch-hook, an audible signal is instantaneously sounded in the connecting operator's head receiver, unless the operator is actually engaged in answering a call or a recall or completing a connection. At 50 the same time a busy test made on any multiple jack connected to the same line will give a signal distinctive to the disconnect condition of the line. Therefore, should another operator hear this disconnect busy 55 signal on testing a line, the line need not be reported "busy" to the calling party but

the operator could wait a moment until the connecting operator had time to remove the plug from the line jack. As the connecting operator can only need a moment or so 60 to remove this plug after hearing the audible disconnect signal, the other operator would lose less time by waiting than if the line is reported busy and the calling party later on initiates a new call for the same line. 65 A "recall" is made whenever a substation receiver is removed before the connection is taken down by the operator. Therefore, to obtain an instantaneous recall, a subscriber need only depress the switch-hook once, instead of continuously moving it up and down as is the old practice. On making a 70 "recall," an audible signal distinct from the disconnect signal is instantaneously sounded in the connecting operator's receiver, unless 75 a call is being attended to. At the same time the line will test busy, thereby evading a connection being made to it by another operator. The operator can select the line making the recall as the supervisory lamp 80 individual thereto is illuminated in a different manner than it is when a disconnect is signaled. The operator can "listen in" when a recall is made by either the calling or called party or both, but cannot "listen 85 in" before a "recall" is made, thereby obtaining the "secret service" feature with the added advantage of being able to supervise the connection whenever it is necessary. When the called line is manually or auto- 90 matically rung the supervisory signal individual to the called line is illuminated in a different manner than it is when the called party has answered, has replaced the receiver on its switch-hook or is signaling a 95 recall, and if the calling party signals a disconnect or recall previous to the response of the called party, then the called line supervisory signal is displayed in the disconnect manner and the ringing current is cut 100 off if automatic ringing is used, or if manual ringing is used, and operator cannot make the common mistake and continue to ring a called line when the calling party has already abandoned the call. When a call is 105 initiated at a substation an audible line pilot signal is sounded in the operator's receiver which may eliminate the disconnect signal or the disconnect and recall signals, or one or both of the latter may eliminate 110 the pilot signal and sound it instead in the receiver of another operator who has means

for answering the call. Means are provided whereby the recall signals may eliminate the disconnect signals and if the latter take precedence over the line pilot signals it will be seen that precedence in calls will be given: first, to "recalls;" second, to "disconnects;" third, to new calls. Arrangements are made whereby the recalls may always take precedence over the disconnects 10 and new calls, but the disconnects will only take precedence over the new calls when there is another operator available to attend to the new calls. Means are provided whereby when a line has two or more visual 15 line signals mounted on different operators' positions, one operator only will receive the audible line pilot signal, the same being transferred to one of the other positions when the first mentioned operator is busy, 20 thereby avoiding the confusion of having two or more operators connecting to the same calling line at the same time. The audible signal system as described herein is a very elastic one and is capable of many 25 variations, some of which I have shown and will hereinafter describe. However, I do not wish to be limited to the specific forms shown herein, as it will be readily understood as the description is proceeded with 30 that by adding or subtracting from the number of the simple three contact relays used or by changing the connections thereof, that an infinite number of variations in the signal operating means may be obtained. 35 Other objects than those hereinbefore mentioned will be apparent from the specification.

In the following description, reference will be had to my U. S. Patent No. 1,128,262 40 and my co-pending applications, Serial Nos. 11,046 and 45,232, now Patent No. 1,421,864, granted July 4, 1922, as the present invention in respect to the automatic ringing and audible signals consists in improvements 45 on the methods described therein.

In order to more fully describe my invention, reference will now be had to the accompanying drawings forming a part of this specification, and wherein;

50 Figure 1 is a diagram illustrating how by adding one simple relay to each cord circuit and one to the operator's equipment, the aforementioned well known type of link connector may be converted so that the audible line pilot signals, ringing supervisory signal and automatic ringing features may be used as hereinbefore mentioned; Figure 2 a diagram illustrated how by adding two simple relays of the same type as the well known 55 supervisory relays, the same link connector may be converted so that the recall and disconnect audible signals and the recall and ringing visual signals are produced, the addition of eight relays of the supervisory 60 type to the operator's equipment providing 65

the means whereby the recall audible signal takes precedence over a line pilot signal and the disconnect, the line pilot signal also taking precedence over the disconnect, the same relays performing various line pilot 70 audible signal transferring operations between adjacent positions so as to insure adequate "team-work" between operators; Figure 3 a diagram illustrating how by adding three simple relays of a well known type to 75 the same link connector the automatic listening and ringing features are added to those shown in Figure 2, the addition of eleven relays of the supervisory type to the operator's equipment providing the means 80 for still further improvement in the "team-work" between operators, and means whereby the disconnect audible signal causes the elimination of the line pilot signal provided, however, there is another operator 85 who is able to attend to the calling line; Figure 4 a diagram illustrating a modification of the link connector illustrated in Figure 2 and a further division of the recall and disconnect features, wherein the calling and 90 called parties have independent control over the recall signal; Figure 5 a diagram illustrating a modification of the link connector illustrated in Figure 3 with the same division of the recall and disconnect 95 features; Figure 6, a diagram illustrating a modification of the audible signal system illustrated in Figure 2, in which two groups of line signals are provided at each operator's position, the pilot signals being independently transferred; Figures 7 and 8 diagrams illustrating modifications of the automatic listening means illustrated in Figures 3 and 5, and Figure 9 a diagram illustrating the means whereby when there are 100 two or more visual line signals located at separate answering positions one operator only will receive the audible pilot signal and the other operator will receive the same only when the first mentioned operator is busy, 105 means being provided for "teamwork" by the operators adjacent to both of the aforementioned operators.

In all the figures the talking circuit is shown by a heavy line, as well as the principal traced circuit for the transferred audible signals.

Referring first to Figure 1, 1 and 2 represent telephone substations of a well known form. The removal of the telephone receiver at substation 1 closes a path for direct current through limbs 3-4, thereby causing the energization of line relay 5. This gives path for current from battery 6 through elements 7, 8, 9, 10 and ground, energizing pilot relay 7. This gives another path for current from battery 6 through elements 11, 12, 13, 14, left winding of relay 15, 16, 17, 18 and ground, energizing audible signal relay 15. However as soon as 130

contacts 13-14 are separated this path is interrupted and relay 15 de-energized. When contacts 13-14 are engaged again relay 15 is once more energized whereupon the path is again interrupted. Therefore, a vibratory action of contact 13 is obtained and a pulsating current traverses primary 18 which induces an alternating current in secondary 19. As operator's receiver 20 is connected to the two terminals of secondary 19 the alternating current produces an audible signal in the receiver. Hearing this signal the operator knows a line is calling and on looking over the visual line signals assigned to the position observes that line lamp 8 is energized, such energization having taken place when the aforementioned path was closed through relay 7, which relay is the pilot relay usually used in conjunction with a group of line signals at an operator's position. The operator thereupon inserts answering plug 21 in answering jack 22 which in a well known manner causes the energization of cut-off relay 23 and the consequent de-energization of line relay 5 and line lamp or signal 8. As the path through pilot relay 7 is thereupon opened the disengagement of contacts 11-12 opens the path through relay 15, thereby stopping the production of the audible pilot signal.

The link connector illustrated in its general features is a well known one and need not be specifically described herein except in its bearing on the new features involved. The insertion of plug 21 in jack 22 also connects limbs 3-4 to repeating coil windings 25-26 and when the operator manipulates listening key 27, in the well known manner, operator's receiver 20, secondary 28 and condenser 29 are connected to repeating coil windings 30-31. The only changes made in this well known manner of connecting the operator's telephone set to the repeating coil is that condenser 29 is shunted by the right winding of relay 15 and that repeating coil winding 30 is connected to spring 32 of key 27 by way of contacts 33-34 of relay 35. Therefore, whenever a key 27 is manipulated path is given for current from battery 6 through elements 30, 33, 34, 32, 36, right winding of relay 15, 28, 19 and 20 in multiple, 37, 38, 31 and ground energizing relay 15. The consequent attraction of the armature of relay 15 causes contacts 13-14 to be disengaged, thereby preventing the sounding of the described audible signal by the energization of another line lamp as long as a key 27 remains manipulated. Therefore, while an operator is engaged in completing a connection or talking to a substation, there is no interference caused by the sounding of the audible signal should another line signal be energized. The right winding of

relay 15 is preferably of an extremely high resistance, so that but a small amount of direct current passes through receiver 20, thereby avoiding the disagreeable click produced in the receiver when an appreciable amount of current passes through the same. As a path for the voice currents is furnished around this winding by condenser 29, talking efficiency is not diminished. As secondary 19 is in multiple relation to receiver 20, it may be of a high resistance, so as not to shunt an appreciable amount of the voice currents. Manually operated switch 16 may or may not be used. It is provided when it is desired to furnish a loud sounding pilot signal when there is no operator on duty or when an operator is not wearing head receiver 20. By changing switch 16 from contact 17 to contact 39, the pulsating direct current flows through loud-speaking receiver 40 instead of primary 18, thereby producing a loud audible signal capable of being heard at some distance. Relays 41—42 correspond at another operator's position to the described relays 7—15 and are similarly connected and operated. If it is desired that when an operator is busy the audible line pilot signal shall be sounded in the receiver at another operator's position then relay 15 is provided with a contact 43 which is connected, as shown by the dotted line to contact 44 of relay 42. Therefore, relay 42 is intermittently energized and the audible signal consequently produced at the other operator's position whenever pilot relay 41 is energized or whenever pilot relay 7 and audible signal relay 15 are energized. Lamp 45, corresponding to lamp 8 is shown connected to contact 46 of line relay 47 of substation 2 corresponding to line relay 5 of substation 1 exemplifying how the line signals of different lines may be apportioned to different operators. It will be understood that if only one operator is used contact 46 would be connected to pilot relay 7.

Having obtained the number of the desired line from the calling party, calling plug 48 is inserted in jack 49 (which may be considered as a multiple jack in a multiple switchboard system or as an answering jack such as 22 in a non-multiple system). Manual ringing may be performed in the well known manner but I prefer the use of a relay such as 35, as illustrated, which constitutes a feature of the present invention. As soon as plug 48 is inserted in the jack, a path is given for ringing current from generator 50 through elements 51, 52, 53, 54, 55, 56, 57, 58, 59, 60, 61, 62, 31, and to ground. Call bell or annunciator 58 is continuously operated by this current. As the return path to ground is through repeating coil winding 31 the calling party receives an audible signal in his receiver,

assuring him the called substation is being rung. By leaving listening key 27 manipulated until after the connection is established, the operator will also receive this signal in receiver 20, which would be an assurance that the called line and the link connector were in proper operating condition and that the call bell had been rung. If periodic ringing is desired an interrupter is inserted between 50 and 51 in a manner well known in the art. Another path in multiple relation to the ringing one is given for direct current from battery 63 through elements 64, 65, 66, 67. As interrupters 51-64 alternately connect their respective sources 50-63 to contact 55, relay 67 is never traversed by the ringing current, and is not energized by the intermittent direct current until there is a path of lower resistance than that offered by elements 58-59 at substation 2. This path is given when the receiver is removed from its switchhook and relay 67 is then energized. This gives a path for current from battery 6 through elements 68, right winding of relay 35, 69, 70, 71, 72, 73, and to ground, energizing ringing relay 35. The disengagement of contacts 52-53 disconnects the ringing current from the substation line. Contact 66 is first connected to contact 33, and then disconnected from contact 65, thereby substituting continuous direct current from battery 6 through repeating coil winding 30 for the intermittent current from battery 63 through interrupter 64. Supervisory relay 67 is thereby maintained actuated as long as a path for direct current remains closed at substation 2. Contact 53 engages contact 74, thereby bridging non-inductive resistance 54 around relay 67. Contact 33 is disengaged from contact 34, thereby preventing the subsequent manipulation of listening key 27 from connecting the operator's set to the repeating coil. Therefore, it will be seen that it is impossible for an operator to "listen in" on a conversation passing between two connected substations. When the receiver is replaced on its switchhook at substation 2 and relay 67 consequently de-energized, the disengagement of contacts 69-70 does not de-energize relay 35, as if it did the call bell at substation 2 would be rung again. Relay 35 remains energized owing to a path for direct current from battery 6 which was closed through the left winding of said relay when the relay was first energized. Therefore, this winding constitutes a locking winding. This path may be traced through contacts 76-77, supervisory lamp 78 and elements 71, 72, 73 and ground. As this locking winding forms a shunt for resistance 68 it is also energized by the current flowing through the right winding when relay 67 is actuated.

Supervisory relay 79, which was ener-

gized when the connection was made to the calling line, shunts supervisory lamp 80 with resistance 81, thereby virtually extinguishing the same. This is well known in the art and the only change I have made in the function of this relay is one which may or may not be used, namely, the provision of contact 82 shown connected by a dotted line to contact 83 of relay 35. These two contacts are used only when it is desired that when the calling party abandons a call previous to the response of the called party, the ringing on the called line should cease. The replacing of the receiver on its switchhook at substation 1 de-energizes supervisory relay 79. This gives a path for current from battery 6 through the left winding of relay 35, elements 76-83, 82, 84, 85, 86, 23 and to ground, energizing relay 35. Contact 77 engages contact 76 before the latter is disengaged from contact 83, thereby establishing the path already traced through supervisory lamp 78 and maintaining relay 35 actuated during the time plug 48 is connected to the called line.

During the time the called line is being rung, a path is given for current from battery 6 through resistance 68, lamp 78 and elements 71, 72, 73 and ground. This energizes cut-off relay 73 but only partially energizes lamp 78. Therefore, the partial illumination of lamp 78 indicates to the operator that the called party has not responded, and key 27 may be manipulated at any time so that the operator may "listen in" and note by the ringing signal in receiver 20 if the called substation bell is being rung. When the called party responds and relay 35 is energized resistance 68 is shunted by the left winding of said relay, the resistance in series with lamp 78 being so lowered thereby that it would be fully illuminated, were it not that lamp 78 is also shunted at the same time by the right winding of relay 35, which is such that lamp 78 is virtually extinguished. Therefore, supervisory lamp 78 is only fully illuminated when supervisory relay 67 is de-energized when the called party replaces the receiver on its switchhook.

Interrupter 64 is shown connected to battery 63 of lower voltage than battery 6 which is connected to the repeating coil, a condenser 87 being shown connecting a brush of said interrupter to the wire leading from the brush of ringing interrupter 51. This use of battery 63 and condenser 87 is what differentiates the ringing interrupter from the form shown and described in my aforementioned Patent No. 1,128,262, to which reference is made for a more complete description of the ringing system than is given herein, it being understood that the form shown in said patent may be substituted for the form shown herein. The use

of a battery of lower voltage than the regular exchange battery will be found to prevent a possible slight energization of relay 67 by the intermittent direct current when 5 the circuit is closed through call-bell 58 and condenser 59 at substation 2. The use of condenser 87 furnishes a path to ground through battery 63 in multiple relation to relay 67, whenever the latter is connected to 10 battery 63; consequently any static charge of the called line finds a path to ground through the condenser instead of through the inductive winding of relay 67. This static charge may be due to the discharge 15 from the line and condenser 59, due to their charge by the alternating current. As supervisory relay 67 is not shunted by non-inductive resistance 54 until after the relay has been first energized, it can be readily caused 20 to attract its armature by a battery of less voltage than that necessary to cause the same attraction after said resistance is bridged around its winding.

Referring now to Figure 2, the vertical 25 line of relays and associate equipment, diagrammatically shown in the center of the page and below the link connector circuit, represents the apparatus individual to the position at which the link connector is located. The vertical rows at the left and 30 right represent similar apparatus individual to the left and right immediately adjacent positions. At the left and right of these rows are shown parts only of similar 35 apparatus individual to the next positions in line.

Line lamp or signal 89 is intended to be connected at its free terminal to contact 9 of line relay 5. Therefore, when the latter is 40 energized a path is given for current from battery 90 through pilot relay 91, left outermost armature switch and alternate contact of relay 103, line lamp 89 and to ground through contacts 9-10 of relay 5, as shown 45 in Figure 1. Lamp 89 and pilot relay 91 are energized, giving another path for current from battery 90 through interrupter 94, elements 95, 96, 97, 98, 99, 100 and to ground, energizing relay 99. Interrupter 94 is shunted 50 by a resistance 101, so that when the brush of the interrupter is engaged with one of the insulating segments current still flows over the path just traced, though it will be less than when the brush engages a metallic 55 segment. Owing to the variable current thus allowed to flow through primary 100, an alternating current is induced in secondary 102 which is connected in a circuit including the alternate contact and right innermost 60 armature switch of relay 103, contact 104 of the operator's set jack, contact 105 of the operator's set plug, operator's receiver 106, contact 107 of the plug and spring contact 108 of the jack. Therefore, an audible signal 65 is produced in receiver 106. Hearing

this signal and observing displayed line signal 89, the operator inserts answering plug 109 in the proper jack. Windings 110-111 of the repeating coil are thereby connected to the calling substation in the well known 70 manner and when the well known form of listening key 112 is manipulated, a path is given for current from battery 113 through elements 114, 115, 116, 117, upper spring of key 112, 118, 119, 121, 122, 123, 108, 107, 106, 75 105, 104, 124, 125, 126, lower spring of key 112, 127 and to ground, energizing relay 122. This gives path for current from battery 90 through wire 128 and elements 129, 130, left winding of relay 131, right windings of relays 132 and 133, 99, 100 and to ground, energizing relays 131, 132, 133 and shunting the connection through relay 99 to battery 90 by way of interrupter 94, by a direct connection to the same battery. The energization 85 of relay 133 causes contact 97 to disengage contact 98, thereby cutting off the variable current from primary 100 and consequently eliminating the audible pilot signal in receiver 106. The constant current still 90 flowing in primary 100 through relays 131, 132 and 133, does not produce any noticeable effect on receiver 106, thereby allowing conversation to take place between the calling 95 substation and the operator, inasmuch as receiver 106 is now connected to windings 116-127 of the repeating coil. Relay 122 is shunted by condenser 134 so as to allow the passage of voice currents. To evade a disagreeable click in receiver 106 caused by an 100 appreciable amount of direct current passing therethrough, relay 122 is preferably of high resistance.

Having obtained the number of the called 105 for line, the operator, if the line tests idle, inserts calling plug 135 in a jack of the line and manipulates ringing key 136 which impresses on the line ringing current from generator 137. The restoral to normal condition of listening key 112 before ringing key 110 136 was manipulated, opens the described circuit through relay 122 and consequently the described circuit through relays 131, 132, 133 and 99 is also opened, restoring the operator's audible signal circuits to their normal 115 condition. The insertion of plug 135 in the jack gives path for direct current from battery 113 through calling supervisory lamp 138, resistance 139, contact 140, and the cut-off relay of the called line to ground. A 120 shunt path for the current from battery 113 to resistance 139 is given through elements 114, 115, 75, 141, 142, 143 and 144, resistance 75 being such that lamp 138 is only partially illuminated. This partial illumination of 125 the supervisory lamp furnishes the signal indicating that the called party has not responded.

When the called party removes the substation 130 receiver from its switch-hook, super-

visory relay 145 is energized and the described shunt path from resistance 139 is opened and another shunt path is given from battery 113 through elements 114, 146, 147, 5 lower winding of relay 148, 149 and 144, energizing relay 148. As the lower winding of relay 148 is of lower resistance than resistance 75 lamp 138 is virtually extinguished and this condition indicates to the operator 10 that the called party has responded.

Supervisory lamp 150 connected to resistance 151 and energized in the same manner as lamp 138 was not illuminated when answering plug 109 was connected to the calling line, as the energization of supervisory relay 152 closed a shunt around the lamp from said resistance through elements 153, 154, 155, 147, 146 and 114. Therefore, lamps 150—138 remain extinguished while the lines 20 are being used.

When calling plug 135 was connected to the called line a path was also given for direct current from battery 113 through wires 114—115, upper windings of relays 159—148, key 176, contact 140 and to ground through the cut-off relay. Relays 159—148 are not energized by the current thus allowed to flow through them. However, said windings are such that they constitute locking windings, so that when the relays have once been energized by the current flowing through their other windings, they are maintained actuated as long as calling plug 135 is connected to a jack. The resistance of 30 these windings is such that lamp 138 is not shunted so as to impede its illumination. It is for this reason that said windings are preferably connected to a point between resistance 139 and contact 140 of plug 135. 35 These upper windings are not connected to contact 160 of answering plug 109, as in that event relay 159 might be prematurely energized when a connection is made to the calling line if contact 160 of the plug engaged the jack contact before the other two contacts did, as the lower winding of relay 159 would be momentarily energized, due to the non-energization of supervisory relay 152, and the locking winding would therefore 40 maintain it actuated.

When the calling substation receiver is replaced on its switch-hook, supervisory relay 152 is de-energized and contact 153 disengages contact 154 and engages contact 156. 55 This gives path for current from battery 90 through interrupter 157, disconnect relay 158, left intermediate alternate contact and armature switch of relay 103, lower winding of relay 159, intermediate winding of 60 relay 148 and elements 156, 153, 151, 160 and to ground through the cut-off relay, energizing recall relay 159 and operator's disconnect relay 158. If the called substation receiver is replaced on its switch-hook, instead of that of the calling substation, sup-

ervisory relay 145 is de-energized and the path from the upper terminal of the intermediate winding of changing relay 148 instead of being through contact 156, would have been through elements 161, 142, 143, 70 144, 139, 140 and to ground through the cut-off relay of the called line. Changing relay 148 was energized by the previous energization of relay 145 and is maintained actuated by its upper locking winding. When both 75 receivers are replaced the path through the intermediate winding of relay 148 is divided and passes through both cut-off relays. In any event operator's disconnect relay 158 is energized when either party replaces his 80 receiver giving path for current from battery 90 through interrupter 157 and elements 162, 163, 164, 165, 92, 100 and to ground. The variable current formed by interrupter 157 is of a different character from that 85 formed by interrupter 94 and consequently the audible signal produced in receiver 106 by the variable current flowing in primary 100 is of a distinct character from that produced by the operation of a line signal. 90 Therefore, the operator knows that there is a link connector which can be disconnected from a line. The shunts through resistance 155 or lower winding of relay 148 are removed. The shunt through disconnect relay 158 does not impede the illumination of 95 a supervisory lamp, or lamps. Therefore, the displayed supervisory lamp, or lamps, indicates the link connector in question.

If the calling party replaces the substation receiver previous to the response of the called party, then changing relay 148 is energized, due to the current flowing through its intermediate winding, and the consequent disconnection of contacts 141—142 removes the shunt, including resistance 75, from around supervisory lamp 138. The consequent full illumination of this lamp warns the operator from further ringing on the called line as said ringing is only 110 done when said lamp is partially illuminated. Therefore, the operator would take down the connection. Should the called party respond after the calling party has abandoned the call and before the operator 115 has taken down the connection, a visual and audible "recall" signal is given, in the manner hereinafter described.

Whenever any of the described disconnect means are put into operation, variable current formed by interrupter 157 flows over the described path to contacts 160 or 140 of the plugs. Therefore, when the usual busy test, which is well known in the art, is made on one of the multiple jacks of a connected 125 line, instead of a "click" being produced in the testing operator's receiver, a continuous audible signal will be produced during the time the test contact of the calling plug is in contact with the test thimble of the 130

jack. Hearing this signal, the testing operator knows that the tested line is really idle and is calling for a disconnect and as the connecting operator must receive the same signal it can be but a moment or two before the established connection will be taken down. Therefore, instead of reporting the tested line "busy" the testing operator may wait a moment or so and when the connecting operator has taken down the connection the cessation of the sustained audible signal will indicate to the testing operator that she may insert the calling plug in the jack. In this way it will be seen that a formerly busy line will really test idle as soon as the receiver is replaced instead of when the connection is taken down. Disconnect relay 158 is maintained actuated by the variable current flowing through it.

Should the calling or called party desire a "recall," instead of a disconnect, then the switch-hook is depressed once instead of several times, and is then allowed to return to its former position. The depression of the switch-hook operates the disconnect circuit, as described, and as relay 159 is energized thereby and is maintained actuated by its upper locking winding the return of the switch-hook to its former position and the consequent re-energization of supervisory relay 152 or 145, as the case may be, gives path for current from battery 90 through elements 166, 167, 168, left innermost alternate contact and armature switch of relay 103, 169, 147; and 155, 154, 153, 151, 160 and to ground through the cut-off relay of the calling line; or lower winding of relay 148, elements 149, 144, 139, 140 and to ground through the cut-off relay of the called line, in either case energizing operator's recall relay 168. This gives path for current from battery 90 through interrupter 170 and elements 171, 172, 173, 174, 130, left winding of relay 131 right windings of relays 132-133, 99, 100 and to ground, energizing the traversed relays. It will be clear that if a receiver is replaced and then removed, before the connection is taken down, or if one receiver is replaced and the other not replaced, the recall signal will also be given. The variable current formed by interrupter 170 is of a different character from that formed by interrupters 94 or 157 and consequently the audible signal produced in receiver 106 by the variable current flowing in primary 100 is of a distinct character from that produced by the operation of a line signal or by an idle link connector being connected to a line. Therefore, the operator knows that there is a line which is making a recall. The shunt which extinguishes supervisory lamp 150 or 138, was removed when contacts 146-147 of relay 159 were disengaged. However, the illumination of

lamp 150 or 138 varies as the current flowing through resistance 151 or 139 has two paths offered to it, one through the lamp to battery 113 and the other through resistance 155 or lower winding of relay 148, relay 168 and resistance 166 to battery 90. Resistance 166 is intermittently short-circuited by interrupter 175, the consequent decrease in the resistance of the circuit causing the illumination of lamp 150 or 138 to vary. Interrupter 175 revolves comparatively slowly, so that the variations in the illumination of the lamp are very noticeable. Interrupter 175 and resistance 166, as well as the other interrupters, may be connected to battery 113, if preferred, instead of to battery 90, the principal purpose in showing two batteries being one of convenience in the drawing. Relay 168 is maintained actuated by this variable current flowing through it. The operator on hearing the "recall" audible signal can select the line making the "recall" by observing the described variations in the illumination of the supervisory lamp of the link connector connected to that line. As soon as listening key 112 is manipulated, thereby connecting the operator's set to the calling or called line, or both, as the case may be, connecting relay 122 is energized, as hereinbefore described. Therefore, the path for the recall signal current is opened when contact 130 of relay 122 disengages contact 174. If the calling line is making the "recall," and a connection to another line is desired, the withdrawal of calling plug 135 from the jack opens the path through relays 159-148, thereby restoring them to their normal condition and de-energizing recall relay 168. If the "recall" is for the same line, then key 176 is manipulated, obtaining the same results. The use of key 176 is optional, inasmuch as plug 135 can always be removed from the jack to de-energize relays 159-148. If the recall is from the called line, in any event the calling plug 135 must be disconnected from the jack and an answering plug inserted, so as to be able to ring the line called for. This would also de-energize relays 159-148.

A busy test made on a jack of a line establishing a recall would produce a busy signal characteristic to interrupter 175, in the same way as the described disconnect busy test was produced, thereby indicating to the testing operator that the line was establishing a recall.

When one connected line signals a "recall" and the other a "disconnect," the respective supervisory lamps indicate this condition and at the same time the disconnect audible signal is prevented from being produced in receiver 106, as it is more important for the operator to attend to the "recall" first. This result is obtained by having the path of the recall variable current to primary 100 trav-

erse relay 99, energizing the latter. The consequent disengagement of contacts 164—165 of this relay opens the path for the disconnect variable current to primary 100.

5 When an operator is engaged in completing a connection and a listening key 112 is manipulated, the described energization of relay 122 as well as eliminating the audible line pilot signals also eliminates the recall 10 and disconnect audible signals. The disengagement of contacts 130—174 of relay 122 opens the path of the recall variable current to primary 100 and the energization of relay 99 and the consequent disengagement of 15 contacts 164—165 opens the path of the disconnect variable current. Therefore, an operator cannot be disturbed by any of the audible signals while busy, but as soon as 20 idle the various signals may be produced again.

Reference is now had to the audible signal and transferring relays shown in the drawing in a vertical line below the link connector. These relays are individual to 25 the operator's position at which the link connector is located and the connections to the same are common to all the link connectors at that position.

Whenever the operator at a position is on 30 duty thereat primary relay 103 is maintained actuated, inasmuch as a path is given for current from battery 113 through said relay as long as the two contacts of operator's transmitter jack 178 are connected together 35 through operator's transmitter 179 by way of plug 180, which is inserted in said jack. As illustrated, relay 103 takes the place of the retardation coil usually used in series with the operator's transmitter and primary 40 of operator's induction coil, when the transmitter is energized from the exchange battery. Primary 181 and transmitter 179 are usually shunted by a condenser which is not shown in the drawing for sake of clearness, 45 the use of the same being well known in the art.

When an operator vacates a position and withdraws the transmitter plug, the circuit through the transmitter jack is opened and 50 primary relay 103 is consequently de-energized. This condition is shown in the drawing in the vertical row at the left of the central position, wherein the reference numerals to corresponding elements at the 55 central position have the exponent "a" added to them.

The de-energization of relay 103^a gives a path for current from battery 113 through the right outermost armature switch and 60 normal contact of said relay, left winding of relay 131^a, right windings of relays 132^a—133^a, relay 99^a, and primary 100^a. The purpose of this circuit is merely to maintain relays 131^a, 132^a and 133^a actuated, so that 65 the transferring functions performed by

their contacts may be attained in the same way as when said relays are energized from time to time, when the operator is on duty. As said relays may be of high resistance, but little current is consumed when the position 70 is vacant.

The right innermost and intermediate armature switches and contacts of relay 103^a are merely for the purpose of changing the listening key leads of a vacant position to 75 the corresponding leads of the next position to the left or right, as the case may be. This allows the operator at the latter position to connect the operator's set thereat to the link connectors of the vacant position, so that 80 they may be used by the operator for establishing connections. If this feature is not desired these armature switches and contacts are dispensed with, and an alternative form of connecting the special audible signal secondary to the operator's receiver is used as 85 shown at the next position to the left where the corresponding reference numerals to instrumentalities shown in the central position, bear the exponent "b." In this form 90 the upper terminal of secondary 102^b connects to an extra spring 182 of the operator's receiver jack so that said secondary is connected direct to contact 105^b instead of to the same contact by way of the right inner- 95 most armature switch of relay 103 and contact 104, as shown at the central position.

The listening key leads of the *a* position, corresponding to 119—125 of the central position, are shown in a corresponding position at 183. The already described circuit from these leads which is closed through relay 122^a, and contacts 104^a—108^a of the operator's receiver jack, when the receiver plug is engaged therewith, is opened by the 100 withdrawal of said plug when the position is vacated. As the right innermost and intermediate armature switches of relay 103^a are connected to the same leads 183 and as 105 said switches are engaged with their normal 110 contacts which are connected to the corresponding listening key leads 184 of the *b* position, it will be seen that receiver 106^b may be connected to any link connector of the *a* position as well as those of the *b* position. It will also be seen that when the central position is vacated and primary relay 103 de-energized listening key leads 119—125 115 will be similarly connected to said leads 183, so that the operator at the *b* position could 120 then use any of the link connectors at both the *a* and central positions as well as those of the *b* position.

The upper terminal of audible signal secondary 102 is preferably connected to the alternate contact of the right innermost armature switch of relay 103, as if it were connected permanently to contact 104 of the receiver jack, leads 119—125 would be permanently bridged by a circuit including relay 125 130

122 and condenser 134 in multiple, secondary 123 and special secondary 102. While the resistance of this circuit may be high, yet, when several adjoining positions were vacant the multiplied resistances of the circuits thus bridged across the listening key leads of the various vacant positions, might impede somewhat the passage of talking currents to and from the link connectors of some of said vacant positions.

The three left armature switches of relay 103 are connected respectively, to the line lamps of the position as shown at 89, and to the disconnect and recall circuits of the link connectors at the position. The respective left normal contacts of relay 103 are connected to the corresponding armature switches of relay 103^a. Therefore, when the central position is vacated the illumination of a line lamp thereat, or a "recall" or "disconnect" signal at that position, will produce their characteristic audible signals in the operator's receiver at the *a* position and if the *a* position is vacant, they will be produced in the receiver at the *b* position or if that position is vacant at the next position to the left at which there is an operator on duty.

It will be readily understood that the direction of the transfers performed by relay 103 is purely arbitrary and that the same may be to the right if desired, or some positions may transfer to the right and others to the left. My idea is providing for these transfers is to provide means whereby an operator who is in charge of several vacant positions may be positively and instantly advised of an initiated call, a recall or a disconnect at any of the vacant positions.

Considering now that all the positions shown are occupied, then when pilot relay 91 is energized by a line initiating a call and at the same time the operator receives a recall or is engaged in completing a connection, left transfer relay 133 is energized, as has been described, and the path for the variable current through contact 97 is transferred from contact 98 to contact 185 and thence through the left winding of relay 133 to the *a* position. If the operator thereat is idle; that is has no recall to attend to or is not busy completing a connection, then the path proceeds by way of contacts 186^a—187^a of relay 131^a, right windings of relays 132^a—133^a, relay 99^a, primary 100^a, and to ground, energizing all the traversed relays. The variable current thus allowed to flow through primary 100^a produces the audible line pilot signal in the receiver of the operator, whereupon this operator would attend to the call. The energization of relay 133^a would in turn transfer to the *b* position any pilot signal produced by the energization of pilot relay 91^b, inasmuch as they are connected in the same way as are relays 91—133

of the central position. Therefore, it will readily be seen and understood that the transfer of the path of an audible pilot signal from one position to the next, in turn transfers the pilot signal of that position to the one next to it, which in turn would transfer its pilot signal to the one next to it, and so on. If the operator at the *a* position is busy, or in other words is receiving a recall or completing a connection, then relay 131^a is energized and the path for the variable current through contact 186^a is re-transferred from contact 187^a to contact 188^a and thence through the right winding of relay 131^a to the position at the right of the central one, where the instrumentalities corresponding to those of the central position are denoted by the use of the exponent "c." If the operator thereat is not receiving a recall, is not busy establishing a connection or is not receiving a transferred signal from the next position at the right by way of relay 131^c, then the path proceeds by way of contacts 189^c—190^c of relay 132^c, right winding of relay 133^c, relay 99^c, primary 100^c and to ground, energizing relays 133^c—99^c. Therefore, the operator at the *c* position would attend to the call. On the other hand if the operator at the *c* position is receiving a recall, or is busy establishing a connection, or is receiving a transferred signal, then relay 132^c would be energized and contact 189^c would disengage contact 190^c and engage contact 193^c. This would re-transfer again the path for the variable current and it would proceed by way of the left winding of relay 132^c to contact 194 of operator's recall relay 168. If the central position is receiving a recall, then the path is open at this point, as contact 173 would be engaged with contact 172. If the operator at the central position is connecting, then connecting relay 122 is energized and the path is open at contact 174. Therefore, the variable current controlled by pilot relay 91 has no path to ground, and no audible pilot signal is sounded as long as the central or originating position and the left and right adjacent positions are all occupied. However, such a path is furnished and the signal produced at the first one of the three positions to become idle. If the central position becomes idle first, due to the release of the recall signal or the completion of the connection, contacts 173 or 180 of relay 168 or 122, disengages contact 172 or 129, as the case may be, and before the circuit can be closed again at contacts 194 or 174, relay 133 is de-energized and contact 97 of relay 133 disengages contact 185, thereby opening the described path to contact 194 of relay 168. Consequently relay 133 remains de-energized and when contact 97 engages contact 98 the audible pilot signal is produced in receiver 106. If the *a* position becomes idle first, as 130

soon as contact 186^a of relay 131^a engages contact 187^a the path to ground is closed through primary 100^a and the signal consequently produced in the operator's receiver 5 therat. As this path includes the left or locking winding of relay 133, this relay will remain energized should the operator at the central position now become idle. Therefore, the signal is not cut off from the *a* position and sounded at the central position, as it would be were it not for this locking winding. If the operator at the *a* position answers the call, the consequent energization 10 of connecting relay 122^a energizes relay 131^a and as soon as contact 186^a disengages contact 187^a, the circuit through this locking winding is opened and relay 133 becomes 15 de-energized. If the *c* position becomes idle first, as soon as contact 189^c of relay 132^c engages contact 190^c, the path to ground is closed through primary 100^c and the signal produced in the operator's receiver therat. As this path includes the right or locking winding of relay 131^c as 20 well as the locking winding of relay 133, both of said relays remain energized should the operators at the central and *a* positions now become idle. Relays 133 and 131^a are 25 de-energized when relay 122^c is energized. Therefore, it will be seen that once a transferred or re-transferred pilot signal has been 30 given to sound in an operator's receiver it cannot be cut-off and sounded in the receiver of another operator if the latter subsequently becomes idle. This is so arranged to evade 35 the resultant confusion of having one, two or three operators receive one after the other the same pilot signal produced by the same illuminated line lamp, as it is one of the purposes of these audible signals to provide 40 means whereby only one operator can ever attempt to connect to a calling line at the same time. However, these locking windings may be eliminated if this feature is not 45 desired.

When the operator at the central position is idle and a signal is transferred thereto from the *c* position or re-transferred thereto from the *b* position, relay 133 is energized in 50 either case, and the signal controlled by pilot relay 91 will be transferred and re-transferred in the same way as hereinbefore described, excepting that recall relay 168 or connecting relay 122 will not be energized. Therefore, if the *a* operator is busy and the *c* operator either busy or receiving a transferred signal, a path is given for the variable 55 current at contact 194 of recall relay 168 and the same proceeds to primary 100 through contacts 173 and the same path as 60 traced for the recall audible signal. This would energize both relays 131 and 132, so that they would perform their transferring and re-transferring functions. Therefore, it will readily be observed that a 65

transferred or re-transferred pilot signal only takes precedence over the pilot signals originating at a position, when there is an adjacent operator able to attend to the latter. As this path for the signal current controlled by pilot relay 91 would be through the locking windings of relays 133, 131^a and 132^c, once the variable current has begun to flow over the described path, these relays cannot be de-energized and the path 70 cannot be interrupted by the operators at the *a* or *c* positions subsequently becoming idle. However, when the central operator attends to the call, the energization of connecting relay 122 opens the path at contact 174, so 75 that relays 131^a, 132^c or both may then be de-energized.

It will readily be seen and understood that the various transferring and re-transferring functions performed by relays 131, 132 and 80 133, might be performed by one relay, by making the same control all the contacts controlled by the aforesaid three relays. However, were this done, it would be possible to have two or three pilot signals sounding at 85 the same time in the one receiver and were these signals of different character (as hereinafter described) this would cause much confusion, also time would be lost as an operator could not attend to two or three calls 90 at once. Therefore, I prefer the embodiment as shown, wherein precedence in function is given as follows: First, the energization of connecting relay 122 stops the production of the recall and disconnect signals and 95 transfers and re-transfers all the pilot signals; second, the energization of recall relay 168 produces its audible signal, stops the production of the disconnect signal and transfers and retransfers all the pilot signals; 100 third, the transfer to a position of a pilot signal from the left or right adjacent position, as the case may be, stops the production of the disconnect signal, re-transfers to the originating position a pilot signal re-transferred from the left or right adjacent 105 position, as the case may be, of said originating position, and transfers the pilot signals of the position itself; fourth, the re-transfer to a position of a pilot signal from the left or right adjacent position, as the case may be, of the originating position, stops the production of the disconnect signal and transfers the pilot signals of the position itself; fifth, the production of a pilot signal at 110 a position stops the production of the disconnect signal; sixth, the production of the disconnect signal. Therefore, only one signal is sounded at a time and the sounding of a signal which takes precedence over the others, automatically and instantaneously transfers the others to other operators' positions or stops their production. In this way simultaneous calls at different positions have 115 an opportunity of being attended to by different operators.

ferent operators. Also the relays are greatly simplified by using them as shown, there being but one moving member for each relay and but one or two contacts engaged by said member. Relay 99 is the last relay traversed by any of the variable currents before primary 100 is traversed, therefore, it is always energized when any pilot signal is produced in receiver 106. As the disengagement of contacts 164—165 of this relay opens the path for the disconnect variable current, the disconnect signal is always prevented from being sounded, until after the pilot signal has been attended to.

15 Lamps may be connected to the relay contacts as shown at the *a* position, if visual pilot signals are desired. Resistance 92 connected to contact 165 of disconnect cut-off relay 99 is used so as to prevent a low resistance shunt being formed around the various transfer and re-transfer relays which at one time or another are energized. This shunt would be formed when disconnect relay 158 connected primary 100 to battery 90 by way of interrupter 157 and its resistance shunt.

As an operator at each position may receive an audible pilot signal denoting a call from a line assigned to that particular position, or a pilot signal from the position at the left or right, it is advisable to provide means whereby the character of signal sounded indicates the position which is to be searched for a displayed line lamp. To accomplish this result three interrupters, 191, 192, 94, are employed, each interrupter being so arranged that the variable current formed by the same is of a different character from that formed by the other two. Consequently, the audible signals produced by these variable currents differ from one another. Therefore, if the contacts 95 of the pilot relays 91 of three adjacent positions are connected respectively to a different interrupter, in whatever way the audible signals are transferred an operator will know from the character of the signal from what position it emanates. As illustrated in the drawing, contact 95^b (not shown) of the *b* position would be connected to interrupter 191, the corresponding contact 95^a is shown connected to interrupter 192 and contact 95 of the central position connected to interrupter 94. The corresponding contact of the *c* position would begin to repeat the sequence, being connected to interrupter 191. The variations in the variable current forming means of these interrupters are purely arbitrary and I have chosen the form shown for purposes of illustration on account of it furnishing simple signals which can readily be distinguished from each other. Interrupters 191, 192 and 94 are intended to revolve comparatively slowly. As long as their brushes are engaged with the insulat-

ing segments of the interrupters, the path from battery 90 is through the resistances, such as 101, which shunt said interrupters. Sufficient current can traverse these resistances to maintain actuated whatever transferring relays may be connected in circuit with the interrupters. However, when the brushes engage the metallic segments of the interrupters the resistance shunts are short-circuited and consequently the resistance of the circuit or circuits connected to the interrupters is lowered. This produces a "click" in the operator's receiver or receivers, due to the variation in current strength in primary 100. Interrupter 191 has one metallic segment; therefore, but one click is produced in said receiver. Interrupter 192 has two metallic segments separated by a short insulating segment and then a longer insulating segment; therefore, the audible signal formed by this interrupter is two clicks an interval then two clicks, and so on. Interrupter 94 is similarly arranged so as to form three clicks and an interval. If the respective adjacent operators' positions are numbered 1—2—3, repeating the sequence for all the positions at the switchboard, and the pilot relay contact connected to the corresponding signal forming interrupter, it will be clear that an operator cannot mistake the originating position of any audible pilot signal. The speed of rotation of these interrupters should be such that the number of clicks can readily be determined. By adding other forms of interrupters as many positions as desired can be given individual character designations.

Referring now to Figure 3, as the link connector and audible signal system illustrated represents modifications of that shown in Figure 2 only that part of each which differs from what has been already described will be described hereinafter, it being understood that those parts not described function in the same way as corresponding parts in Figure 2.

The principal change made in the link connector illustrated is that no listening or ringing keys are used. The energization of a line lamp or signal 201 energizes pilot relay 202. This gives path for current from battery 203 through elements 204, 205, 206, 207, 208, 209, 210, 211 and to ground. A path for alternating current is given over the same path formed by secondary 205 due to the interrupted current flowing in primary 212. Primary 212 and secondary 205 may constitute windings of an induction or repeating coil. Primary 212 may be of a high resistance while secondary 205 may be of a low resistance, thereby obtaining economy in the use of current from battery 203 and impeding but little the passage of current from the same battery through said secondary. Interrupter 213 intermittently gives

path for current from battery 203 through primary 212. Therefore, the alternating current produced in secondary 205 will be in accordance with the metallic segments of 5 said interrupter. Interrupters 214 and 215 function similarly to 213, the three interrupters furnishing the audible pilot signals current for three adjacent positions at the switchboard, as described in relation to 10 interrupters 191, 192 and 94 in Figure 1. The interrupters are the same, the connections only being different. Operator's receiver 216 is in circuit with secondary 217 and windings 218-219 of an operator's repeating coil. Therefore, the alternating current traversing primary 211, induces a corresponding current in secondary 217 which produces the audible signal in receiver 216.

When answering plug 220 is inserted in 20 the answering jack of the calling line, tip and ring contacts 221-222 are not connected to battery through supervisory relay 223 and the link connector repeating coil windings 224-225, but instead are connected to 25 battery through said relay and the operator's repeating coil; the path being as follows: battery 203, elements 226, 227, 228, 229 and engaged armature switch, 230, 231, 232, 223; and 233, 234, 235 in multiple relation to 223; 222 and thence to the substation 30 line, returning through 221, 236, 237, 238, armature switch and engaged contact 239, 240, 241 and to ground, energizing supervisory relay 223 and connecting relay 241. 35 This gives path for current from battery 203 through elements 226, 227, 242, 243, 244, 245, 246, 247, 248, 249, 250, 251, 211, and to ground, energizing all the traversed relays. The energization of relay 251 causes 40 contacts 209-210 to be disengaged, thereby preventing the production of the audible pilot signal, controlled by pilot relay 202. Conversation can now take place between 45 the calling party and the operator, due to the connection of the latter's receiver to the operator's repeating coil windings. Relay 241 is shunted by a condenser to facilitate the passage of the voice currents. The operator's transmitter is shown connected to 50 primary 252 associated with the same secondary as audible signal primary 211. If preferred, separate induction coils may be used, as shown in Figure 2. The dotted lines connecting the operator's transmitter, 55 represent the transmitter jack connections as shown in Figure 2.

When calling plug 253 is inserted in the 60 jack of the called line a path is given for ringing current from generator 254 through elements 255, 256, 257, 258, 259, 260, 261, called substation call-bell, 262, 263, 264, 238, armature switch and engaged contact 239, 240, 241, and to ground. As the ringing current has returned to ground through 65 winding 240 of the operator's repeating

coil, both the operator and the calling party receive an audible ringing signal in their respective receivers.

The insertion of the calling plug also gives path for current from battery 265 through elements 266, 267, 268, 269, 270, 271, lower winding of 272, 273, and to ground through the cut-off relay, energizing the latter and relay 272. Relay 272 may be made slow acting, due to its upper short-circuited winding as shown, or by any other means, provided it is desired that the operator should receive the ringing signal when a connection is made to a called line, thus assuring the operator that the called line is in working condition and that the call-bell has been rung. When relay 272 is energized contacts 274-275 first engage contacts 232-236, thereby connecting repeating coil windings 224-225 to the calling line, and then disengage contacts 232-236 from contacts 231-237. In this manner supervisory relay 223 is not momentarily de-energized though it and the calling substation now receive current from battery 265. The operator's repeating coil and consequently the operator's telephone set is disconnected from the link connector when contacts 231-237 are disengaged and the described circuit through relay 241 is opened and consequently the described circuit through relays 245, 246, 247, 248, 249, 250 and 251 is also opened, restoring the operator's audible signal circuits to their normal condition. The engagement of contact 276 of relay 272 with contact 263 and the disengagement of the latter from contact 264 changes the ground connection for the ringing current to winding 277 of the cord repeating coil; consequently, the calling party only continues to receive the ringing signals. The engagement of contact 279 with contact 278 and the disengagement of the latter from contact 280, prevents the connection of the called line to the operator's repeating coil, when the called party responds, and instead connects it to winding 281 of the cord repeating coil.

The automatic ringing system illustrated in Figure 3 is a modified form of the system illustrated in Figure 1 and described in relation thereto. Interrupter 282 is used instead of condenser 87 (Figure 1) for the purpose of relieving the called line of static charges, thereby similarly avoiding the necessity of 115 adjusting the supervisory relay so that it will not be actuated by the charge retained in the called substation condenser and line due to the impressions of ringing current. Interrupters 255-283 and battery 284 correspond in function to interrupters 51-64 and battery 63 shown in Figure 1 and described in relation thereto. Interrupter 283 is connected by way of elements 285, 286 and 287 to plug contact 261. Interrupters 120 125 and 287 to plug contact 261. Interrupters 130

255, 282 and 283, as illustrated revolve in a clockwise direction and are so mounted that their speed of rotation and the relative position of their metallic segments is always the same. Therefore, when the brush of interrupter 255 has disengaged a metallic segment and is engaged with one of the insulating segments, the brush of interrupter 282 engages a metallic segment, thereby closing the circuit through the called line directly to ground and consequently the charge retained in the line and substation condenser is led directly to ground instead of to ground by way of supervisory relay 287, interrupter 283 and battery 284. When the brush of interrupter 282 has disengaged the metallic segment and is engaged with one of the insulating segments, the brush of interrupter 283 engages a metallic segment, thereby connecting battery 284 to the called line through supervisory relay 287. When the brush of interrupter 283 has disengaged the metallic segment and is engaged with one of the insulating segments, the brush of interrupter 255 engages another metallic segment and the sequence of operations is repeated. In this way, the called line is momentarily short-circuited after each impression of ringing current and consequently no line discharge can ever take place through supervisory relay 287. Interrupters 255, 282 and 283 are illustrated diagrammatically only and their respective metallic segments are shown as being equal in size. However, this is not essential and the metallic segments of interrupter 282 may be smaller than the corresponding segments of the other interrupters, inasmuch as the static discharge is practically instantaneous. By making the metallic segments of interrupter 282 smaller, those of interrupter 283 may be made correspondingly larger, thereby allowing longer impressions of the intermittent direct current for operating supervisory relay 287 when the called party responds.

Supervisory lamp 288 is only partially illuminated due to the shunt path to battery 265 from resistance 289 through elements 290, 291, 292, 293, 294, 295. Interrupter 295, preferably revolves at high speed so that the shunt is sufficiently maintained to obtain the desired partial illumination of lamp 288, yet at the same time its insulating segments are such that if a busy test is made on a multiple jack of the same line to which plug 253 is connected the variations in current strength at the tested jack will produce a sustained audible busy test in the testing operator's receiver which will be distinctive to interrupter 295.

Supervisory lamp 296 is not illuminated, due to the shunt path from resistance 297 through elements 298, 299, 300, 301, 302, 303. Interrupter 303 is similar to 295, though it has a different number of insulat-

ing segments. Therefore, a busy test made on a multiple jack of the calling line will give an audible busy test signal distinctive to interrupter 303. Interrupters 295—303 may be shunted by a resistance such as 305, though the use of such a resistance is not essential. As two busy tests are provided, one peculiar to the talking condition of a line and one peculiar to the ringing condition of the line, a testing operator is enabled to report to a calling party which condition it is that makes the line busy.

When the called party removes the substation receiver from its switch-hook, supervisory relay 287 is energized and the described shunt path around lamp 288 through resistance 289 is opened and another shunt path is given therethrough from battery 265 through interrupter 303, elements 302, 301, upper winding of ringing relay 306, 307, and 290, energizing relay 306. If interrupter 303 is not shunted by a resistance the current flowing over this path is an intermittent one; however, ringing relay 306 is nevertheless maintained actuated, without any vibration of its armature as when contact 267 disengages contact 268 the short-circuit around the lower winding of said relay is removed and the constant current flowing through this winding is sufficient to actuate it or maintain it actuated. As the upper winding of relay 306 is of lower resistance than resistance 294, lamp 288 is now virtually extinguished, which indicates to the operator that the called party has responded. As the shunt around lamp 288 is now through interrupter 303 instead of 295, any further busy tests made on the called line will give the testing operator the "talking" busy test.

The energization of ringing relay 306 causes contact 308 to first engage contact 286 and then disengage the latter from contact 285. By this means the path for current through supervisory relay 287 is changed from interrupter 283 to battery 265 by way of winding 281 of the repeating coil, thereby completing the telephonic connection of the calling and called substations. Contact 257 disengages contact 256 and engages contact 309, disconnecting non-inductive resistance 260 from ringing interrupter 255 and connecting it to the other terminal of relay 287, thereby bridging said resistance around the winding of said relay and cutting off the impression of ringing current on the called line. Contact 268 disengages contact 267, thereby removing the short-circuit around the lower winding of said relay. Consequently, the current flowing through relay 272 now flows through this winding, thereby maintaining relay 306 actuated, independent of its upper winding, so that when supervisory relay 287 is de-energized ringing current is not again impressed on the called line.

When the calling party replaces the sub-

station receiver, supervisory relay 223 is de-energized, giving path for current from battery 203 through elements 226, 227, 310, contact 312 and engaged armature switch, 5 313, upper winding of relay 314, 315, 298, 297, 316 and to ground through the cut-off relay, energizing relays 310—314. If the called substation receiver is replaced, instead of that of the calling substation, supervisory relay 287 is de-energized and the path 10 from the upper terminal of the upper winding of relay 314 instead of being through contact 315 is through elements 317, 292, 291, 290, 289, 273, and to ground through the cut-off relay of the called line. When both receivers are replaced the path from said winding is divided through both cut-off relays. In any event disconnect relay 310 is energized giving path for current from battery 203 through elements 204, 318, 319, 320, 20 321, 322, 323, 324, 249, 250, 251, 211 and to ground, energizing all the traversed relays. Interrupter 325, causes a current to be induced in secondary 318, which is distinct in 25 character from that induced in secondary 205 by interrupter 213. Therefore, the audible signal sounded in receiver 216 is distinct from the audible pilot signal. Illuminated lamp 296 or 288, or both, indicate the cord to disconnect, as the shunt path through disconnect relay 310 does not impede their illumination. Any busy tests made on a line which is 30 signaling a disconnect, will produce the well-known click only, as the disconnect relay is connected by way of wires 227—226 direct to battery 203 and not by way of an interrupter as shown in Figure 2. Therefore, when this form of busy test is used the production of the click in the testing operator's 35 receiver, would indicate to that operator that the line is really idle and is signaling a disconnect and the testing operator could then wait a moment before connecting to the tested line, the absence of the click indicating 40 when the link connector has been removed by the connecting operator.

It will be noted that the busy tests illustrated in Figure 3 and described in relation thereto, are just the reverse from those illustrated in Figure 2 and described in relation thereto. It will be readily seen and understood, that this is merely an alternative form and that either form may be used with either of the illustrated link connectors or 50 signal systems.

If the calling party replaces the receiver previous to the response of the called party, relay 314 is energized, as described, and contact 259 disengages contact 258, thereby disconnecting non-inductive resistance 260 60 from ringing interrupter 255. This prevents the continued ringing of the called party's call-bell after the call has been abandoned by the calling party. As relay 306 is not energized, supervisory lamp 288 remains

only partially illuminated and as lamp 296 would be fully illuminated, the operator would know that the calling party had abandoned the call. Should the called party respond after the calling party has abandoned the call and before the operator has taken down the connection then supervisory relay 287 is energized as the intermittent current formed by interrupter 283 was not disconnected from the called line when the ringing current was disconnected. This would establish a recall and the corresponding audible signal would be sounded and the visual signal displayed, as hereinafter described.

The described energization of recall relay 80 314 causes contact 271 to disengage contact 270, thereby removing the short-circuit around the lowering winding of said relay. Therefore, the current flowing through relay 272 now flows through this winding, thereby 85 maintaining relay 314 actuated, independent of its upper winding. Contact 233 disengages contact 234, thereby opening the shunt around the winding of supervisory relay 223 through non-inductive resistance 235. The removal of this shunt facilitates the subsequent energization of relay 223 if a recall is made, inasmuch as it will now receive all the current flowing through the calling line. The disengagement of contact 259 from contact 258, opens the shunt around the winding of supervisory relay 287 through non-inductive resistance 260; consequently the energization of relay 287 is similarly facilitated. Therefore, the re- 90 energization of either relay 223 or 287, gives path for current from battery 203 through elements 204, 327, 328, 329, alternate contact and right innermost armature switch of primary relay 330, 331, 301; and then by way 100 of 300, 299, 298, 297, 316, and to ground through the calling line cut-off relay; or by way of upper winding of relay 306, 307 105 290, 289, 273 and to ground through the called line cut-off relay, in either case energizing operator's recall relay 329. This gives path for current from battery 203 through elements 204, 332, 333, 334, 335, 336, 243, 244, 245, 246, 247, 248, 249, 250, 251, 211 and to ground, energizing all the traversed relays. 110 The variable current induced in secondary 332 by interrupter 337, produces the proper recall signal in receiver 216. The illumination of lamp 296 or 288 varies, as the current flowing through resistance 297 or 289 has two 115 paths offered to it, one through the lamp to battery 265 and the other through resistance 300 or upper winding of relay 306, recall relay 329 and resistance 327 to battery 203. Resistance 327 is intermittently short-circuited by interrupter 338, the consequent decrease in the resistance of the circuit causing the illumination of lamp 296 or 288, or both, to vary in accordance with the speed 120 with which interrupter 338 rotates. Bat- 125 130

series 203—265, may of course be the same battery.

The operator is enabled to "listen in" on the link connector only after a disconnect or recall signal is given. This assures the subscribers of "secret service" and guarantees their conversation against any interruptions, either accidental or deliberate. At the same time it enables the operator to "listen in" and talk to either or both of the connected substations, whenever operating conditions require it. When relay 314 is energized, contact 271 engages contact 339, which is connected to spring 199 of key 340. This allows the manipulation of key 340 to short-circuit the winding of relay 272, thereby de-energizing said relay and substituting the connection of the operator's repeating coil to the calling and called lines for the connection of the link connector repeating coil. As relay 314 is not energized while a conversation is taking place between the connected substations it will be evident that the manipulation of key 340 could not possibly obtain this short-circuit. The engagement of spring 200 with its two contacts, when key 340 is used, connects non-inductive resistance shunts 235—260 to contact 232 of relay 272, so that supervisory relays 223—287 are again shunted by the same, notwithstanding that the actuation of relay 314 opened the connection of the shunts. This connection of the operator's repeating coil causes connecting relay 241 to be energized and the path for the recall signal current is opened when contact 243 of relay 241 disengages contact 336. If the recall is from the calling line and it is desired that the same called line be rung again, key 341 is manipulated, thereby short-circuiting the lower windings of relays 314—306 and consequently de-energizing the same. As soon as contact 271 of relay 314 engages contact 270, and contact 268 of relay 306 engages contact 267, the lower windings are separately short-circuited, so that key 341 may be restored to normal. On account of key 341 needing to make a momentary engagement only with its contact it may be of the self restoring type. Key 340 may be of the same type if the winding of relay 272 is such that it receives enough current to initially actuate the relay only when the lower winding of relay 314 is short-circuited, though once actuated it will so remain when the short-circuit is removed. The use of key 340 or key 341, or both, is purely optional. If only recalls from the calling line are to be attended to, the withdrawal of calling plug 253 from the line jack would de-energize relays 314, 272 and 306.

If relay 314 is made to control the connection of non-inductive resistance shunt 235 around supervisory relay 223, as hereinbefore described, when plug 220 is connected to the calling line, relay 223 may not receive

sufficient current to operate it as it will be shunted by this resistance. Therefore, relay 314 would be energized in the same way as if a disconnect was signaled and this energization would disengage contacts 233—234, thereby removing the shunt. This would cause relay 223 to receive all the current flowing to the line and cause its armature to be attracted, thereby opening the disconnect circuit and de-energizing relay 314 which thereupon restores the shunt.

When the well known form of busy test is made, which consists in touching contact 262 of calling plug 253 to the sleeve contact (such as 72 or 86 in Figure 1) of the tested jack, if the line is busy a path is given from interrupter 303 or 295 or batteries 265—203, as the case may be, through the connected link connector to contact 273, (as hereinbefore described) the sleeve contact of said jack, the corresponding tested sleeve contact in multiple relation thereto, said contact 262 and elements 263, 264, 238, armature switch and engaged contact 239, 240, 241, and to ground. The current flowing through the winding 240 of the operator's repeating coil produces the busy test in operator's receiver 216 and that of the calling substation. Therefore, as the "talking" and "ringing" busy signals are sustained ones, the calling subscriber is automatically advised of this condition.

Reference is now had to the audible signal and transferring relays shown in the drawing in the vertical line below the link connector. These relays are individual to the operator's position at which said link connector is located and the connections to the illustrated link connector are common to all the link connectors at that position.

Four more relays are used than in the system shown in Figure 2 and described in relation thereto. However, the principle is the same and it will be seen that the four relays are added to further divide the transferring functions. Primary relay 330 corresponds in function to relay 103 in Figure 2. When the position is vacated and relay 330 de-energized the left outermost and three right armature switches transfer their corresponding link connector leads to the corresponding armature switches of relay 330^a. However, when the right intermediate armature switch disengages contact 229, the latter engages contact 342. This gives path for current from battery 203 through repeating coil winding 228, said contacts and relays 245, 246, 247, 248, 249, 250, 251 and to ground through primary 211, energizing all the traversed relays, thereby permanently maintaining their transferring functions during the time the position is vacant. The transfer of the connection from the line signals such as 201 or 201^c is different from that described in relation to relay 103 in Figure 130.

2. The *c* position is shown vacant and when lamp 201^c is energized path is given through the left intermediate armature switch and normal contact of relay 330^c, left innermost armature switch and alternate contact of relay 330, pilot relay 343, wires 227—226, battery 203, and to ground, energizing relay 343. This gives path for current from battery 203 through elements 204, 344, 345, 346, 347, 335, 336, 243, 244, 245, 246, 247, 248, 249, 250, 251, 211, and to ground, energizing all the traversed relays. The audible signal produced in receiver 216 by the closure of this path will be different from that produced by the energization of pilot relay 202, inasmuch as the variable current is formed by interrupter 215 instead of 213; consequently, the operator knows that the pilot signal sounded originated in a position to the right. At the same time should a line lamp be illuminated at the central position, the energization of relay 251, transfers the corresponding pilot signal to the next position at the left. Therefore, the vacant position pilot signals take precedence, the energization of the other transfer and re-transfer relays, attending to the proper re-transferring of other audible signals. As well as obtaining a distinct pilot signal from a vacant position the use of pilot relay 343, prevents a pilot signal from a vacant position at the right of an operator from being transferred to the next position at the left of said operator, as in that case the operator at this left position would have to reach around the first mentioned operator, something which might be difficult to do. If the form shown in Figure 2 is used, wherein the line lamps of a vacant position are connected to the same pilot relay at the next position to the left as are the line lamps of that position, a pilot signal produced by a line lamp of either of the positions is transferred whenever the operator is busy or receiving other audible signals. Therefore, for the convenient working of the system, when that form is used, the positions are so vacated that whenever an operator has a vacant position at the right, she also has a vacant position at the left. With the form shown in Figure 3, this is not necessary and the positions may be vacated in any manner desired. The pilot signal from the vacant position or positions, as described, is arranged to take precedence over any audible signal at the central position, excepting a recall. This is done as the other pilot signals which, at one time or another, are sounded in the receiver at the central position can be attended to by the operator at the *a* position. Therefore, the pilot signal of the vacant position or positions transfers or re-transfers said signals to the *a* position. When the central operator is connecting and connecting relay 241 is consequently energized, the vacant position pilot

signal path is opened at contact 336. If a recall is made, the same path is opened at contact 347 of relay 329.

The principal difference in the pilot signal transferring means shown in Figure 3 from that shown in Figure 2, is that in addition to the functions of the latter, the former allows the operation of the disconnect signal also to transfer the line pilot signal to the *a* position and if the operator thereat is receiving a disconnect signal this also re-transfers the pilot signal to the *c* position and if a disconnect signal is operating there also, this also re-transfers again the pilot signal to the central position where it eliminates the disconnect signal and the other transferred signals and is sounded in operator's receiver 216. It is so arranged that if the central operator is busy, or is receiving a recall instead of receiving a disconnect signal, the pilot signal is again transferred to the *a* position, where it eliminates the disconnect signal and is sounded in the receiver thereat, or if the operator at that position, instead of receiving a disconnect signal, is busy or is receiving a recall or a pilot signal from that position which cannot be attended to by another operator, then it is again re-transferred to the *c* position where it is sounded in the receiver thereat or if the operator instead of receiving a disconnect signal is busy or is receiving a recall or a pilot signal which takes precedence, it is either transferred to still another position or is prevented from being sounded until one of the operators becomes idle. In this way, a disconnect signal is always given precedence over any of the line pilot signals, provided there is another operator able to attend to said pilot signals. This tends to greatly facilitate the disconnections from formerly busy lines and at the same time does not delay the incoming calls.

Consider now that the three positions shown are all occupied, and that a disconnect signal is being sounded at the three positions. Relays 310, 310^a, 310^c, are energized, thereby energizing relays 251, 249^a, 250^c. If pilot relay 202 is now energized, relay 251, transfers the path for variable current to relay 249^a, which re-transfers it to relay 250^c, which re-transfers it again to relay 245, whence it proceeds through contacts 349, 350, and relays 246, 247, 248, 249, 250, 251, primary 211, and to ground, energizing the traversed relays. Relay 248 opens the path for the disconnect signal current therefore the pilot signal is sounded in the place of the disconnect signal. If the central operator is connecting or receiving a recall instead of a disconnect signal then relay 245 is energized and the variable current path is transferred to relay 246^a and thence by way of contacts 351^a—352^a, re-

lays 247^a, 248^a, 249^a, 250^a, 251^a, primary 211^a, and to ground, energizing the traversed relays. Relay 248^a opens the path for the disconnect signal current. If the *a* position operator instead of receiving a disconnect signal is connecting or receiving a recall, or is receiving a re-transferred pilot signal from the same position by way of relay 245^a, then relay 246^a is energized and the 10 variable current path is transferred to relay 247^c and thence by way of contacts 353^c—354^c, relays 248^c, 249^c, 250^c, 251^c, primary 211^c, and to ground, energizing the traversed relays. Relay 248^c opens the path 15 for the disconnect signal. If the *c* position operator instead of receiving a disconnect signal is connecting or receiving a recall, or is receiving a re-transferred pilot signal by way of relay 245^c or 246^c, then 20 relay 247^c is energized and the variable current path is not closed until one of the cited relays becomes de-energized. Therefore, the pilot signal, in such event, would be sounded in the receiver of the first operator able 25 to attend to the same. Should two operators become idle at the same time and one of them have a disconnect waiting, the pilot signal is sounded in the receiver of the other operator. Should one operator become idle 30 and have a disconnect waiting, then the pilot signal is sounded in the receiver of that operator eliminating the disconnect signal.

Relay 247^c may be provided with an alternate contact connected in a similar way by 35 dotted line 355^c to other operator's positions, allowing the pilot signal to be produced thereat. These positions may have a line lamp or lamps such as 516 in series with lamp 201^a, operated by the same line relay 40 as operates the described line lamp, as more fully illustrated in Figure 9 and described in relation thereto. When the plurality of line lamps is used, as shown in Figure 3, they may be formed in various groups at 45 each position and a greater number of variable current interrupters used, as described in relation to Figure 2. In such a case an operator would pay no attention to an illuminated line lamp of a group unless it was accompanied by the audible pilot signal of the 50 group.

Relays 249, 250, 251, which attend to the first transfers of the pilot signals, are energized not only by the energization of disconnect relay 310, but also by the energization 55 of relays 245, 246, 247, which attend to the second transfers of the same pilot signals. Therefore, the energization of one of the latter acts the same as if a recall signal was 60 being attended to or the operator was busy connecting. It will be noted that only one signal can be sounded at a time, precedence being given to one transferred or re-transferred signal over the others in a regular sequence, the sounding of one signal of this

sequence re-transferring all those signals which are below it in order of precedence.

The locking windings on the transfer and re-transfer relays, as illustrated in Figure 2 and described in relation thereto, are also 70 shown in Figure 3. Their use is optional and on this account they are only shown in Figure 3 in relation to the described transfer circuit. It will be understood that the other transfer relays shown can be similarly 75 equipped. Their purpose has been fully described hereinbefore.

The use of resistance 208 connected to contact 209 of transfer relay 251, and resistance 324 in series with contact 323 of relay 248, 80 is optional. They are used to assist the operation of the various relays which, at one time or another, may be connected in a divided path to battery 203 from audible signal primary 211. Unless this primary is 85 made of very low resistance, the relays might not receive sufficient current as the path direct to battery 203 would provide a low resistance shunt around these relays. In Figure 2, relay 99 or the locking winding 90 on transfer relay 133, takes the place of resistance 208. Visual pilot signals may be used as shown at the *a* position, 93 being the disconnect, 177 the recall and 515 a general visual pilot energized whenever any of the 95 pilot signal relays are operated.

The link connectors illustrated in Figures 4—5, represent modifications of those illustrated in Figures 2—3, respectively; therefore, only the changes that have been made 100 will be described. When the forms shown in Figures 2—3 are used, if the connected parties do not replace the substation receivers approximately at the same time, a false recall signal may be given which will 105 continue until both receivers have been replaced. This is due to the fact that relay 159 (Figure 2) or 314 (Figure 3) is energized when either of the connected parties replaces the receiver, the other connected 110 party causing the recall connection to be established by keeping the receiver off the switch-hook, in the same way as if the switch-hook had been deliberately manipulated. In practice, both parties generally 115 replace the receivers at approximately the same time. However, by using two relays such as 159 or 314, operable respectively by one of the connected parties, independent of the other party, the false recall is absolutely 120 avoided. This is the principal difference between Figures 4—5 and Figures 2—3.

In Figure 4 for the sake of clearness I have not shown the repeating coil and its connections through supervisory relays 125 356—357, nor the listening and ringing keys, as the modifications do not affect them in any way.

Relay 358 is arranged to operate in a slightly different manner from the corre- 130

- sponding relay 148 in Figure 2. When the calling plug is inserted in a line jack a path is given for current from battery 359 through conductor 360, lower windings of relays 361—362 and 358, key 363, sleeve contact 364 of the calling plug, and to ground through the cut-off relay. Relays 361—362 do not attract their armatures when this path is given, though their armatures are maintained actuated by the current in this path once said armatures have been attracted by the energization of the upper windings. Relay 358 does attract its armature, due to the current flowing in this path, but only when the shunt around its lower winding is removed. This shunt is formed through contacts 365—366 of relay 358, contacts 367—368 of relay 357, and resistance 369.
- Supervisory lamp 370 is only partially illuminated as it is shunted through the lower windings of relays 361—362, contacts 365—366 of relay 358, contacts 367—368, of relay 357, and the lower part of resistance 369.

When the called party responds and supervisory relay 357 is energized, the described shunt around relay 358 is removed when contact 368 disengages contact 367; consequently, relay 358 is energized. Supervisory lamp 370 is now virtually extinguished as the lower part of resistance 369 is connected direct to battery 359 through contacts 368—371 of relay 357 and contacts 372—373 of relay 362.

Supervisory lamp 374 was not illuminated when the answering plug was connected to the calling line, the energization of supervisory relay 356 forming a low resistance shunt around said lamp through the lower part of resistance 375, contacts 376—377 of relay 356 and contacts 378—379 of relay 361.

When the calling party replaces the substation receiver and supervisory relay 356 is de-energized, path is given for current from battery 359 through disconnect pilot lamp 380, conductor 381, upper windings of relays 358—361, contacts 382—376 of relay 356, resistance 375, sleeve contact 383 of the answering plug, and to ground through the cut-off relay, energizing relay 361 and, if the called party has not previously responded, energizing relay 358 as well. Lamp 374 is fully illuminated as the shunt path through pilot lamp 380 does not affect it, the lamp being of sufficiently high resistance to not furnish a low resistance shunt. At the same time pilot lamp 380 is energized, serving as a visual disconnect signal to the operator. If the calling party desires a recall, the removal of the receiver re-energizes supervisory relay 356 and a path is given for current from battery 359 through conductor 360, interrupter 384, recall pilot

lamp 385, conductor 386, contacts 387—378 of relay 361, contacts 377—376 of relay 356, resistance 375, sleeve contact 383 of the answering plug, and to ground through the cut-off relay. The illumination of supervisory lamp 374 varies, as it is intermittently shunted by the path through the lower part of resistance 375, pilot lamp 385 and interrupter 384. Pilot lamp 385 is of low enough resistance to cause this variation. The intermittent flashing of pilot lamp 385 serves as a visual recall signal to the operator.

When the called party replaces the receiver and supervisory relay 357 is de-energized, path is given for current from battery 359 through the same disconnect pilot lamp 380, upper winding of relay 362, contacts 388—366 of relay 358, contacts 367—368 of relay 357, resistance 369, sleeve contact 364, and to ground through the cut-off relay energizing relay 362. If a recall is made, a path through recall lamp 385 is given by way of contact 389 of relay 362, instead of contact 387 of relay 361. The illumination of lamp 370 varies, the variation being produced in the same manner as described in relation to lamp 374. When one party replaces the receiver and the other one does not, no recall signal is given as no circuit is closed at either of the branch circuits through contacts 387 of relay 361 or 389 of relay 362. Therefore, it will be seen that by duplicating the recall relay shown in Figure 2, the recall function of one substation is made independent of the condition of the other connected substation.

The manipulation of key 363 enables the operator to de-energize relays 358, 361, 362, without removing the calling plug from the line jack when a recall is made by the calling line for the same called line.

If desired, relay 358 may be of the same form as relay 148 in Figure 2, and the latter may be of the same form as the former. Also resistances 369—375 in series with the supervisory lamps may be as shown in Figure 2.

I have purposely shown the connection of the disconnect and recall circuits to pilot lamps 380—385. This is an optional form for any of the illustrated link connectors, and may be used alone or with the audible pilot signal as described in relation to Figure 2.

It will readily be understood that when the audible pilot signals are used alone conductors 381—386, instead of leading to lamps 380—385, would lead respectively to the left intermediate and innermost armature switches of primary relay 103 as illustrated in Figure 2, and if the visual signals are used also, then said armature switches would be connected to pilot lamps 380—385 as indicated by dotted lines 390—391.

Referring now to Figure 5, the functions performed by relay 314 as illustrated in Figure 3 have been divided so that each connected party has independent control over the disconnect and recall signals from the respective substation lines, relays 392-393 performing the functions performed by relay 314 in Figure 3. Operator's relay 394, corresponding to operator's relay 272 in Figure 3 is a modified form which may or may not be used as desired. Its use simplifies the form of the key used to connect the operator's set to the link connector when a recall is made.

When answering plug 395 is inserted in the answering jack of the calling line, the given path for battery current through supervisory relay 396 is by way of contacts 397-398 of relay 392, contacts 399-400 of relay 394 and conductor 401 (corresponding to conductor 230 in Figure 3) to the operator's repeating coil. As non-inductive resistance 402 is bridged across the winding of relay 396, the passage of voice currents is not impeded. If supervisory relay 396 is so adjusted that it only attracts its armature when not shunted by this resistance, then when the plug was connected to the calling line relay 392 (as hereinbefore described in relation to relay 314 of Figure 3) would be momentarily energized, thereby removing the shunt momentarily and allowing relay 396 to be actuated. The path from the tip contact of plug 395 is by way of contacts 403-404 of relay 394 and conductor 405 (corresponding to conductor 238 in Figure 3) to the grounded winding of the operator's repeating coil.

When the calling plug is inserted in the line jack and operator's relay 394 consequently energized (as described in relation to relay 272 in Figure 3) contacts 406-407 engage contacts 408-409, thereby connecting battery 410 and ground to the link connector repeating coil, which is connected to the talking strands of the link connector. This engagement causes contacts 400-404 to disengage contacts 399-403, thereby disconnecting the operator's repeating coil from the calling line.

Relay 411 corresponds in function to relay 306 in Figure 3 and connects and disconnects the ringing current to the called line in the same way as described in relation thereto. The path through non-inductive resistance 412 is by way of contacts 413-414 of relay 393, these contacts corresponding to contacts 258-259 of relay 314 in Figure 3.

Resistance 415 and contact 416 of relay 392 are shown connected to battery 410. Such a connection is made when the sustained busy signals described in relation to Figure 3 are not used.

When the calling party replaces the sub-

station receiver and supervisory relay 396 is de-energized, path is given from the operator's disconnect relay through conductor 417, (corresponding to conductor 313 in Figure 3) intermediate winding of relay 411, upper winding of relay 392, contacts 418-419 of relay 396, resistance 420, sleeve contact 412 of plug 395, and to ground through the cut-off relay, energizing relay 392; and if the called party has not previously responded, energizing relay 411 as well, thereby disconnecting the ringing current from the called line. The re-energization of supervisory relay 396, when a recall is made causes contact 419 to engage contact 422, thereby giving path by way of contacts 423-424 of relay 392 and conductor 425 to the operator's recall relay. (Conductor 425 corresponds to the conductor connected to the right innermost armature switch of relay 380 in Figure 3).

The disconnect signal from one connected line does not cause a false recall from the other line when one receiver is replaced before the other, inasmuch as the recall signal of the called line is not operated until relay 393 is energized, which takes place only when the supervisory relay is de-energized, giving path for current from the operator's disconnect relay by way of conductor 417, upper winding of relay 393, contacts 426-427 of relay 411 (energized when the called party responded), contacts 428-429 of supervisory relay 430, resistance 431, sleeve contact 432 of the calling plug, and to ground through the cut-off relay. The energization of relay 393 removes the short-circuit around its lower winding by way of contacts 433-434, the current flowing through the circuit including this winding and relay 394 being sufficient to maintain relay 393 actuated. Contact 435 disengaging contact 436 and engaging contact 437, removes the low resistance shunt formed by the upper winding of relay 411 from around supervisory lamp 438 and closes the circuit through conductor 425 to the operator's recall relay.

When either relay 392 or 393 is energized the operator is enabled to short-circuit operator's relay 394 by manipulating key 439, the two contacts of the key being connected to contacts 311-326 of relays 392-393, battery current being supplied through the lower winding of one or the other of the relays. When both relays are actuated the manipulation of key 439 short-circuits the lower winding of relay 392 and the relay is consequently de-energized, providing a recall is being made by the calling line. However, this does not affect the short-circuiting of operator's relay 394 as relay 393 remains actuated. The operator can talk to either of the connected substations, as non-inductive resistance 402 is connected by way of

contacts 399—400 of relay 394 to the operator's repeating coil and non-inductive resistance 412 is connected by way of contacts 413—440 of relay 393 and contacts 441—400 of relay 394 to the same coil; contacts 403—442 connecting the respective tip strands to the grounded winding of the operator's repeating coil, by way of contact 404. Contact 440 is used on relay 393 as if contact 413 of the relay was connected to contact 441 of relay 394, ringing current through contact 414 would normally find path to ground through the operator's repeating coil.

15 When the described recall connection of the operator's telephone set is made, supervisory relays 396—430 do not receive any current, as contacts 406—407 of relay 394 have disconnected battery 410 and ground from the respective windings of the link connector repeating coil and the path for current from the operator's repeating coil is opened by the disengagement of contacts 397—398 of relay 392. However, this does 20 not affect the talking between the operator and the party or parties making the recall and as soon as key 439 is released and relay 394 consequently re-energized, the supervisory relay or relays are once more energized. It will readily be understood that 25 key 439 and relay 394 may be the same as corresponding elements in Figure 3, in which event the supervisory relays would remain energized.

30 The manipulation of key 443 short-circuits the lower windings of relays 392, 393 and 411, its optional use being as described in relation to key 341 illustrated in Figure 3. When this key is manipulated, should the 35 called party have removed the substation receiver, ringing relay 411 is not momentarily de-energized, thereby impressing ringing current on the called line, as the upper winding receives current by way of contact 435 of relay 393 and when the latter is de-energized contact 436 engages contact 435 before contact 437 is disengaged from it. This prevents a disagreeable sound in the 40 receiver at the called substation.

45 Reference is now had to Figure 6, which represents a modification of the signal transferring means illustrated in Figure 2, though it will readily be understood that it could be adapted to the forms shown in Figures 3 and 9. This modification requires the use of 50 three more relays and represents a division of the line signals at a position into two groups, preferably a left and right group. When the operator receives a recall, a transferred call or a re-transferred call, or is 55 busy connecting, a pilot signal from the left group is transferred to the left immediately adjacent position and a pilot signal from the right group is transferred to the right immediately adjacent position, the simultane-

ous operation of a line signal of each group causing the pilot signal of one group to be similarly transferred.

60 Relay 465 corresponds to relay 168 in Figure 2 and is connected in the same way as relay 168; the wires shown ending above relay 465 are connected to the same instrumentalities as the corresponding wires in Figure 2. The relay immediately under 65 465 corresponds in function to 122 in Figure 2, 70 460 corresponds to 132, 459 and 462 together to 75 131, 454 and 456 together to 133, 457 to 99, the relay immediately below 457 to 158 and 458 to 453 together to 91. The functions of each of the relays 131, 133 and 91 are necessarily performed by two relays in Figure 6 on account of the described division of the line signals of a position into two groups. Line lamp 444 corresponds to the left group and lamp 445 corresponds to the right group. Dotted lines 446—447 represent the connections through the respective armature switches of the primary relay, such as 103 in Figure 2, or 330 in Figure 3, provided the same is used. The sources of 95 variable current for furnishing the line, pilot, recall and disconnect audible signals are direct current generators 448, 449, 450, 451, 452, whose commutators (shown connected to ground) vary in the number of 99 segments they contain, thereby obtaining a variable current which produces distinct signals in the operator's receivers. The number of segments is purely arbitrary, and is represented diagrammatically only in the 100 drawing. It will readily be understood that these generators constitute merely an alternative form of variable current producing means and that either of the hereinbefore described means may be substituted therefor.

105 The energization of right pilot relay 453 whenever a line lamp such as 445 is illuminated gives a path for current from generator 450, through the contacts of relays 453—454, elements 455, 456, 457 and to ground through the primary associated with the operator's receiver, energizing relays 456—457. The energization of relay 456 would transfer any audible signal produced by the energization of left pilot relay 458 110 to re-transfer relay 459^a, causing the pilot signal to be produced in the operator's receiver at the *a* position in the hereinbefore described manner. Therefore, when a call is received from both groups of line signals 115 simultaneously, two operators are at once notified.

120 If the operator at the *a* position is connecting, receiving a recall or a re-transferred pilot signal from the position at the left, by way of relay 460^a, then relay 459^a is energized and the signal current path from the central position is re-transferred to relay 460^a, causing the pilot signal to be produced 125 in the operator's receiver at the *c* position.

If the operator at the central position is connecting, receiving a recall, or a re-transferred or transferred pilot signal by way of relay 460, 459 or 462, then both relays 5 454 and 456 are energized and the left group signal current path is transferred as just described and the right group signal current path is transferred to re-transfer relay 462^c and if that relay is energized, on account of 10 the operator connecting or receiving other signals, then the path is transferred to a point 463 connected to the same conductor which transfers the left group signal current path to the *a* position. Therefore, the 15 operator at the *a* position receives a pilot signal from both groups of the line signals at the central position if the operator at the *c* position can not attend to the signal from the right group. Similarly, the operator at 20 the *c* position, if idle, receives a pilot signal from both groups if the operator at the *a* position cannot attend to the signal from the left group.

If the operator at the central position is 25 receiving a transferred or re-transferred signal by way of relays 460, 459 or 462, the operator at the *a* position connecting, or receiving a recall, or re-transferred pilot signal by way of relay 460^a and the operator at 30 the *c* position connecting or receiving a recall, the path for both the left and right group pilot signal current of the central position is from point 463 and contacts of relay 459^a, contacts of relay 460^a and contact 464 of recall relay 465, proceeding by 35 way of all the transfer and re-transfer relays of the central position. Therefore, in such a case, the pilot signal of either group at a position takes precedence over the 40 pilot signals transferred and re-transferred thereto.

The other transferring features are similar to those hereinbefore amply described and therefore not further mentioned. The order 45 of precedence of the signals may be changed if desired.

The use of resistances, such as 455, which are shown connected to the normal contacts of the transfer and re-transfer relays, is 50 purely optional. They may also be used with the relays shown in Figures 2 and 3. If used they serve to equalize the current flowing in the path through the special primary associated with the operator's receiver 55 and also facilitate the operation of the relays, as whenever a path is given through one or more of the relays it will always be of similar resistance to the other path which may have been given through the contacts 60 of one of the relays. Therefore, resistance 466 would preferably be equal to the combined resistances of relays 460, 459, 462, 454, 456, 457; resistance 467 and relay 457 would equal resistance 466; resistance 455 and relay 456—457 would equal resistance 466, etc. 65

Referring now to Figure 7, which represents another modification of the operator's relay, such as 394, and the recall key, such as 439, in Figure 5; contact 468 (corresponding to 399 in Figure 5) instead of being connected to non-inductive resistance 402 direct, is connected thereto by way of key 469 and conductor 470. There is no contact corresponding to 441 of relay 394, in Figure 5, instead the conductor leading to said contact is connected to conductor 471 which is connected to the alternate contact of the right spring switch of key 469. When a recall is made by the calling party, the operator manipulates key 472, the contact of 70 which is connected to contact 395 of relay 392, in Figure 5, thereby short-circuiting the operator's relay and allowing the operator to talk to the calling line only, the connection to the called line being open. This prevents 75 confusion when both lines recall at the same time or when the called party removes the substation receiver while the operator is talking to the calling party. If the recall had been from the called line, the operator would 80 have manipulated key 469, the contact of the left spring switch of which is connected to contact 396 of relay 393, in Figure 5, thereby short-circuiting the operator's relay and allowing the operator to talk to the called line 85 only, inasmuch as the right spring switch of key 469 disengages its normal contact and engages its alternate one. Therefore, it will be seen that the operator can only talk to one of the connected parties at a time and 90 when so engaged the other connected substation is completely cut off from any current supply, so that the party thereat cannot interrupt the conversation. Conductors 473— 95 474 correspond to 401—405 in Figure 5, 100 which lead to the operator's repeating coil. The other elements in Figure 7 are connected in the same way as the corresponding elements in Figure 5.

Reference is now made to Figure 8, which 110 represents a simpler form of the operator's relay, such as 272 in Figure 3. The connections to the repeating coil which in Figure 3 are made by way of contacts 232—279 and 236—263 of relay 272, in Figure 8 are made 115 direct to the windings, the two upper windings being connected to battery when the top armature switch of relay 475 engages its contact and the two lower windings being connected to ground when the lower armature switch engages its contact. The operator's repeating coil is normally connected to the same windings by way of conductors 476—477 (corresponding to 230—238 in Figure 3) and is disconnected therefrom 120 when said armature switches engage their contacts. In this form, the operator's talking circuit is always by way of the windings of the link connector repeating coil. Therefore, the repeating coil is so made as to offer 125 130

but little impedance, so that the voice currents which pass through the link connector are always sufficiently strong for operating purposes.

Reference is now made to Figure 9, which illustrates the disclosed audible signal system as applied to those exchange systems where a calling line energizes two or more line signals located at different answering positions. Heretofore, when such systems are used, the operators at the various positions often simultaneously connect to the calling line, thereby causing confusion and often keeping other calling lines waiting for attention, due to this duplication of effort. I overcome this difficulty by providing means whereby however many line signals pertaining to the same line there may be energized at various operators' positions only one operator will receive the proper audible pilot signal which indicates that a connection should be made to the line in question. For the sake of clearness, I have shown but two line lamps for each line, representing two answering positions, but it will readily be understood that the system may be extended to cover any desired number of answering positions. The form shown in Figure 9 is modeled on the form shown in Figure 3 and needs six more relays than does the latter form. It will readily be understood that it could be modeled on the form shown in Figure 2, in which case but three extra relays for each multiplied answering position would be needed.

For the sake of clearness but one circuit has been traced between the contacts of the various relays, it being understood that all the relays of the six positions shown which are on the same horizontal line are connected in the same way as the one relay on each horizontal line which is shown connected. The precedence of the disconnect signal is the same as that described in relation to Figure 3 and many other features described in relation thereto are shown in Figure 9 but will not be described. Pilot relay 343 shown in Figure 3 is not shown, though it may be added if desired. The top relay of each of the vertical rows of relays is connected to connecting relay 241, Figure 3, in the same way as relay 245 is connected.

The free terminal of line lamp 478 is connected to the line relay as illustrated in Figure 1 in relation to line lamp 8. Therefore, when a call is initiated at a substation of the line, lamps 478 and 479 are both illuminated, as the lower terminal of lamp 479 is connected to battery 480 by way of pilot relay 481. The energization of pilot relay 481 whenever the line lamps such as 478 and 479 are illuminated, connects variable current, formed by interrupter 482, by way of elements 483, 484, 485, 486 and 487 to the

special primary (such as 211 in Figure 3) associated with the operator's telephone set. Therefore, the operator at the right central position only receives the pilot signal and the operator at the left central or *c* position would pay no attention to the illuminated line lamp.

Should line lamp 488 be illuminated at the same time and pilot relay 481^c, consequently energized, the operator at the *c* position would receive an audible signal characteristic to interrupter 489. Interrupters 482—489 revolve comparatively slowly, forming the "two" signal as described in relation to Figure 3. However, interrupter 482 is connected to a rapidly revolving interrupter 490, which may be the one which forms the disconnect signal, as shown; while interrupter 489 is connected to another rapidly revolving interrupter 491, which may be the one which forms the recall signal. Therefore, the signals formed by interrupters 482—489 vary in quality, though they both produce the "two" signal.

All the line lamps such as 478 are mounted in one group at a position, while all lamps such as 488 are mounted in a separate group. Therefore, when the operator at the *c* position hears the "two" audible signal produced by interrupters 489—491, a connection to the line to which lamp 488 pertains is indicated and not to the line to which lamp 478 pertains, should the latter be illuminated also. In this manner an operator can never mistake the group to which a pilot signal pertains, there being a signal of different quality for each group of line signals at an answering position.

If relay 492 is energized by the operator connecting, receiving a recall or a disconnect signal, or a transferred or re-transferred pilot signal by way of any of the relays above 492, in the manner hereinbefore described; contact 485 disengages contact 486 and engages contact 493, thereby transferring the pilot-signal current by way of conductor 494 to relay 495^c and sounding the pilot signal in the receiver at the *c* position. As this signal would be a "two" signal characteristic to the group to which line lamp 478 belongs, the operator at the *c* position would connect to that line. As relay 492^c is energized by the passage of this signal current, the pilot signal produced by the illumination of a line lamp such as 488 is transferred to the position where the lamp in series with 488 is located.

If relay 495^c is energized by current from a relay above it, which would mean that the operator could not attend to the call as she was receiving another pilot signal or was busy connecting, the signal current path is changed to relay 496^a at the next position to the immediate left, and the signal is produced at that position. The sounding of the

"two" signal would indicate to the operator thereat that the calling line is at the position to the right, as the *d* position receives the "one" signal for the line lamps located thereat. The quality of the signal would also indicate the proper group.

If relay 496^a is energized in a manner similar to that already described, the path is changed to relay 497^e at the position to the immediate right of the *c* position and the signal is produced at that position. As this position receives the "three" signal for the line lamps thereat, the operator knows that the calling line is at the position to the left and belongs to the group in which lamp 478 is located.

If relay 497^e is energized, the path is changed, by way of conductor 498, to relay 499^a at the position to the immediate left of the signal originating position and the signal is produced thereat. The operator would know the group at the right central position to which the signal applied in the manner already described, the *a* position receiving the "one" pilot signal for the line lamps located thereat.

If relay 499^a is energized, the path is changed to relay 500^b at the position to the immediate right of the originating position and the signal produced thereat. The operator receiving a "three" pilot signal for the line lamps located thereat knows that the call must originate at the position to the left.

If relay 500^b is energized, the path is changed to relay 501 at the originating position and as the path traverses all the relays below 501 and above 481, except disconnect relay 502, and continues to ground by way of conductor 487, said relays are all energized and perform their re-transferring functions and at the same time prevent the sounding of the disconnect signal or a pilot signal other than the one produced by pilot relay 481.

Relay 501 is only energized by the energization of recall relay 329 or connecting relay 241 (Figure 3). Therefore, should either of these relays be energized, the path is changed to relay 503^a, which causes all the traversed relays between 503^a and 499^a to be energized, thereby performing their re-transferring functions. Therefore, if actuated relay 499^a is energized, by way of the contacts of one of the relays between it and 501^a, this pilot signal path is cut off and re-transferred and the pilot signal from the right central position is substituted therefor.

If relay 503^a is energized by the recall or connecting relay or relay 501^a, the path is changed to relay 504^b; which causes all the traversed relays between 504^b and 500^b to be energized and the signal current passing through relay 500^b is changed.

If relay 504^b is energized by the recall or

connecting relay, or the relays above it, the path is changed, by way of conductor 505, to relay 506^c; which energizes all the traversed relays between 506^c and 495^e, and changes the signal produced at the *c* position. 70

If relay 506^c is energized similarly to 504^b, the path is changed to relay 507^d, energizing the traversed relays between 507^d and 496^d, and changing the signal at the *d* position.

If relay 507^d is energized similarly to 506^c, 75 the path is changed to relay 508^e, energizing the traversed relays between 508^e and 497^e, and changing the signal at the *e* position.

If relay 508^e is energized similarly to 507^d, 80 the path is left open until one of the aforementioned relays is de-energized, or would be continued by way of dotted line 509^e to still other operators' positions, as described in relation to dotted line 355^c of relay 247^c, in Figure 3.

The relay immediately under relay 508^e is the disconnect signal relay and the one below that which is traversed by the current from any of the relays above the disconnect relay is the relay which opens the disconnect signal circuit when it is traversed by any one of the signal currents or by the steady current from the connecting relay. Therefore, it will readily be understood that the signal current first sent to the *c*, *d* or *e* 90 positions by way of conductor 494, is dominated by the disconnect signal of the respective positions, but if it returns again to said positions by way of conductor 505, it takes precedence over the disconnect signal. Consequently, a disconnect signal at one of these positions is only eliminated when the other available operators at the right central, *a* and *b* 95 positions are receiving calls other than disconnect calls.

The order of precedence for the various relays and signals is of course arbitrary. The only essential point being that any given relay controls only one signal path and that signal current flowing through the 100 contacts of any given relay energizes all the traversed relays below it, thereby evading the production of more than one audible signal at one time and providing for the re-transferring to other positions of those signals controlled by the traversed relays.

Conductor 510 of disconnect relay 502 is connected to contact 312 of primary relay 330, in Figure 3.

Interrupters 511—512, as well as 489, 120 are connected to interrupter 491 so that the quality of all the pilot signals of the *c*, *d* and *e* positions is characteristic to interrupter 491. Interrupters 513—514, as well as 482, are connected to interrupter 490, so 125 that the quality of all the corresponding pilot signals at the right central, *a* and *b* positions is characteristic to interrupter 490.

The locking windings used on the transfer and retransfer relays in Figures 2 and 3 130

and the resistances used in conjunction with the same in Figures 3 and 6, may be used in whole or in part with the system illustrated in Figure 9.

5 While I have purposely illustrated and described various modifications and variations of the link connector circuits and audible signal system herein disclosed, such is the elasticity of the means used that I do 10 not wish to be limited to any of the specific forms shown, as the same may be re-combined or changed to produce many forms other than those illustrated and described herein. For instance, the order of precedence of the described audible signals may 15 be changed as desired.

What I claim is:

1. A telephone exchange system including telephone lines extending from substations to an exchange, link connectors for connecting said lines, apparatus at said substations for signaling an exchange operator and having normal and abnormal conditions for said apparatus, a recall signal, a 20 called line ringing signal; means, operative during the time a link connector remains connected to a calling and a called line, whereby a single change from abnormal to normal condition of said apparatus at a 25 substation of either of said lines and the subsequent single change from normal to abnormal condition of said apparatus operates said recall signal; means for displaying said ringing signal; and means whereby a 30 single change from abnormal to normal condition of said apparatus at a calling substation may, and a single change from normal to abnormal condition of said apparatus at a called substation does, discontinue 35 said ringing signal.

2. A telephone exchange system including telephone lines extending from substations to an exchange, link connectors for connecting said lines, apparatus at said substations for signaling an exchange operator and having normal and abnormal conditions for said apparatus, a visual signal device individual to each of said link connectors, means to cause said device to indicate a recall or a disconnect; means, operative during the time a link connector remains connected to a calling and a called line, whereby a single change from abnormal to normal condition of said apparatus at a substation of said called line operates said device to indicate a disconnect and the subsequent single change from normal to abnormal condition of said apparatus operates said device to indicate a recall; and 50 means whereby a single change from abnormal to normal condition of said apparatus at the calling substation may also operate said device to indicate a disconnect.

3. A telephone exchange system including 55 telephone lines extending from substations

to an exchange, link connectors for connecting said lines, apparatus at said substations for signaling an exchange operator and having normal and abnormal conditions for said apparatus, a disconnect pilot 70 signal and a recall pilot signal individual to a group of said link connectors; means, operative during the time a link connector remains connected to a line, whereby a change from abnormal to normal condition of said apparatus at a substation of said line operates said disconnect pilot signal and the subsequent single change from normal to abnormal condition of said apparatus operates said recall pilot signal; and means to 75 prevent the operation of but one of said signals at the same time.

4. A telephone exchange system including telephone lines extending from substations to an exchange, link connectors for connecting said lines, apparatus at said substations for signaling an exchange operator and having normal and abnormal conditions for said apparatus, an audible recall pilot 80 signal associated with and individual to a group of said link connectors, an operator's telephone receiver; means, operative during the time a link connector remains connected to a line, whereby a single change from abnormal to normal condition of said apparatus at a substation of said line and the subsequent single change from normal to abnormal condition of said apparatus sounds 85 said signal in said receiver, and means, operative when said receiver is telephonically connected to a substation line, to prevent the sounding of said signal until said receiver is telephonically disconnected from 90 said line.

5. A telephone exchange system including telephone lines extending from substations to an exchange, link connectors for connecting said lines, apparatus at said substations for signaling an exchange operator and having normal and abnormal conditions for said apparatus, a visual recall 105 signal individual to each of said link connectors, an audible recall pilot signal associated with and individual to a group of said link connectors, an operator's telephone 110 receiver; means, operative during the time a link connector remains connected to a line, whereby a single change from abnormal to normal condition of said apparatus at a substation of said line and the subsequent 115 single change from normal to abnormal condition of said apparatus operates said visual signal and sounds said audible signal in said receiver; and means, operative when said receiver is telephonically connected to a substation line, whereby said 120 audible signal is not sounded until said receiver is telephonically disconnected from said line.

6. A telephone exchange system includ- 125

- ing telephone lines extending from substations to an exchange, groups of link connectors for connecting said lines, apparatus at said substations for signaling an exchange operator and having normal and abnormal conditions for said apparatus, a supervisory lamp for each of said link connectors, two pilot signals for each of said groups; and means operative during the time a link connector remains connected to a line, whereby a single change from abnormal to normal condition of said apparatus at a substation of said line causes said lamp to be steadily illuminated and one of said pilot signals to be operated, and the subsequent single change from normal to abnormal condition of said apparatus causes the illumination of said lamp to periodically fluctuate and the other of said pilot signals to be operated to the exclusion of said first mentioned pilot signal.
7. A telephone exchange system including telephone lines extending from substations to an exchange, link connectors for connecting calling and called lines, apparatus at said substations for signaling an exchange operator and having normal and abnormal conditions for said apparatus, a supervisory lamp for each of said link connectors; means, operative when a link connector is connected to a called line, whereby said lamp is only partially illuminated as long as said apparatus at the called substation is in its normal condition; means whereby a change from normal to abnormal condition of said apparatus extinguishes said lamp; and means whereby a subsequent change from abnormal to normal condition of said apparatus of the called line, independent of the condition of said apparatus at the calling line, fully illuminates said lamp.
8. A telephone exchange system including telephone lines extending from substations to an exchange, link connectors for connecting said lines, apparatus at said substations for signaling an exchange operator and having normal and abnormal conditions for said apparatus, a supervisory lamp for each of said link connectors, an audible recall pilot signal individual to a group of said link connectors; and means, operative during the time a link connector remains connected to a line, whereby a single change from abnormal to normal condition of said apparatus at a substation of said line causes said lamp to be steadily illuminated and the subsequent single change from normal to abnormal condition of said apparatus causes the illumination of said lamp to periodically fluctuate and said signal to be sounded.
9. A telephone exchange system including telephone lines extending from substations to an exchange, link connectors for connecting said lines, apparatus at said substations for signaling an exchange operator and having normal and abnormal conditions for said apparatus, a supervisory lamp for each of said link connectors, an audible recall pilot signal individual to a group of said link connectors, an operator's telephone receiver; means, operative during the time a link connector remains connected to a line, whereby a single change from abnormal to normal condition of said apparatus at a substation of said line causes said lamp to be steadily illuminated and the subsequent single change from normal to abnormal condition of said apparatus causes the illumination of said lamp to periodically fluctuate, and said signal to be sounded in said receiver; and means, operative when said receiver is telephonically connected to a substation line, whereby said signal is not sounded until said receiver is telephonically disconnected from said line.
10. A telephone exchange system including telephone lines extending from substations to an exchange, link connectors for connecting said lines, apparatus at said substations for signaling an exchange operator and having normal and abnormal conditions for said apparatus, a visual signal device individual to each of said link connectors, means to cause said device to produce a recall or a disconnect signal, a disconnect and a recall pilot signal individual to a group of said link connectors; means, operative during the time a link connector remains connected to a line, whereby a single change from abnormal to normal condition of said apparatus at a substation of said line operates both of said disconnect signals and the subsequent single change from normal to abnormal condition of said apparatus operates both of said recall signals; and means to prevent the operation of said disconnect pilot signal whenever said recall pilot signal is operated.
11. A telephone exchange system including telephone lines extending from substations to an exchange, link connectors for connecting said lines, apparatus at said substations for signaling an exchange operator and having normal and abnormal conditions for said apparatus, an audible recall pilot signal individual to a group of said link connectors; means, operative during the time a link connector remains connected to a line, whereby a single change from abnormal to normal condition of said apparatus at a substation of said line and the subsequent single change from normal to abnormal condition of said apparatus operates said signal; and manually controlled exchange means whereby said signal is discontinued, during an established connection by way of said link connector, until the condition of said apparatus is again changed as described.

12. A telephone exchange system including telephone lines extending from substations to an exchange, link connectors for connecting said lines, apparatus at said substations for signaling an exchange operator and having normal and abnormal conditions for said apparatus, an audible recall pilot signal individual to a group of said link connectors, an operator's telephone receiver; means, operative during the time a link connector remains connected to a line, whereby a single change from abnormal to normal condition of said apparatus at a substation of said line and the subsequent single change from normal to abnormal condition of said apparatus sounds said signal in said receiver, means, operative when said receiver is telephonically connected to a substation line, whereby said signal is not sounded until said receiver is telephonically disconnected from said line; and manually controlled exchange means whereby said signal is discontinued, until the condition of said apparatus is again changed as described.
13. A telephone exchange system including telephone lines extending from substations to an exchange, link connectors for connecting said lines, apparatus at said substations for signaling an exchange operator and having normal and abnormal conditions for said apparatus, a visual recall signal individual to each of said link connectors, an audible recall pilot signal individual to a group of said link connectors, an operator's telephone receiver; means, operative during the time a link connector remains connected to a line, whereby a single change from abnormal to normal condition of said apparatus at a substation of said line and the subsequent single change from normal to abnormal condition of said apparatus operates said visual signal and sounds said audible signal in said receiver, means, operative when said receiver is telephonically connected to a substation line, whereby said signals are not sounded until said receiver is telephonically disconnected from said line; and manually controlled exchange means whereby said signals are discontinued, until the condition of said apparatus is again changed as described.
14. A telephone exchange system including telephone lines extending from substations to an exchange, link connectors for connecting said lines, apparatus at said substations for signaling an exchange operator and having normal and abnormal conditions for said apparatus, a supervisory lamp for each of said link connectors, an audible recall pilot signal individual to a group of said link connectors; means, operative during the time a link connector remains connected to a line, whereby a single change from abnormal to normal condition of said apparatus at a substation of said line causes

said lamp to be steadily illuminated and the subsequent single change from normal to abnormal condition of said apparatus causes the illumination of said lamp to periodically fluctuate and said signal to be sounded, and manually controlled exchange means whereby said signal is discontinued, until the condition of said apparatus is again changed as described.

15. A telephone exchange system including telephone lines extending from substations to an exchange, link connectors for connecting said lines, apparatus at said substations for signaling an exchange operator and having normal and abnormal conditions for said apparatus, a supervisory lamp for each of said link connectors, an audible recall pilot signal individual to a group of said link connectors, an operator's telephone receiver; means, operative during the time a link connector remains connected to a line, whereby a single change from abnormal to normal condition of said apparatus at a substation of said line causes said lamp to be steadily illuminated and the subsequent single change from normal to abnormal condition of said apparatus causes the illumination of said lamp to periodically fluctuate, and said signal to be sounded in said receiver, means, operative when said receiver is telephonically connected to a substation line, whereby said signal is not sounded until said receiver is telephonically disconnected from said line; and manually controlled exchange means whereby the periodical fluctuation of said lamp and the sounding of said signal is discontinued, until the condition of said apparatus is again changed as described.

16. A telephone exchange system including telephone lines extending from substations to an exchange, link connectors for connecting said lines, apparatus at said substations for signalling an exchange operator and having normal and abnormal conditions for said apparatus, a recall signal circuit, a calling and a called line supervisory relay and two other relays for each of said link connectors; means, operative during the time a link connector is connected to a calling line, whereby the abnormal condition of said apparatus at a substation of said calling line energizes its supervisory relay and a subsequent change from abnormal to normal condition of said apparatus de-energizes said relay, thereby energizing one of said other relays; means, other than said supervisory relay, for thereafter maintaining said other relay energized during said connection; means, including said other relay, whereby the subsequent re-energization of said supervisory relay during said connection, by the subsequent change of said apparatus from normal to abnormal condition, closes said recall signal circuit; means,

- operative during the time said link connector is connected to a called line, whereby a change from normal to abnormal condition of said apparatus at the called substation energizes said called line supervisory relay and the other of said two other relays; and means whereby said last mentioned relay may be energized at the same time as said first mentioned other relay.
17. A telephone exchange system including telephone lines extending from substations to an exchange, link connectors for connecting said lines, apparatus at said substations for signaling an exchange operator and having normal and abnormal conditions for said apparatus, a recall signal circuit, a supervisory relay and two other relays for each of said link connectors; means, operative during the time a link connector is connected to a called line, whereby a change from normal to abnormal condition of said apparatus at a substation of said line energizes said supervisory relay and a subsequent change from abnormal to normal condition of said apparatus closes said disconnect circuit and de-energizes said relay, thereby energizing said other relay; means, other than said supervisory relay, for thereafter maintaining said other relay energized during said connection; means, including said other relay, whereby the subsequent re-energization of said supervisory relay during said connection, by the subsequent change of said apparatus from normal to abnormal condition, closes said recall signal circuit and energizes said relay included therein, thereby opening said disconnect signal circuit.
18. A telephone exchange system including telephone lines extending from substations to an exchange, link connectors for connecting said lines, apparatus at said substations for signaling an exchange operator and having normal and abnormal conditions for said apparatus, a recall signal circuit, a supervisory relay and two other relays for each of said link connectors; means, operative during the time a link connector is connected to a called line, whereby a change from normal to abnormal condition of said apparatus at a substation of said line energizes said supervisory relay, thereby energizing one of said other relays; means, other than said supervisory relay, for thereafter maintaining said relay energized during said connection; means, whereby the subsequent change from abnormal to normal condition of said apparatus de-energizes said supervisory relay and by means of said other relay energizes the third of said relays; means, other than said supervisory relay, for thereafter maintaining said third mentioned relay energized during said connection; and means, including said third mentioned relay, whereby the re-energization of said supervisory relay by the subsequent change from normal to abnormal condition of said apparatus closes said recall signal circuit; and manually operated exchange means, whereby said second and third mentioned relays may be de-energized, during an established connection with said link connector, thereby opening said recall signal circuit.
19. A telephone exchange system including telephone lines extending from substations to an exchange, link connectors for connecting said lines, apparatus at said substations for signaling an exchange operator and having normal and abnormal conditions for said apparatus, a recall signal circuit, a supervisory relay and two other relays for each of said link connectors; means, operative during the time a link connector is connected to a called line, whereby a change from normal to abnormal condition of said apparatus at a substation of said line energizes said supervisory relay, thereby energizing one of said other relays; means, other than said supervisory relay, for thereafter maintaining said relay energized during said connection; means whereby the subsequent change from abnormal to normal condition of said apparatus de-energizes said supervisory relay and by means of said other relay energizes the third of said relays; means, other than said supervisory relay, for thereafter maintaining said third mentioned relay energized during said connection; and means, including said third mentioned relay, whereby the re-energization of said supervisory relay by the subsequent change from normal to abnormal condition of said apparatus closes said recall signal circuit; and manually operated exchange means, whereby said second and third mentioned relays may be de-energized, during an established connection with said link connector, thereby opening said recall signal circuit.
20. A telephone exchange system including telephone lines extending from substations to an exchange, link connectors for connecting said lines, apparatus at said substations for signaling an exchange operator and having normal and abnormal conditions for said apparatus, a disconnect pilot signal and a recall pilot signal, individual to a group of said link connectors; means, operative during the time a link connector remains connected to a line whereby a change from abnormal to normal condition of said apparatus at a substation of said line operates said disconnect pilot signal and a subsequent change from normal to abnormal condition of said apparatus operates said recall pilot signal; and means whereby said disconnect signal cannot be operated at the same time as said recall signal.
21. A telephone exchange system including telephone lines extending from substations to an exchange, link connectors for connecting said lines, apparatus at said substations for signaling an exchange operator and having normal and abnormal conditions for said apparatus, an audible disconnect pilot signal and an audible recall pilot signal.

individual to a group of said link connectors, an operator's telephone receiver; means, operative during the time a link connector remains connected to a line whereby 5 a single change from abnormal to normal condition of said apparatus at a substation of said line sounds said disconnect pilot signal in said receiver and a subsequent change from normal to abnormal condition 10 of said apparatus sounds said recall pilot signal in said receiver; and means to prevent the sounding of but one of said signals at the same time.

22. A telephone exchange system including 15 telephone lines extending from substations to an exchange, link connectors for connecting said lines, apparatus at said substations for signaling an exchange operator and having normal and abnormal conditions 20 for said apparatus, an audible disconnect pilot signal and an audible recall pilot signal individual to a group of said link connectors, an operator's telephone receiver; means, operative during the time a link connector remains connected to a line whereby 25 a single change from abnormal to normal condition of said apparatus at a substation of said line sounds said disconnect pilot signal in said receiver and a subsequent change from normal to abnormal condition 30 of said apparatus sounds said recall signal in said receiver; means to prevent the sounding of said disconnect signal when said recall signal is sounded; and means, operative 35 whenever said receiver is telephonically connected to a substation line, whereby neither of said signals are sounded until said receiver is telephonically disconnected from said line.

40 23. A telephone exchange system including 45 telephone lines extending from substations to an exchange switchboard having a line signal for each line, link connectors for connecting said lines, apparatus at said substations for signaling an exchange operator and having normal and abnormal conditions 50 for said apparatus, a visual disconnect signal individual to each of said link connectors, an audible disconnect signal and a circuit therefor individual to a group of said link connectors, an operator's telephone receiver; means, operative during the time 55 a link connector remains connected to a line whereby a single change from abnormal to normal condition of said apparatus at a substation of said line operates said visual signal, closes said circuit and sounds said audible signal in said receiver; and means, operative when said receiver is telephonically 60 connected to a substation line or when one of said line signals is energized, whereby said circuit is maintained opened and said signal is not sounded until said receiver is telephonically disconnected from said line 65 or said line signal is deenergized.

24. A telephone exchange system including 70 telephone lines extending from substations to an exchange switchboard having a line signal for each line, link connectors for connecting said lines, apparatus at said substations for signaling an exchange operator and having normal and abnormal conditions 75 for said apparatus; a disconnect pilot signal, a recall pilot signal and a line pilot signal individual to a group of said link connectors; means, operative during the time a link connector remains connected to a line, whereby a single change from abnormal to normal condition of said apparatus at a substation of said line operates said 80 disconnect signal; means whereby a subsequent single change from normal to abnormal condition of said apparatus operates said recall signal; means, operative whenever said recall pilot signal or said line pilot signal is operated, to prevent the operation of said disconnect signal; and means, operative whenever said recall signal is operated, to prevent the operation of said line pilot signal. 90

25. A telephone exchange system including 95 telephone lines extending from substations to an exchange, link connectors for connecting said lines, apparatus at said substations for signaling an exchange operator and having normal and abnormal conditions for said apparatus, a disconnect signal circuit, a supervisory relay and another relay for each of said link connectors; means, operative during the time a link connector 100 is connected to a called line, whereby a change from normal to abnormal condition of said apparatus at a substation of said line energizes said supervisory relay, thereby closing a circuit through and energizing 105 said other relay; means, other than said supervisory relay and including a locking winding on said relay, for thereafter maintaining said relay energized during said connection; means, whereby the subsequent 110 change from abnormal to normal condition of said apparatus de-energizes said supervisory relay and by means of said other relay closes said disconnect signal circuit; and means whereby the re-energization of said 115 supervisory relay by the subsequent change from normal to abnormal condition of said apparatus opens said disconnect signal circuit. 120

26. A telephone exchange system including 125 telephone lines extending from substations to an exchange switchboard having a line signal for each line, link connectors for connecting said lines, apparatus at said substations for signaling an exchange operator and having normal and abnormal conditions for said apparatus; an audible disconnect pilot signal, an audible recall pilot signal and an audible line pilot signal individual to a group of said link connectors; an oper- 130

ator's telephone receiver; means, operative during the time a link connector remains connected to a line, whereby a single change from abnormal to normal condition of said apparatus at a substation of said line sounds said disconnect signal in said receiver, means whereby a subsequent single change from normal to abnormal condition of said apparatus sounds said recall signal in said receiver; means, operative whenever said recall pilot signal or said line pilot signal is sounded, to prevent the sounding of said disconnect signal; means, operative whenever said recall signal is sounded, to prevent the sounding of said line pilot signal; and means, operative whenever said receiver is telephonically connected to a substation line, to prevent the sounding of any of said signals in said receiver.

20 27. A telephone exchange system including telephone lines extending from substations to an exchange switchboard having a line signal for each line, link connectors for connecting said lines, apparatus at said substations for signaling an exchange operator and having normal and abnormal conditions for said apparatus; a pilot disconnect signal and an operating circuit therefor including the normally engaged contacts of a relay, a line pilot signal and an operating circuit therefor including the normally engaged contacts of another relay and a winding of said first mentioned relay, a recall pilot signal and an operating circuit therefor including windings of both of said relays, all individual to a group of said link connectors; means, operative during the time a link connector remains connected to a line, whereby a single change from abnormal to normal condition of said apparatus at a substation of said line closes said disconnect signal circuit and operates said disconnect signal, means whereby a subsequent single change from normal to abnormal condition of said apparatus closes said recall signal circuit, energizes said relays and operates said recall signal, the energization of said relays opening the circuits and preventing the operation of said disconnect and line pilot signals; means whereby the operation of one of a plurality of said line signals closes said line pilot signal circuit, energizes said relay included in said circuit and operates said line pilot signal, the energization of said relay opening the circuit and preventing the operation of said disconnect signal.

28. A telephone exchange system including telephone lines extending from substations to an exchange switchboard having a line signal for each line, link connectors for connecting said lines, apparatus at said substations for signaling an exchange operator and having normal and abnormal conditions for said apparatus; an audible dis-

connect pilot signal and an operating circuit therefor comprising a source of fluctuating current, the normally engaged contacts of a relay and the primary of an induction coil, circuit closing means for said circuit under the control of said apparatus at a connected substation; an audible line pilot signal and an operating circuit therefor comprising a source of fluctuating current of different quality from said first mentioned source, the normally engaged contacts of another relay, a winding of said first mentioned relay and said primary, circuit closing means for said circuit under the control of any of a group of said line signals; an audible recall pilot signal and an operating circuit therefor comprising a source of fluctuating current of different quality from said first and second mentioned sources, windings of both of said relays and said primary, circuit closing means for said circuit under the control of said apparatus at a connected substation; all of said signals and circuits being individual to a group of said link connectors; an operator's telephone receiver in inductive relation to said primary; whereby a change from abnormal to normal condition of said apparatus at a substation connected to any one of said link connectors operates said disconnect circuit closing means, thereby producing an audible signal in said receiver; whereby a change from normal to abnormal condition of said apparatus at a substation connected to any one of said link connectors operates said recall circuit closing means, thereby energizing said relays and preventing the closing of said disconnect and line pilot signal circuits and also sounding an audible signal in said receiver distinct in character from said disconnect signal and whereby the operation of any one of said line signals in said group operates said line pilot circuit closing means, thereby energizing said relay included in said circuit and preventing the closing of said disconnect signal circuit and also sounding an audible signal in said receiver distinct in character from either said disconnect or recall signal; and means, operating whenever said receiver is telephonically connected to a substation line, to prevent the closing of any of said operating circuits and consequently the sounding of any of said signals in said receiver.

29. A telephone exchange system including telephone lines extending from substations to an exchange, link connectors for connecting said lines, apparatus at said substations for signaling an exchange operator and having normal and abnormal conditions for said apparatus, a visual disconnect and recall signal individual to each of said link connectors, means operative during the time a link connector remains connected to a calling and a called line whereby a single change

from abnormal condition to normal condition of said apparatus at a substation of either of said lines operates said signal to indicate a disconnect and the subsequent 5 single change from normal to abnormal condition of said apparatus operates said signal to indicate a recall, and operator controlled means to discontinue said recall signal without removing said link connector from connection with said lines.

30. A telephone exchange system including telephone lines extending from substations to an exchange, link connectors for connecting said lines, apparatus at said substations for signaling an exchange operator and having normal and abnormal conditions for said apparatus, a disconnect signal individual to each of said link connectors, an audible recall pilot signal associated with 15 and individual to a group of said link connectors; means operative during the time a link connector remains connected to a line, whereby a single change from abnormal to normal condition of said apparatus at a substation of said line operates said disconnect signal and the subsequently single change from normal to abnormal condition of said apparatus sounds said recall signal; and operator controlled means for preventing the 20 sounding of said recall signal when said last mentioned change of said apparatus is made.

31. A telephone exchange system including telephone lines extending from substations to an exchange, link connectors for connecting said line, apparatus at said substations for signaling an exchange operator and having normal and abnormal conditions for said apparatus, a disconnect signal individual to each of said link connectors, an audible recall pilot signal individual to a group of said link connectors, an operator's telephone receiver; means operative during the time a link connector remains connected 40 to a line, whereby a single change from abnormal to normal condition of said apparatus at a substation of said line operates said disconnect signal and the subsequent single change from normal to abnormal condition 45 of said apparatus sounds said recall signal in said receiver; and means, operative when said receiver is telephonically connected to a substation line, whereby said recall signal is not sounded until said receiver is telephonically disconnected from said line.

32. A telephone exchange system including telephone lines extending from substations to an exchange, link connectors for connecting said lines, apparatus at said substations for signaling an exchange operator and having normal and abnormal conditions for said apparatus, a visual disconnect signal and a visual recall signal individual to each of said link connectors, an audible 60 recall signal individual to a group of said

link connectors, an operator's telephone receiver; means operative during the time a link connector remains connected to a line, whereby a single change from abnormal to normal condition of said apparatus at a substation of said line operates said disconnect signal and the subsequent single change from normal to abnormal condition of said apparatus operates said visual recall signal and sounds said audible signal in said receiver; and means, operative when said receiver is telephonically connected to a substation line, whereby said audible signal is not sounded until said receiver is telephonically disconnected from said line.

33. A telephone exchange system including telephone lines extending from substations to an exchange, link connectors for connecting said lines, apparatus at said substations for signaling an exchange operator and having normal and abnormal conditions for said apparatus, a visual disconnect signal and a visual recall signal individual to each of said link connectors, an audible recall signal individual to a group of said link connectors, an operator's telephone receiver; means operative during the time a link connector remains connected to a line, whereby a single change from abnormal to normal condition of said apparatus at a substation of said line operates said disconnect signal and the subsequent single change from normal to abnormal condition of said apparatus eliminates said disconnect signal, operates said visual recall signal and sounds 100 said audible signal in said receiver; and means, operative when said receiver is telephonically connected to a substation line, whereby said audible signal is not sounded until said receiver is telephonically disconnected from said line.

34. A telephone exchange system including telephone lines extending from substations to an exchange, link connectors for connecting said line, apparatus at said substations for signaling an exchange operator and having normal and abnormal conditions for said apparatus, a visual disconnect signal and a visual recall signal for each of said link connectors, an audible disconnect signal and an audible recall signal individual to a group of said link connectors; and means, operative during the time a link connector remains connected to a line, whereby a single change from abnormal to 110 normal condition of said apparatus at a substation of said line operates said visual disconnect signal and sounds said audible disconnect signal and the subsequent single change from normal to abnormal condition 115 of said apparatus eliminates both of said disconnect signals, operates said visual recall signal and sounds said audible recall signal.

35. A telephone exchange system includ-

- ing telephone lines extending from substations to an exchange, link connectors for connecting said lines, apparatus at said substations for signaling an exchange operator 5 and having normal and abnormal conditions for said apparatus, a visual disconnect signal and a visual recall signal for each of said link connectors, an audible disconnect signal and an audible recall signal individual to a 10 group of said link connectors, an operator's telephone receiver; means, operative during the time a link connector remains connected to a line, whereby a single change from abnormal to normal condition of said apparatus 15 at a substation of either of said lines operates said disconnect signal and the subsequent single change from normal to abnormal condition of said apparatus 20 apparatus eliminates both of said disconnect signals, operates said visual recall signal and sounds said audible disconnect signal in said receiver and the subsequent single change from normal to abnormal condition of said apparatus 25 at a substation of said line operates said visual disconnect signal and sounds said audible disconnect signal in said receiver and means, operative when said receiver is telephonically connected to a substation line, whereby neither of said audible signals is sounded until said receiver is telephonically disconnected from said line. 36. A telephone exchange system including telephone lines extending from substations to an exchange, link connectors for connecting said lines, apparatus at said substations for signaling an exchange operator and having normal and abnormal conditions for said apparatus, a visual disconnect signal 35 and a visual recall signal for each of said link connectors, an audible disconnect signal and an audible recall signal individual to a group of said link connectors, an operator's telephone receiver; means, operative during 40 the time a link connector remains connected to a line, whereby a single change from abnormal to normal condition of said apparatus at a substation of said line operates said visual disconnect signal and sounds said audible disconnect signal in said receiver and the subsequent single change from normal to abnormal condition of said apparatus eliminates both of said disconnect signals, operates said visual recall signal and sounds said 45 audible recall signal in said receiver; means, operative when said receiver is telephonically disconnected to a substation line, whereby neither of said audible signals is sounded until said receiver is telephonically 50 connected from said line; and operator controlled means whereby both of said recall signals are discontinued, during an established connection by way of said link connector, until the condition of said apparatus 55 is again changed as described. 37. A telephone exchange system including telephone lines extending from substations to an exchange, link connectors for connecting said lines, apparatus at said substations for signaling an exchange operator 60 and having normal and abnormal conditions for said apparatus, a disconnect pilot signal, a recall pilot signal individual to a group of said link connectors; and means, operative during the time a link connector remains connected to a calling and a called line, whereby a single change from abnormal to normal condition of said apparatus at a substation of either of said lines operates said disconnect signal and the subsequent single change from normal to abnormal condition of said apparatus 65 apparatus eliminates both of said disconnect signals, operates said visual recall signal and sounds said audible disconnect signal in said receiver and means, operative when said receiver is telephonically connected to a substation line, whereby neither of said audible signals is sounded until said receiver is telephonically disconnected from said line. 38. A telephone exchange system including telephone lines extending from substations to an exchange, link connectors for connecting said lines, apparatus at said substations for signaling an exchange operator and having normal and abnormal conditions for said apparatus, a visual disconnect pilot signal and a visual recall pilot signal individual to a group of said link connectors; and means, operative during the time a link connector remains connected to a line, whereby a single change from abnormal to normal condition of said apparatus at a substation of said line operates said disconnect signal and the subsequent single change from normal to abnormal condition of said apparatus prevents said disconnect signal from being operated and operates said recall signal. 39. A telephone exchange system including telephone lines extending from substations to an exchange, link connectors for connecting said lines, apparatus at said substations for signaling an exchange operator and having normal and abnormal conditions for said apparatus, an audible disconnect pilot signal and an audible recall pilot signal individual to a group of said link connectors; and means, operative during the time a link connector remains connected to a line, whereby a single change from abnormal to normal condition of said apparatus at a substation of said line sounds said disconnect signal and the subsequent single change from normal to abnormal condition of said apparatus sounds said recall signal and prevents the sounding of said disconnect signal. 40. A telephone exchange system including telephone lines extending from substations to an exchange, link connectors for connecting said lines, apparatus at said substations for signaling an exchange operator and having normal and abnormal conditions for said apparatus, an audible disconnect pilot signal, an audible recall pilot signal individual to a group of said link connectors, an operator's telephone receiver; and means, operative during the time a link connector remains connected to a line, whereby a single change from abnormal to normal

condition of said apparatus at a substation of said line sounds said disconnect signal in said receiver and the subsequent single change from normal to abnormal condition 5 of said apparatus prevents said disconnect signal from being sounded and sounds said recall signal in said receiver.

41. A telephone exchange system including telephone lines extending from substations to an exchange, link connectors for connecting said lines, apparatus at said substations for signaling an exchange operator and having normal and abnormal conditions for said apparatus, a supervisory lamp for 15 each of said link connectors, an audible disconnect pilot signal and an audible recall pilot signal individual to a group of said link connectors; and means, operative during the time a link connector remains connected to a line, whereby a single change from abnormal to normal condition of said apparatus at a substation of said line causes said lamp to be steadily illuminated and said disconnect signal to be sounded and the subsequent single change from normal to abnormal condition of said apparatus causes the illumination of said lamp to periodically fluctuate and sounds said recall signal instead of said disconnect signal.

42. A telephone exchange system including telephone lines extending from substations to an exchange, link connectors for connecting said lines, apparatus at said substations for signaling an exchange operator and having normal and abnormal conditions for said apparatus, a supervisory lamp for 35 each of said link connectors, an audible disconnect pilot signal and an audible recall pilot signal individual to a group of said link connectors, an operator's telephone receiver; means, operative during the time a link connector remains connected to a line, whereby a single change from abnormal to normal condition of said apparatus at a substation of said line causes said lamp to be steadily illuminated and said disconnect signal to be sounded in said receiver and the subsequent single change from normal to abnormal condition of said apparatus causes the illumination of said lamp to periodically fluctuate and sounds said recall signal in said receiver instead of said disconnect signal; and means, operative when said receiver is telephonically connected to a 50 substation line, whereby neither of said signals is sounded until said receiver is telephonically disconnected from said line.

43. A telephone exchange system including telephone lines extending from substations to an exchange, link connectors for connecting said lines, apparatus at said substations for signaling an exchange operator and having normal and abnormal conditions for said apparatus, a supervisory lamp 65 for each of said link connectors, an audible

disconnect pilot signal and an audible recall pilot signal individual to a group of said link connectors, an operator's telephone receiver; means, operative during the time a link connector remains connected to a line, whereby a single change from abnormal to normal condition of said apparatus at a substation of said line causes said lamp to be steadily illuminated and said disconnect signal to be sounded in said receiver and the subsequent single change from normal to abnormal condition of said apparatus causes the illumination of said lamp to periodically fluctuate and sounds said recall signal in said receiver instead of said disconnect signal; means, operative when said receiver is telephonically connected to a substation line, whereby neither of said signals is sounded until said receiver is telephonically disconnected from said line; and operator controlled means whereby said fluctuating illumination of said lamp and said sounding of said recall signal is discontinued, during an established connection by way of said link connector, until the condition of said apparatus is again changed as described.

44. A telephone exchange system, including telephone lines extending from substations to an exchange switchboard, a plurality of pilot signals operable at an operator's position of said switchboard, an operating circuit for each of said signals, a plurality of relays for said position, each relay controlling one of said signals; means for operating said signals; means to give precedence to each of said signals in a regular sequence, comprising means, operative whenever one of said signals is operated superior in order of precedence established by said sequence to another signal or other signals, to operate the relay or relays controlling said other signal or signals inferior in order of precedence, thereby opening said circuit or circuits of said last mentioned signal or signals.

45. A telephone exchange system including telephone lines extending from substations to an exchange, link connectors for connecting said lines, apparatus at said substations for signaling an exchange operator and having normal and abnormal conditions for said apparatus, a disconnect signal circuit and a recall signal circuit; a supervisory relay and two other relays for each of said link connectors; means, operative during the time a link connector is connected to a called line, whereby a change from normal to abnormal condition of said apparatus at a substation of said line energizes said supervisory relay, thereby closing a circuit through and energizing one of said other relays; means, other than said supervisory relay and comprising a locking winding, for thereafter maintaining said relay energized

5 during said connection; means, whereby the subsequent change from abnormal to normal condition of said apparatus de-energizes said supervisory relay and by means
 10 of said other relay closes said disconnect signal circuit and energizes the third of said relays; means, other than said supervisory relay, for thereafter maintaining said third mentioned relay energized during said connection; and means, including said third
 15 mentioned relay, whereby the re-energization of said supervisory relay by the subsequent change from normal to abnormal condition of said apparatus opens said disconnect signal circuit and closes said recall signal circuit.

46. A telephone exchange system including telephone lines extending from substations to an exchange, an operator's telephone equipment including a receiver, a plurality of link connectors for connecting calling and called substations, talking strands for said connectors; means for normally connecting said strands of all of said link connectors to said equipment only, whereby when one of said link connectors is connected to a calling line said receiver is telephonically connected thereto exclusively; means to prevent said receiver from being shunted by instrumentalities associated with the other link connectors of said plurality; and means, operative upon said link connector being connected to a called line for disconnecting said equipment from said strands of said link connector and telephonically connecting the calling and called substations.

47. A telephone exchange system including telephone lines extending from substations to an exchange, an operator's telephone equipment including a receiver, a plurality of link connectors for connecting calling and called substations, talking strands for said connectors; means for normally connecting said strands of all of said link connectors to said equipment only, whereby when one of said link connectors is connected to a calling line said receiver is telephonically connected thereto exclusively; means to prevent said receiver from being shunted by instrumentalities associated with the other link connectors of said plurality; means, operative when said link connector is connected to a called line for disconnecting said equipment from said strands of said link connector and telephonically connecting the calling and called substations; and means under the control of said calling substation whereby said equipment may be again connected to said strands during an established connection between said substations by way of said link connector.

48. A telephone exchange system including telephone lines extending from substations to an exchange, an operator's telephone

equipment including a receiver, a plurality of link connectors for connecting calling and called substations, talking strands for said connectors; means for normally connecting said strands of all of said link connectors to said equipment only, whereby when one of said link connectors is connected to a calling line said receiver is telephonically connected thereto exclusively; means to prevent said receiver from being shunted by instrumentalities associated with the other link connectors of said plurality; means, operative when said link connector is connected to a called line for disconnecting said equipment from said strands of said link connector and telephonically connecting the calling and called substations; and means under the control of said called substation whereby said equipment may be again connected to said strands during an established connection between said substations by way of said link connector.

49. A telephone exchange system including telephone lines extending from substations to an exchange, link connectors for connecting said lines, apparatus at said substations for signaling an exchange operator, an operator's telephone set normally connected telephonically to a group of said link connectors; means for automatically telephonically disconnecting said set from one of said link connectors when the link connector is connected to a called line; and manually operated exchange means controlled by said apparatus at either a calling or a called substation only, during an established connection therebetween, whereby said set may be again telephonically connected to said link connector, during an established connection therewith.

50. A telephone exchange system including telephone lines extending from substations to an exchange, link connectors for connecting said lines, apparatus at said substations for signaling an exchange operator, an operator's telephone set normally connected telephonically to a group of said link connectors; means for automatically telephonically disconnecting said set from one of said link connectors when the link connector is connected to a called line; and manually operated exchange means controlled by said apparatus at the calling substation during an established connection therefrom, whereby said set may be again telephonically connected to said link connector, during an established connection of said link connector to the calling and the called lines.

51. A telephone exchange system including telephone lines extending from substations to an exchange, link connectors for connecting said lines, apparatus at said substations for signaling an exchange operator, an operator's telephone set normally con-

nected telephonically to a group of said link connectors; means for automatically telephonically disconnecting said set from one of said link connectors when the link 5 connector is connected to a called line; and manually operated exchange means controlled by said apparatus at the called substation during an established connection thereto, whereby, said set may be again telephonically connected to said link connector, during an established connection of said link connector to the calling and the called lines.

52. A telephone exchange system including telephone lines extending from substations to an exchange, link connectors for connecting said lines, talking strands and a relay individual to each of said link connectors, a source of electric energy, an operator's telephone equipment including a receiver; means whereby said source is normally connected to the talking strands of a group of said link connectors exclusively by way of said equipment; means whereby said receiver is normally connected telephonically to said group; and means, operative when a link connector is connected to a called line, whereby said relay is caused to disconnect said strands from said equipment and connect them telephonically to the calling and called lines.

53. A telephone exchange system including telephone lines extending from substations to an exchange, link connectors for connecting said lines, talking strands and a relay individual to each of said link connectors, a source of electric energy, an operator's telephone set; means whereby said source is connected to the talking strands of said link connectors; means whereby said set is normally connected telephonically to said strands of a group of said link connectors; means, operative when a link connector is connected to a called line, whereby said relay is caused to disconnect said strands from said set and connect them telephonically to the calling and called lines; and manually operated exchange means for causing said relay to re-connect said set to said strands during an established connection of said link connector to the connected lines.

54. A telephone exchange system including telephone lines extending from substations to an exchange, link connectors for connecting said lines, talking strands and a relay individual to each of said link connectors, a source of electric energy, an operator's telephone equipment including a receiver; means whereby said source is normally connected to the talking strands of a group of said link connectors exclusively by way of said equipment; means whereby said receiver is normally connected telephonically to said group; and means, operative when a link connector is connected to a called line,

whereby said relay is caused to disconnect said strands from said equipment and connect them telephonically to the calling and called lines without disconnecting said source from said strands.

55. A telephone exchange system including telephone lines extending from substations to an exchange, link connectors comprising talking strands for connecting said lines, apparatus at said substations for signaling an exchange operator and having normal and abnormal conditions for said apparatus, a supervisory relay and a non-inductive resistance shunt for voice currents normally connected around said relay and included in a talking strand of each of said link connectors; and means, operative during the time a link connector remains connected to a calling line, whereby a change from abnormal to normal condition of said apparatus at a substation of said line removes said shunt, thereby allowing a freer operation of said relay should said apparatus be again changed from normal to abnormal condition.

56. A telephone exchange system including telephone lines extending from substations to an exchange, link connectors comprising talking strands for connecting said lines, apparatus at said substations for signaling an exchange operator and having normal and abnormal conditions for said apparatus; a supervisory relay and a non-inductive resistance shunt for voice currents normally connected around said relay and included in a talking strand of each of said link connectors, another relay for each of said link connectors; means, operative during the time a link connector is connected to a calling line, whereby the abnormal condition of said apparatus at a substation of said line energizes said supervisory relay and a subsequent change from abnormal to normal condition of said apparatus de-energizes said relay, thereby energizing said other relay, the energization of said other relay removing said shunt from around said supervisory relay, thereby allowing a freer operation of said relay should said apparatus be again changed from normal to abnormal condition; and means, other than said supervisory relay, for thereafter maintaining said other relay energized during said connection.

57. A telephone exchange system including telephone lines extending from substations to an exchange, link connectors comprising talking strands for connecting said lines, apparatus at said substations for signaling an exchange operator and having normal and abnormal conditions for said apparatus; a supervisory relay and a non-inductive resistance shunt for voice currents normally connected around said relay and included in a talking strand of each of said link connectors, another relay for each of

- 5 said link connectors; means, operative during the time a link connector is connected to a calling line, whereby the abnormal condition of said apparatus at a substation of said line energizes said supervisory relay and a subsequent change from abnormal to normal condition of said apparatus de-energizes said relay, thereby energizing said other relay, the energization of said other relay removing said shunt from around said supervisory relay, thereby allowing a freer operation of said relay should said apparatus be again changed from normal to abnormal condition; means, other than said supervisory relay, for 10 thereafter maintaining said other relay energized during said connection; and manually operated means, whereby said other relay may be de-energized without disconnecting said link connector from said line, thereby 15 20 restoring said shunt around said supervisory relay.
58. A telephone exchange system including telephone lines extending from substations to an exchange, link connectors comprising talking strands for connecting said lines, apparatus at said substations for signaling an exchange operator and having normal and abnormal conditions for said apparatus, a supervisory relay and a non-inductive resistance shunt for voice currents adapted to be connected around said relay and included in a talking strand of each of said link connectors, two other relays for 25 each of said link connectors; means, operative during the time a link connector is connected to a called line, whereby a change from normal to abnormal condition of said apparatus at a substation of said line energizes said supervisory relay, thereby energizing one of said other relays and connecting said shunt around said supervisory relay; means, other than said supervisory relay, for 30 thereafter maintaining said relay energized during said connection; means whereby the subsequent change from abnormal to normal condition of said apparatus de-energizes said supervisory relay and energizes the third of said relays, the energization of said 35 40 relay removing said shunt from around said supervisory relay, thereby allowing a freer operation of said relay should said apparatus be again changed to its abnormal condition.
59. A telephone exchange system including telephone lines extending from substations to an exchange, link connectors comprising talking strands for connecting said lines, apparatus at said substations for signaling an exchange operator and having normal and abnormal conditions for said apparatus; a supervisory relay and a non-inductive resistance shunt for voice currents adapted to be connected around said relay and included in a talking strand of each of said link connectors, two other relays for 45 each of said link connectors; means, operative during the time a link connector is connected to a called line, whereby a change from normal to abnormal condition of said apparatus at a substation of said line energizes said supervisory relay, thereby energizing one of said other relays and connecting said shunt around said supervisory relay; means, other than said supervisory relay, for 50 55 60 65 thereafter maintaining said relay energized during said connection; means whereby the subsequent change from abnormal to normal condition of said apparatus de-energizes said supervisory relay and energizes the third of said relays, the energization of said relay removing said shunt from around said supervisory relay, thereby allowing a freer operation of said relay should said apparatus be again changed to its abnormal condition.
61. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality, an operator's telephone receiver, a test circuit associated with said receiver, which includes said con-

tacts, and one or more of said sources; whereby different audible signals are produced in said receiver, when a test is made, according to the connection of said sources in said circuit; apparatus at said substations for signaling an exchange operator, a normal and abnormal condition for said apparatus, a disconnect signal; and means, operative during the time a link connector 5 remains connected to a line, whereby a change from abnormal to normal condition of said apparatus at a substation of said line operates said disconnect signal and changes the current included in said test 10 circuit, thereby signaling the connecting operator to disconnect said link connector from said line and signaling a testing operator to that effect.

62. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality, an operator's telephone receiver, a test circuit associated 25 with said receiver, which includes said contacts, and one or more of said sources; whereby different audible signals are produced in said receiver, when a test is made, according to the connection of said sources 30 in said circuit; apparatus at said substations for signaling an exchange operator, a normal and abnormal condition for said apparatus, a disconnect signal; means, operative during the time a link connector remains connected to a line, whereby a change 35 from abnormal to normal condition of said apparatus at a substation of said line operates said disconnect signal and changes the current included in said test circuit, thereby 40 signaling the connecting operator to disconnect said link connector from said line and signaling a testing operator to that effect; and means whereby the association of a calling substation's telephone receiver 45 with said operator's receiver, when a test is made, produces said audible signals in said 50 substation receiver also.

63. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality, an operator's telephone receiver, a test circuit associated 55 with said receiver which includes said contacts, and one or more of said sources;

whereby different audible signals are produced in said receiver, when a test is made, according to the connection of said sources in said circuit; apparatus at said substations for signaling an exchange operator, a 70 normal and abnormal condition for said apparatus, a disconnect signal; and means, operative during the time a link connector remains connected to a called line, whereby a change from normal to abnormal and then to normal condition again of said apparatus at a substation of said line operates said disconnect signal and changes the current included in said test circuit, thereby signaling the connecting operator to disconnect so 75 said link connector from said line and signaling a testing operator to that effect.

64. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality for producing busy and disconnect audible signals, an operator's telephone receiver, a test circuit associated with said receiver which includes said contacts and one or both of said sources; whereby said audible signals are produced in said receiver, when a test is made, according to the connection of said sources in said circuit; apparatus at said substations for signaling an exchange operator, a normal and abnormal condition for said apparatus; and means, operative during the time a link connector remains connected to a line, whereby the abnormal condition of said apparatus at a substation of said line includes current in said test circuit which produces said busy signal and a subsequent change from abnormal to normal condition of said apparatus changes the current included in said circuit so as to produce said disconnect signal, thereby indicating to a testing operator whether a party is using the tested line or is signaling to be disconnected from another line.

65. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality for producing busy, 120 disconnect and recall audible signals, an operator's telephone receiver, a test circuit associated with said receiver which includes said contacts and one or more of said sources; whereby said signals are produced in said re- 125 130

ceiver, when a test is made, according to the connection of said sources in said circuit; apparatus at said substations for signaling an exchange operator, a normal and abnormal condition for said apparatus; and means, operative during the time a link connector remains connected to a line, whereby the abnormal condition of said apparatus at a substation of said line includes current in said test circuit which produces said busy signal, a subsequent change from abnormal to normal condition of said apparatus changes the current included in said circuit so as to produce said disconnect signal and a subsequent change from normal to abnormal condition of said apparatus changes the current included in said circuit so as to produce said recall signal, thereby indicating to a testing operator whether a party is using the tested line, is signaling to be disconnected from another line or is establishing a recall.

66. A telephone exchange system including telephone lines extending from substations to an exchange, link connectors for connecting said lines, a testing contact associated with a strand of each of said link connectors, a test system which includes contacts associated with the line apparatus of said lines and adapted to engage said testing contact when a test is made; sources of current of different quality for producing ringing, talking and disconnect audible signals, an operator's telephone receiver, a test circuit associated with said receiver which includes said contacts and one or more of said sources; whereby said audible signals are produced in said receiver, when a test is made, according to the connection of said sources in said circuit; apparatus at said substations for signaling an exchange operator, a normal and abnormal condition for said apparatus; means, operative when a link connector is connected to a called line, provided said apparatus at a substation thereof is in its normal condition, whereby current is included in said test circuit which produces said ringing signal; means, operative when said apparatus is subsequently changed from normal to abnormal condition, whereby the current included in said circuit is changed so as to produce said talking signal; and means, operative when said apparatus is subsequently changed from abnormal to normal condition, whereby the current included in said circuit is changed so as to produce said disconnect signal, thereby indicating to a testing operator whether the tested line is being rung upon, is being held for conversational purposes or whether a party is signaling to be disconnected from another line.

67. A telephone exchange system including telephone lines extending from substations to an exchange, link connectors for connecting said lines, a supervisory relay

and another relay for each of said link connectors, a plurality of operator's signals controlled by said relays, a source of signaling current; means directly controlled by said other relay when not energized for impressing current from said source on a called line when one of said link connectors is connected thereto; means, under the control of apparatus at a substation of said line, for energizing said supervisory relay, thereby energizing said other relay, the energization of said relay directly opening the circuit to said source, thereby causing the impressions of signaling current on said line to be discontinued and the operator's signal controlled by said supervisory relay to be changed; and means, other than said supervisory relay, for thereafter maintaining said other relay energized during the time said link connector is connected to said line, thereby preventing further impressions of signaling current on said line when said supervisory relay is de-energized under the control of said substation apparatus.

68. A telephone exchange system including telephone lines extending from substations to an exchange, link connectors for connecting said lines, a calling line and a called line supervisory relay, another relay for each of said link connectors; a source of signaling current; means directly controlled by said other relay when not energized for impressing current from said source on a called line when one of said link connectors is connected thereto; means, under the control of apparatus at a substation of said line, for energizing said called line supervisory relay, thereby energizing said other relay, the energization of said relay directly opening the circuit to said source and thereby causing the impressions of signaling current on said line to be discontinued; means, other than said supervisory relay, for thereafter maintaining said other relay energized during the time said link connector is connected to said line, thereby preventing further impressions of signaling current on said line when said supervisory relay is de-energized under the control of said substation apparatus; and means, under the control of apparatus at a calling substation, operative previous to said energization of said called line supervisory relay, whereby the de-energization of said calling line supervisory relay causes said impressions of signaling current to be discontinued, thereby preventing the continued signaling of the called substation when the calling party abandons a call therefor.

69. A telephone exchange system including telephone lines extending from substations to an exchange, link connectors for connecting said lines, a calling line and a called line supervisory relay, a ringing relay for each of said link connectors; a source

of signaling current; a supervisory lamp; means controlled by said ringing relay for impressing current from said source on a called line when one of said link connectors 5 is connected thereto; means for partially illuminating said lamp when said impression takes place; means under the control of apparatus at a substation of said line, for energizing said called line supervisory relay, 10 thereby energizing said ringing relay, the energization of said ringing relay disconnecting the signaling current from said line; means, other than said supervisory relay, for thereafter maintaining said ringing relay energized during the time said link connector is connected to said line, thereby preventing further impressions of signaling current on said line when said supervisory 15 relay is de-energized under the control of said substation apparatus; means, operative when said supervisory relay is de-energized, whereby said lamp is fully illuminated; and means, under the control of apparatus at a calling substation, operative previous to said 20 energization of said called line supervisory relay, whereby the de-energization of said calling line supervisory relay energizes said ringing relay, thereby preventing the continued signaling of the called substation 25 30 when the calling party abandons a call therefor.

70. A telephone exchange system, including telephone lines extending from substations to an exchange switchboard, a plurality of pilot signals operable at an operator's position of said switchboard; means for operating said signals; means to give precedence in operation to each of said signals in a regular sequence; and means, operative whenever one of said signals is operated superior in order of precedence established by said sequence to another signal or other signals, to prevent the operation of the other signal or signals inferior in said order 40 45 of precedence to the operated signal.

71. A telephone exchange system, including telephone lines extending from substations to an exchange switchboard, a plurality of pilot signals operable at an operator's position of said switchboard; means for operating said signals; means to give precedence in operation to each of said signals in a regular sequence; means, operative whenever one of said signals is operated superior in order of precedence established by said sequence to another signal or other signals, to prevent the operation of the other signal or signals inferior in said order of precedence to the operated signal, and means, operative whenever the operator at said position is engaged in connecting said lines, to prevent the operation of all of said signals.

72. A telephone exchange system, including telephone lines extending from substations to an exchange switchboard, a plurality of operators' positions at said switchboard; a plurality of line pilot signals operable at each of said positions; means for operating said signals; means to prevent more than one of said signals from being operated at the same time; means to give precedence in operation to each of said signals in a regular sequence, and means, operative when the operator at said position is engaged in connecting said lines, whereby none of said signals are operated.

tions to an exchange switchboard having a line signal individual to each line, a plurality of link connector and line pilot signals operable at an operator's position of said switchboard; means for operating said signals; means to give precedence in operation to each of said signals in a regular sequence; and means operative whenever one of said signals is operated superior in order of precedence established by said sequence to another signal or other signals, to prevent the operation of the other signal or signals inferior in said order of precedence to the operated signal.

73. A telephone exchange system, including telephone lines extending from substations to an exchange switchboard having a line signal individual to each line, a plurality of link connector and line pilot signals operable at an operator's position of said switchboard; means for operating said signals; means to give precedence in operation to each of said signals in a regular sequence; means, operative whenever one of said signals is operated superior in order of precedence established by said sequence to another signal or other signals, to prevent the operation of the other signal or signals inferior in said order of precedence to the operated signal, and means, operative whenever the operator at said position is engaged in connecting said lines, to prevent the operation of all of said signals.

74. A telephone exchange system, including telephone lines extending from substations to an exchange switchboard; recall, disconnect and line pilot signals operable at an operator's position of said switchboard; means for operating said signals; means to prevent more than one of said signals from being operated at the same time; and means to give precedence in operation to each of said signals in a regular sequence.

75. A telephone exchange system, including telephone lines extending from substations to an exchange switchboard; recall, disconnect and line pilot signals operable at an operator's position of said switchboard; means for operating said signals; means to prevent more than one of said signals from being operated at the same time; means to give precedence in operation to each of said signals in a regular sequence, and means, operative when the operator at said position is engaged in connecting said lines, whereby none of said signals are operated.

76. A telephone exchange system, including telephone lines extending from substations to an exchange switchboard; a plurality of operators' positions at said switchboard; a plurality of line pilot signals operable at each of said positions; means for operating said signals; means to prevent more than one of said signals from being operated at the same time; means to give precedence in operation to each of said signals in a regular sequence, and means, operative when the operator at said position is engaged in connecting said lines, whereby none of said signals are operated.

precedence in operation to each of said signals in a regular sequence; and means, operative when one of said signals is operated, superior in order of precedence to another signal or other signals, whereby the pilot signal or signals, as the case may be, inferior in the order of precedence established by said sequence to said operated signal become operable at another position or positions, as the case may be, at which said signals are also operable.

77. A telephone exchange system, including telephone lines extending from substations to an exchange switchboard; a plurality of operators' positions at said switchboard; a plurality of line pilot signals operable at each of said positions; means for operating said signals; means to prevent more than one of said signals from being operated at the same time; means to give precedence in operation to each of said signals in a regular sequence; means, operative when one of said signals is operated, superior in order of precedence to another signal or other signals, whereby the pilot signal or signals, as the case may be, inferior in the order of precedence established by said sequence to said operated signal become operable at another position or positions, as the case may be, at which said signals are also operable; and means, operative when the operator at a position is engaged in connecting said lines, whereby all of said line pilot signals become operable at said other positions.

78. A telephone exchange system, including telephone lines extending from substations to an exchange switchboard having a line signal individual to each line, a plurality of operators' positions at said switchboard; a plurality of link connector and line pilot signals operable at each of said positions; means for operating said signals; means to prevent more than one of said signals from being operated at the same time; means to give precedence in operation to each of said signals in a regular sequence; and means, operative when one of said signals is operated, superior in order of precedence to another signal or signals, whereby the line pilot signal or signals, as the case may be, inferior in the order of precedence established by said sequence to said operated signal become operable at another position or positions, as the case may be, at which said signals are also operable.

79. A telephone exchange system, including telephone lines extending from substations to an exchange switchboard having a line signal individual to each line, a plurality of operators' positions at said switchboard; a plurality of link connector and line pilot signals operable at each of said positions; means for operating said signals; means to prevent more than one of said sig-

nals from being operated at the same time; means to give precedence in operation to each of said signals in a regular sequence; means, operative when one of said signals is operated, superior in order of precedence

70 to another signal or signals, whereby the line pilot signal or signals, as the case may be, inferior in the order of precedence established by said sequence to said operated signal become operable at another position 75 or positions, as the case may be, at which said signals are also operable, and means, operative when the operator at a position is engaged in connecting said lines, whereby all of said line pilot signals become operable 80 at said other positions.

80. A telephone exchange system, including telephone lines extending from substations to an exchange switchboard, a telephone receiver at an operator's position of 85 said switchboard, a plurality of audible pilot signals operable at said position; means for sounding said pilot signals in said receiver; means to give precedence in sounding to each of said signals in a regular sequence; means 90 operative whenever one of said signals is sounded superior in order of precedence established by said sequence to another signal or other signals, to prevent the sounding of the other signal or signals inferior in said 95 order of precedence to the signal sounded; and means, operative whenever the operator at said position is engaged in connecting said lines, to prevent the sounding of all of 100 said signals.

81. A telephone exchange system, including telephone lines extending from substations to an exchange switchboard having a line signal for each line, a telephone receiver at an operator's position of said switchboard, 105 a plurality of audible link connector and line pilot signals operable at said position; means for sounding said pilot signals in said receiver; means to give precedence in sounding to each of said signals in a regular 110 sequence; means operative whenever one of said signals is sounded superior in order of precedence established by said sequence to another signal or other signals, to prevent the sounding of the other signal or signals inferior in said order of precedence to the signal sounded; and means, operative whenever the operator at said position is engaged in connecting said lines, to prevent the 115 sounding of all of said signals.

82. A telephone exchange system, including telephone lines extending from substations to an exchange switchboard having a line signal individual to each line, a telephone receiver at an operator's position of 125 said switchboard, audible recall, disconnect and line pilot signals operable at said position; means for sounding said pilot signals in said receiver; means to give precedence in sounding to each of said signals in a 130

regular sequence; means, operative whenever one of said signals is sounded superior in order of precedence established by said sequence to another signal or other signals, 5 to prevent the sounding of the other signal or signals inferior in said order of precedence to the signal sounded; and means, operative whenever the operator at said position is engaged in connecting said lines, to 10 prevent the sounding of all of said signals.

83. A telephone exchange system, including telephone lines extending from substations to an exchange switchboard having a line signal individual to each line, a plurality of operators' positions at said switchboard, a telephone receiver individual to each of said positions; a plurality of audible line pilot signals operable at each of said positions; means for sounding said signals 15 in said receivers; means to prevent more than one of said signals from being sounded in one of said receivers at the same time; means to give precedence in sounding to each of said signals in a regular sequence; 20 transferring means, operative when one of said signals is sounded, superior in order of precedence to another signal or other signals, whereby the pilot signal or signals, as the case may be, inferior in the order of 25 precedence established by said sequence to said sounded signal may be sounded in the receiver at another position or positions, as the case may be, at which said signals are also capable of being sounded instead of in 30 said first mentioned receiver; and means operative when the operator at a position is engaged in connecting said lines, whereby all of said line pilot signals may be sounded in the receivers at said other positions instead of in said first mentioned receiver. 35

84. A telephone exchange system, including telephone lines extending from substations to an exchange switchboard having a line signal individual to each line, a plurality of operators' positions at said switchboard, a telephone receiver individual to each of said positions, a plurality of audible link connector and line pilot signals operable at each of said positions; means for sounding 45 said signals in said receivers; means to prevent more than one of said signals from being sounded in one of said receivers at the same time; means to give precedence in sounding to each of said signals in a regular sequence; transferring means, operative when one of said signals is sounded, superior in order of precedence to another signal or other signals, whereby the line pilot signal or signals, as the case may be, inferior in the 55 order of precedence established by said sequence; 60

and means operative when the operator at a position is engaged in connecting said lines, whereby all of said line pilot signals may be sounded in the receivers at said other positions instead of in said first mentioned receiver. 70

85. A telephone exchange system, including telephone lines extending from substations to an exchange switchboard having a line signal individual to each line, a plurality of operators' positions at said switchboard; a line pilot signal for each of said positions; means for operating said signals at each of said positions; means for transferring to each position the pilot signals of other operators' positions and operating said signals thereat; means to prevent the operation of more than one of said signals at the same time; and means to give precedence in operation to each of said signals in a regularly established sequence. 80

86. A telephone exchange system, including telephone lines extending from substations to an exchange switchboard; a plurality of operators' positions at said switchboard and pilot signals individual thereto; means for operating said signals at each of said positions; means for transferring to each position the pilot signals of other operators' positions and operating said signals 90 thereat; means to prevent the operation of more than one of said signals at the same time; means to give precedence in operation to each of said signals in a regularly established sequence; and means, operative when 95 one of said transferred signals is operated, for retransferring the signal or signals, as the case may be, inferior in the order of precedence established by said sequence to said operated signal to another position or positions, as the case may be, at which said signals are also operable. 100

87. A telephone exchange system, including telephone lines extending from substations to an exchange switchboard having a line signal individual to each line, a plurality of operators' positions at said switchboard, a telephone receiver and a line pilot signal for each of said positions; means for sounding said signal in the receiver at each 110 of said positions; means for transferring to each position the pilot signals of other operators' positions and sounding said signals in the receiver thereat; means to prevent the sounding of more than one of said signals 115 at the same time; and means to give precedence in sounding to each of said signals in a regular sequence. 120

88. A telephone exchange system, including telephone lines extending from substations to an exchange switchboard; a plurality of operators' positions at said switchboard, a telephone receiver and a pilot signal for each of said positions; means for sounding said signal in the receiver at each 125 130

of said positions; means for transferring to each position the pilot signals of other operators' positions and sounding said signals in the receiver thereat; means to prevent the 5 sounding of more than one of said signals at the same time; means to give precedence in operation to each of said signals in a regularly established sequence; and means, operative when one of said transferred signals 10 is sounded for re-transferring the signal or signals, as the case may be, inferior in the order of precedence established by said sequence to said sounded signal to another position, or positions, as the case may be, at 15 which said signals are also capable of being sounded.

89. A telephone exchange system, including telephone lines extending from substations to an exchange switchboard having a 20 line signal individual to each line, a plurality of operators' positions at said switchboard, a line pilot signal individual to an operator's position and operated thereat upon the energization of one or more of the 25 line signals of the lines assigned to said position for answering, link connectors at said position for connecting said lines, a disconnect signal operative when one of said link connectors is connected to a line and under 30 the control of apparatus at a substation thereof; means, operative when said disconnect signal is operated, whereby said pilot signal is operated at another of said positions, provided said pilot signal can be 35 attended to thereat; and means, operative at said second mentioned position, provided said pilot signal cannot be attended to thereat, whereby said disconnect signal is prevented from being operated at said first 40 mentioned position and instead said pilot signal is operated thereat.

90. A telephone exchange system, including telephone lines extending from substations to an exchange switchboard having a 45 line signal individual to each line, a plurality of operators' positions at said switchboard, a line pilot signal individual to an operator's position and operated thereat upon the energization of one or more of the 50 line signals of the lines assigned to said position for answering, link connectors at said position for connecting said lines, a disconnect signal operative when one of said link connectors is connected to a line and under 55 the control of apparatus at a substation thereof; means, operative when said disconnect signal is operated, whereby said pilot signal is operated at one of a plurality of other operators' positions at which said pilot signal is operable, provided said pilot 60 signal can be attended to thereat, instead of operated at said first mentioned position; and means, operative when none of said positions can attend to said pilot signal, whereby said pilot signal is operated at said first 65 mentioned position instead of at said second mentioned position.

instead said pilot signal is operated thereat. 91. A telephone exchange system, including telephone lines extending from substations to an exchange switchboard having a line signal individual to each line, a plural- 70 ity of operators' positions at said switchboard, a line pilot signal individual to an operator's position and operated thereat upon the energization of one or more of the line signals of the lines assigned to said position 75 for answering, link connectors at said position for connecting said lines, a disconnect signal operative when one of said link connectors is connected to a line and under the control of apparatus at a substation thereof; 80 means, operative when said disconnect signal is operated, whereby said pilot signal is operated at another of said positions, provided said line pilot signal can be attended to thereat, instead of operated at said first mentioned 85 position; and means, operative at said second mentioned position, provided said pilot signal cannot be attended to thereat, whereby said pilot signal is operated at said first mentioned position instead of at said second 90 mentioned position.

92. A telephone exchange system, including telephone lines extending from substations to an exchange switchboard having a line signal individual to each line, a plural- 95 ity of operators' positions at said switchboard, a line pilot signal individual to an operator's position and operated thereat upon the energization of one or more of the line signals of the lines assigned to said position 100 for answering, link connectors at said position for connecting said lines, a disconnect signal operative when one of said link connectors is connected to a line and under the control of apparatus at a substation 105 thereof; means, operative when said disconnect signal is operated, whereby said pilot signal is operated at one of a plurality of other operators' positions at which said pilot signal is operable, provided said pilot 110 signal can be attended to thereat, instead of operated at said first mentioned position; and means, operative when none of said positions can attend to said pilot signal, whereby said pilot signal is operated at said first 115 mentioned position instead of at said second mentioned position.

93. A telephone exchange system, including telephone lines extending from substations to an exchange switchboard having a line signal individual to each line, a plural- 120 ity of operators' positions at said switchboard, a telephone receiver for each of said positions, link connectors at said position for connecting said lines, a disconnect signal operative when one of said link connectors is connected to a line and under the control of apparatus at a substation thereof; means, operative upon the energization 125 of one or more of the line signals of the 130

lines assigned to said position for answering, whereby an audible pilot signal is sounded in said receiver; and means, operative when said disconnect signal is operated, whereby said pilot signal is sounded in the receiver at another operator's position, provided said pilot signal can be attended to thereat, instead of in said first mentioned receiver; and means, operative at 5 said second mentioned position, provided said pilot signal cannot be attended to thereat, whereby said pilot signal is sounded in said first mentioned receiver instead of in said second mentioned receiver.

15 94. A telephone exchange system, including telephone lines extending from substations to an exchange switchboard having a line signal individual to each line, a plurality of operators' positions at said switchboard, a telephone receiver for each of said positions, link connectors at said position for connecting said lines, a disconnect signal operative when one of said link connectors is connected to a line and under the control 20 of apparatus at a substation thereof; means, operative upon the energization of one or more of the line signals of the lines assigned to said position for answering, whereby an audible pilot signal is sounded in said receiver; means operative when said disconnect signal is operated, whereby said pilot signal is sounded in the receiver at one of a plurality of other operators' positions at which said pilot signal is operable, 25 provided said pilot signal can be attended to thereat, instead of in said first mentioned receiver; and means, operative when none of said positions can attend to said pilot signal, whereby said pilot signal is sounded 30 in said first mentioned receiver instead of in said second mentioned receiver.

95. A telephone exchange system, including telephone lines extending from substations to an exchange switchboard having a line signal individual to each line, a plurality of operators' positions at said switchboard, a telephone receiver for each of said positions, link connectors at said position for connecting said lines, a disconnect signal 45 operative when one of said link connectors is connected to a line and under the control of apparatus at a substation thereof; means, operative upon the energization of one or more of the line signals of the lines assigned to said position for answering, whereby an audible pilot signal is sounded in said receiver; and means, operative when said disconnect signal is operated, whereby said pilot signal is sounded in the receiver 50 at another operator's position, provided said pilot signal can be attended to thereat, instead of in said first mentioned receiver; and means, operative at said second mentioned position, provided said pilot signal 55 cannot be attended to thereat, whereby said

disconnect signal is prevented from being operated at said first mentioned position and said pilot signal is sounded in said first mentioned receiver instead of in said second mentioned receiver.

96. A telephone exchange system, including telephone lines extending from substations to an exchange switchboard having a line signal individual to each line, a plurality of operators' positions at said switchboard, a telephone receiver for each of said positions, link connectors at said position for connecting said lines, a disconnect signal operative when one of said link connectors is connected to a line and under the control 70 of apparatus at a substation thereof; means, operative upon the energization of one or more of the line signals of the lines assigned to said position for answering, whereby an audible pilot signal is sounded in said receiver; means, operative when said disconnect signal is operated, whereby said pilot signal is sounded in the receiver at one of a plurality of other operators' positions at which said pilot signal is operable, 75 provided said pilot signal can be attended to thereat, instead of in said first mentioned receiver; and means, operative when none of said positions can attend to said pilot signal, whereby said disconnect 80 signal is prevented from being operated at said first mentioned position and said pilot signal is sounded in said first mentioned receiver instead of said second mentioned receiver.

97. A telephone exchange system, including telephone lines extending from substations to an exchange switchboard having a line signal individual to each line, a plurality of operators' positions at said switchboard, pilot signal operating means and a plurality of pilot signal transferring means for each of said positions, a plurality of pilot signals operated respectively by way of said signal means; means to give precedence to said signals in a regular sequence; means whereby the operation of one of said signals operates all of the pilot signal transferring means inferior to said signal in the order of precedence established by said 100 sequence, whereby the pilot signals controlled by said transferring means become operable at other positions; a pilot signal, other than said first mentioned signal, individual to one of said operators' positions and 105 operable thereat; means, including one of said transferring means, whereby said signal becomes operable at another of said positions by way of one of said transferring means thereat; means, operative when said 110 transferring means is operated, whereby said signal becomes operable at said first mentioned position by way of one of said transferring means thereat superior in order of precedence to said first mentioned trans- 115

ferring means thereat; and means, operative at said first mentioned position when said second mentioned transferring means is operated, whereby said signal becomes operable at said second mentioned position by way of one of said transferring means superior in order of precedence to said first mentioned transferring means thereat.

98. A telephone exchange system, including telephone lines extending from substations to an exchange switchboard having a line signal individual to each line, a plurality of operators' positions at said switchboard, pilot signal operating means and a plurality of pilot signal transferring means for each of said positions, a plurality of pilot signals operated respectively by way of said signal means; means to give precedence to said signals in a regular sequence; means whereby the operation of one of said signals operates all of the pilot signal transferring means inferior to said signal in the order of precedence established by said sequence, whereby the pilot signals controlled by said transferring means become operable at other positions; a pilot signal, other than said first mentioned signal, individual to one of said operators' positions and operable thereat; means, including one of said transferring means, whereby said signal becomes operable at another of said positions by way of one of said transferring means thereat; means, operative when said transferring means is operated, whereby said signal becomes operable at said first mentioned position by way of one of said transferring means thereat superior in order of precedence to said first mentioned transferring means thereat; means, operative at said first mentioned position when said second mentioned transferring means is operated, whereby said signal becomes operable at said second mentioned position by way of one of said transferring means superior in order of precedence to said first mentioned transferring means thereat; and means, operative at said second mentioned position when said second mentioned transferring means is operated, whereby said signal becomes similarly operable at still other positions.

99. A telephone exchange system, including telephone lines extending from substations to an exchange switchboard having a line signal individual to each line, a plurality of operators' positions at said switchboard, pilot signal operating means and a plurality of pilot signal transferring means for each of said positions, a plurality of pilot signals operated respectively by way of said signal means; means to give precedence to said signals in a regular sequence; means whereby the operation of one of said signals operates all of the pilot signal transferring means inferior to said signal in the

order of precedence established by said sequence, whereby the pilot signals controlled by said transferring means become operable at other positions; a pilot signal, other than said first mentioned signal, individual to one of said operators' positions and operable thereat; means, including one of said transferring means for selecting one of a plurality of other positions at which said signal is operable and operating said signal by way of one of said transferring means thereat; means, operative when all of said transferring means of said plurality of positions are operated, whereby said signal becomes operable at said first mentioned position by way of one of said transferring means thereat superior in order of precedence to said first mentioned transferring means thereat; and means, operative at said first mentioned position when said second mentioned transferring means is operated, whereby one of said plurality of positions is again selected and said signal becomes operable thereat by way of one of said transferring means superior in order of precedence to said first mentioned means thereat.

100. A telephone exchange system, including telephone lines extending from substations to an exchange switchboard having a line signal individual to each line, a plurality of operators' positions at said switchboard, pilot signal operating means and a plurality of pilot signal transferring means for each of said positions, a plurality of pilot signals operated respectively by way of said signal means; means to give precedence to said signals in a regular sequence; means whereby the operation of one of said signals operates all of the pilot signal transferring means inferior to said signal in the order of precedence established by said sequence, whereby the pilot signals controlled by said transferring means become operable at other positions; a pilot signal, other than said first mentioned signal, individual to one of said operators' positions and operable thereat; means, including one of said transferring means for selecting one of a plurality of other positions at which said signal is operable and operating said signal by way of one of said transferring means thereat; means, operative when all of said transferring means of said plurality of positions are operated, whereby said signal becomes operable at said first mentioned position by way of one of said transferring means thereat superior in order of precedence to said first mentioned transferring means thereat; and means, operative at said first mentioned position when said second mentioned transferring means is operated, whereby one of said plurality of positions is again selected and said signal becomes operable thereat by way of one of said transferring means superior in order of precedence to said first mentioned means thereat.

dence to said first mentioned means thereat; and means, operative when all of said second mentioned transferring means of said plurality of positions are operated, whereby 5 said signal becomes similarly operable at still other positions.

101. A telephone exchange system, including telephone lines extending from substations to an exchange switchboard having a 10 line signal individual to each line, a plurality of operators' positions at said switchboard, a line pilot signal individual to an operator's position and operated thereat upon the energization of one or more of the 15 line signals of the lines assigned to said position for answering, link connectors at said position for connecting said lines, a link connector signal operative when one of said link connectors is connected to a line 20 and under the control of apparatus at a substation thereof; means, operative when said link connector signal is operated, whereby said pilot signal becomes operable at another of said positions; and means, operative at 25 said second mentioned position when said pilot signal is operated thereat, whereby the pilot signal individual to said second mentioned position becomes operable at still another of said positions.

102. A telephone exchange system, including telephone lines extending from substations to an exchange switchboard having a 30 line signal individual to each line, a plurality of operators' positions at said switchboard, a line pilot signal individual to an operator's position and operated thereat upon the energization of one or more of the 35 line signals of the lines assigned to said position for answering, link connectors at said position for connecting said lines, a link connector signal operative when one of said 40 link connectors is connected to a line and under the control of apparatus at a substation thereof; means, operative when said link connector signal is operated, whereby said pilot signal becomes operable at one of a plurality of other operators' positions at 45 which said pilot signal is operable; and means, operative at said second mentioned position when said pilot signal is operated thereat, whereby the pilot signal individual to said second mentioned position becomes operable at still another of said positions.

103. A telephone exchange system, including telephone lines extending from substations to an exchange switchboard having a 50 line signal individual to each line, a plurality of operators' positions at said switchboard, a line pilot signal individual to an operator's position and operated thereat upon the energization of one or more of the line signals of the lines assigned to said 55 position for answering, link connectors at said position for connecting said lines, a link connector signal operative when one of

said link connectors is connected to a line and under the control of apparatus at a substation thereof; means, operative when said link connector signal is operated, whereby said pilot signal becomes operable at another of said positions; means, operative at 70 said second mentioned position when said pilot signal is operated thereat, whereby the pilot signal individual to said second mentioned position becomes operable at still another of said positions; means operative at 75 said third mentioned position when said second mentioned position signal is operated thereat, whereby the pilot signal individual to said third mentioned position becomes operable at still another of said positions; and means whereby the pilot signals individual to still other of said positions are successively and similarly operated.

104. A telephone exchange system, including telephone lines extending from substations to an exchange switchboard having a line signal individual to each line, a plurality of operators' positions at said switchboard; a line pilot signal individual to an operator's position at said switchboard and operated thereat upon the energization of one or more of the line signals of the lines assigned to said position for answering, link connectors at said position for connecting said lines, a link connector signal operative when one of said link connectors is connected to a line and under the control of apparatus at a substation thereon; and means, operative when said link connector signal is operated, 95 whereby said pilot signal is not operated at 100 said position.

105. A telephone exchange system, including telephone lines extending from substations to an exchange switchboard having a 105 line signal individual to each line, a plurality of operators' positions at said switchboard; a line pilot signal individual to an operator's position at said switchboard and operated thereat upon the energization of 110 one or more of the line signals of the lines assigned to said position for answering, link connectors at said position for connecting said lines, a link connector signal operative when one of said link connectors is connected 115 to a line and under the control of apparatus at a substation thereof; and means, operative when said link connector signal is operated, whereby said pilot signal becomes operable at another operator's position.

106. A telephone exchange system, including telephone lines extending from substations to an exchange switchboard having a line signal individual to each line, a plurality of operators' positions at said switchboard; a line pilot signal individual to an operator's position at said switchboard and operated thereat upon the energization of one or more of the line signals of the lines assigned to said position for answering,

link connectors at said position for connecting said lines, a link connector signal operative when one of said link connectors is connected to a line and under the control of apparatus at a substation thereof; means, operative when said link connector signal is operated, whereby said pilot signal becomes operable at another operator's position; and means operative at said second 10 mentioned position whereby said pilot signal becomes operable at still another position.

107. A telephone exchange system, including telephone lines extending from substations to an exchange switchboard having a line signal individual to each line, a plurality of operators' positions at said switchboard; a line pilot signal individual to an operator's position at said switchboard and operated thereat upon the energization of 15 one or more of the line signals of the lines assigned to said position for answering, link connectors at said position for connecting said lines, a link connector signal operative when one of said link connectors is connected to a line and under the control of apparatus at a substation thereof; means, operative when said link connector signal is operated, whereby said pilot signal becomes operable at another operator's position, 20 means operative at said second mentioned position whereby said pilot signal becomes operable at still another position; and means operative at said third mentioned position 25 whereby said pilot signal is not at once operated at any of said positions but is ultimately operated at said first, second or third mentioned position, according to which position first restores said means thereat to its 30 normal condition; and means, operative when said pilot signal has begun to be operated at one of said positions, whereby it is neither discontinued nor operated at one of the other of said positions should said 35 means thereat subsequently be restored to normal condition.

108. A telephone exchange system, including telephone lines extending from substations to an exchange switchboard having a line signal individual to each line, a plurality of operators' positions at said switchboard; a line pilot signal individual to an operator's position at said switchboard and operated thereat upon the energization of one 40 or more of the line signals of the lines assigned to said position for answering, link connectors at said position for connecting said lines, a link connector signal operative when one of said link connectors is connected to a line and under the control of apparatus 45 at a substation thereof; means, operative when said link connector signal is operated whereby said pilot signal becomes operable at another operator's position; means operative at said second mentioned position whereby said pilot signal becomes operable at still another position; and means operative at said third mentioned position whereby said pilot signal is not at once operated at any of said positions but is ultimately operated at said first, second or third mentioned position, according to which position first restores said means thereat to its normal 50 condition.

109. A telephone exchange system, including telephone lines extending from substa-

tions to an exchange switchboard having a line signal individual to each line, a plurality of operators' positions at said switchboard; a line pilot signal individual to an operator's position at said switchboard and 70 operated thereat upon the energization of one or more of the line signals of the lines assigned to said position for answering, link connectors at said position for connecting said lines, a link connector signal operative 75 when one of said link connectors is connected to a line and under the control of apparatus at a substation thereof; means, operative when said link connector signal is operated, whereby said pilot signal becomes 80 operable at another operator's position; means operative at said second mentioned position whereby said pilot signal becomes operable at still another position; means operative at said third mentioned position 85 whereby said pilot signal is not at once operated at any of said positions but is ultimately operated at said first, second or third mentioned position, according to which position first restores said means thereat to its 90 normal condition; and means, operative when said pilot signal has begun to be operated at one of said positions, whereby it is neither discontinued nor operated at one of the other of said positions should said 95 means thereat subsequently be restored to normal condition.

110. A telephone exchange system, including telephone lines extending from substations to an exchange switchboard having a line signal individual to each line, a plurality of operators' positions at said switchboard, a telephone receiver for one of said positions, link connectors at said position for connecting said lines, a link connector signal operative when one of said link connectors is connected to a line and under the control of apparatus at a substation thereof; means, operative upon the energization of one or more of the line signals of the lines assigned to said position for answering, link connectors at said position for connecting said lines, a link connector signal operative when one of said link connectors is connected to a line and under the control of apparatus at a substation thereof; means, operative when said link connector signal is operated, whereby said pilot signal becomes capable of being 100 sounded in the receiver at another operator's position, instead of sounded in said first mentioned receiver; and means, operative at said second mentioned position when said pilot signal is sounded in said receiver thereat, 105 whereby the audible pilot signal individual to said second mentioned position becomes capable of being sounded in the receiver at still another position.

111. A telephone exchange system, including telephone lines extending from substations to an exchange switchboard having a line signal individual to each line, a plurality of operators' positions at said switchboard, a telephone receiver for one of said 110

signal becomes capable of being similarly sounded at still other operators' positions.

116. A telephone exchange system, including telephone lines extending from substations to an exchange switchboard having a line signal individual to each line, a plurality of operators' positions at said switchboard, a telephone receiver for one of said positions, link connectors at said position for connecting said lines, a link connector signal operative when one of said link connectors is connected to a line and under the control of apparatus at a substation thereof; means, operative upon the energization of one or 10 more of the line signals of the lines assigned to said position for answering, whereby an audible pilot signal is sounded in said receiver; means, operative when said link connector signal is operated, whereby said pilot 15 signal becomes capable of being sounded in the receiver at another operator's position, instead of sounded in said first-mentioned receiver; means, operative at said second mentioned position whereby said pilot signal 20 becomes capable of being sounded in the receiver at still another position instead of sounded in said second mentioned receiver; and means, operative at said third mentioned position whereby said pilot signal is not 25 30 at once sounded in any of said receivers, but is ultimately sounded in said first, second or third mentioned receiver, according to which position first restores said means thereat to its normal condition.

35 117. A telephone exchange system, including telephone lines extending from substations to an exchange switchboard having a line signal individual to each line, a plurality of operators' positions at said switchboard, a telephone receiver for one of said positions, link connectors at said position for connecting said lines, a link connector signal operative when one of said link connectors is connected to a line and under the control of apparatus at a substation thereof; means, operative upon the energization of one or 40 more of the line signals of the lines assigned to said position for answering, whereby an audible pilot signal is sounded in said receiver; means, operative when said link connector signal is operated, whereby said pilot signal becomes capable of being sounded in the receiver at another operator's position, instead of sounded in said first mentioned receiver; means, operative at said second mentioned position whereby said pilot signal 45 becomes capable of being sounded in the receiver at still another position instead of sounded in said second mentioned receiver; and means, operative at said third mentioned position where 50 by said pilot signal is not at once sounded in any of said receivers, but is ultimately sounded in said first, second or third mentioned receiver, according to which position first restores said means thereat to its normal condition.

its normal condition; and means, operative when said pilot signal has begun to be sounded at one of said positions, whereby it is neither discontinued nor sounded at one of the other of said positions should said means thereat subsequently be restored to normal condition.

118. A telephone exchange system, including telephone lines extending from substations to an exchange switchboard having a line signal individual to each line, a plurality of operators' positions at said switchboard, a line pilot signal individual to an operator's position at said switchboard and operated thereat upon the energization of one or more of the line signals of the lines assigned to said position for answering, link connectors at said position for connecting said lines, a disconnect signal and a recall signal operative when one of said link connectors is connected to a line; means under the control of apparatus at a substation of said line for operating either said disconnect or recall signal; means, operative when said disconnect or recall signal is operated, whereby said pilot signal becomes operable at another operator's position; means, similarly operative at said second mentioned position whereby said pilot signal is not operated thereat but becomes operable at still another position; and means, similarly operative, at said third mentioned position whereby said pilot signal is not operated thereat but becomes operable at said first mentioned position, provided the operation of said first mentioned means was caused by the operation of said disconnect signal; means at said first mentioned position, operative when said recall signal is operated thereat, whereby said pilot signal is not operated thereat but becomes operable again at said second mentioned position; means at said second mentioned position, operative when said recall signal is operated thereat, whereby said pilot signal is not operated but becomes operable again at said third mentioned position; and means at said third mentioned position, operative when said recall signal is operated thereat, whereby said pilot signal is similarly operated at still other positions.

119. A telephone exchange system, including telephone lines extending from substations to an exchange switchboard having a line signal individual to each line, a plurality of operators' positions at said switchboard, a line pilot signal individual to an operator's position at said switchboard and operated thereat upon the energization of one or more of the line signals of the lines assigned to said position for answering, link connectors at said position for connecting said lines, a disconnect signal and a recall signal operative when one of said link connectors is connected to a line; means under the control of appa-

ratus at a substation of said line for operating either said disconnect or recall signal; means, operative when said disconnect or recall signal is operated, whereby said pilot signal becomes operable at another operator's position; means, similarly operative, at said second mentioned position whereby said pilot signal is not operated thereat but becomes operable at still another position; means, 10 similarly operative, at said third mentioned position whereby said pilot signal is not operated thereat but becomes operable at said first mentioned position, provided the operation of said first mentioned means was caused by the operation of said disconnect signal; means at said first mentioned position, operative when said recall signal is operated thereat, whereby said pilot signal is not operated thereat but becomes operable again 15 at said second mentioned position; means at said second mentioned position, operative when said recall signal is operated thereat, whereby said pilot signal is not operated but becomes operable again at said third mentioned position; and means at said third mentioned position, operative when said recall signal is operated thereat, whereby said pilot signal is not operated at any of said positions but is operated at said first, second or third mentioned position according to which position first discontinues said recall signal.

120. A telephone exchange system, including telephone lines extending from substations to an exchange switchboard having a line signal individual to each line, a plurality of operators' positions at said switchboard, a telephone receiver for each of said positions, link connectors at said positions for connecting said lines, a disconnect signal and a recall signal operative when one of said link connectors is connected to a line and under the control of apparatus at a substation thereof; means, operative upon the energization of one or more of the line signals of the lines assigned to a position for answering, whereby an audible pilot signal is sounded in said receiver; means, operative when said disconnect or recall signal is operated, whereby said pilot signal becomes capable of being sounded in the receiver at another operator's position, instead of sounded in said first mentioned receiver; means, similarly operative, at said second mentioned position whereby said pilot signal becomes capable of being sounded in the receiver at still another operator's position, instead of sounded in said second mentioned receiver; and means, similarly operative at said third mentioned position whereby said pilot signal becomes capable of being similarly sounded at still other operators' positions.

121. A telephone exchange system, including telephone lines extending from substa-

tions to an exchange switchboard having a line signal individual to each line, a plurality of operators' positions at said switchboard, a telephone receiver for each of said positions, link connectors at said positions for connecting said lines, a disconnect signal and a recall signal operative when one of said link connectors is connected to a line and under the control of apparatus at a substation thereof; means, operative upon the energization of one or more of the line signals of the lines assigned to a position for answering, whereby an audible pilot signal is sounded in said receiver; means, operative when said disconnect or recall signal is operated, whereby said pilot signal becomes capable of being sounded in the receiver at another operator's position, instead of sounded in said first mentioned receiver; means, similarly operative, at said second mentioned position whereby said pilot signal becomes capable of being sounded in the receiver at still another operator's position, instead of sounded in said second mentioned receiver; and means, similarly operative, at said third mentioned position whereby said pilot signal is not sounded in the receiver thereat but becomes capable of being sounded in the receiver at the first, second or third mentioned position according to which position first restores said means thereat to its normal condition.

122. A telephone exchange system, including telephone lines extending from substations to an exchange switchboard having a line signal individual to each line, a plurality of operators' positions at said switchboard, a telephone receiver for each of said positions, link connectors at said positions for connecting said lines, a disconnect signal and a recall signal operative when one of said link connectors is connected to a line and under the control of apparatus at a substation thereof; means, operative upon the energization of one or more of the line signals of the lines assigned to a position for answering, whereby an audible pilot signal is sounded in said receiver; means, operative when said disconnect or recall signal is operated, whereby said pilot signal becomes capable of being sounded in the receiver at another operator's position, instead of sounded in said first mentioned receiver; means, similarly operative, at said second mentioned position whereby said pilot signal becomes capable of being sounded in the receiver at still another operator's position, instead of sounded in said second mentioned receiver; means, similarly operative, at said third mentioned position whereby said pilot signal is sounded in the receiver at said first mentioned position, provided said first mentioned means thereat was operated upon the sounding of said disconnect signal, in which event said disconnect signal is discontinued;

means at said first mentioned position operative when said recall signal is operated thereat, whereby said pilot signal is not sounded thereat but becomes capable again of being sounded in said receiver at said second mentioned position; means at said second mentioned position, operative when said recall signal is operated thereat, whereby said pilot signal is not sounded thereat but becomes capable again of being sounded in said receiver at said third mentioned position; and means at said third mentioned position, operative when said recall signal is operated thereat, whereby said pilot signal becomes capable of being similarly sounded at still other positions.

123. A telephone exchange system, including telephone lines extending from substations to an exchange switchboard having a line signal individual to each line, a plurality of operators' positions at said switchboard, a telephone receiver for each of said positions, link connectors at said position for connecting said lines, a disconnect signal and a recall signal operative when one of said link connectors is connected to a line and under the control of apparatus at a substation thereof; means, operative upon the energization of one or more of the line signals of the lines assigned to said position for answering, whereby an audible pilot signal is sounded in said receiver; means, operative when said disconnect or recall signal is operated, whereby said pilot signal becomes capable of being sounded in the receiver at another operator's position, instead of sounded in said first mentioned receiver; means, operative at said second mentioned position whereby said pilot signal becomes capable of being sounded in the receiver at still another operator's position instead of sounded in said second mentioned receiver; means, operative at said third mentioned position whereby said pilot signal becomes capable of being sounded in the receiver at said first mentioned position instead of sounded in said receiver at said third mentioned position; provided said first mentioned means thereat was operated by said disconnect signal, in which event said disconnect signal is discontinued; and means at said first mentioned position, operative when said first mentioned means thereat was operated by said recall signal, whereby said last mentioned pilot signal is not at once sounded in any of said receivers, but is ultimately sounded in said first, second or third mentioned receiver according to which position first restores said means thereat to its normal condition.

125. A telephone exchange system, including telephone lines extending from substations to an exchange switchboard having a line signal individual to each line, a plurality of operators' positions at said switchboard, a line pilot signal individual to an operator's position at said switchboard and operated thereat upon the energization of one or more of the line signals of the lines assigned to said position for answering, link connectors at said position for connecting said lines, a disconnect signal and a recall signal operative when one of said link connectors is connected to a line; means under the control of apparatus at a substation of said line for operating either said disconnect or recall signal; means, operative when

mately sounded in the receiver at said first, second or third mentioned position according to which position first discontinues said recall signal.

124. A telephone exchange system, including telephone lines extending from substations to an exchange switchboard having a line signal individual to each line, a plurality of operator's positions at said switchboard, a telephone receiver for each of said positions, link connectors at said position for connecting said lines, a disconnect signal and a recall signal operative when one of said link connectors is connected to a line and under the control of apparatus at a substation thereof; means, operative upon the energization of one or more of the line signals of the lines assigned to said position for answering, whereby an audible pilot signal is sounded in said receiver; means, operative when said disconnect or recall signal is operated, whereby said pilot signal becomes capable of being sounded in the receiver at another operator's position, instead of sounded in said first mentioned receiver; means, operative at said second mentioned position whereby said pilot signal becomes capable of being sounded in the receiver at still another operator's position instead of sounded in said second mentioned receiver; means, operative at said third mentioned position whereby said pilot signal becomes capable of being sounded in the receiver at said first mentioned position instead of sounded in said receiver at said third mentioned position; provided said first mentioned means thereat was operated by said disconnect signal, in which event said disconnect signal is discontinued; and means at said first mentioned position, operative when said first mentioned means thereat was operated by said recall signal, whereby said last mentioned pilot signal is not at once sounded in any of said receivers, but is ultimately sounded in said first, second or third mentioned receiver according to which position first restores said means thereat to its normal condition.

125. A telephone exchange system, including telephone lines extending from substations to an exchange switchboard having a line signal individual to each line, a plurality of operators' positions at said switchboard, a line pilot signal individual to an operator's position at said switchboard and operated thereat upon the energization of one or more of the line signals of the lines assigned to said position for answering, link connectors at said position for connecting said lines, a disconnect signal and a recall signal operative when one of said link connectors is connected to a line; means under the control of apparatus at a substation of said line for operating either said disconnect or recall signal; means, operative when

a call is being answered at said position and also when said disconnect or recall signal is operated, whereby said pilot signal becomes operable at another operator's position; 5 means, operative at said second mentioned position whereby said pilot signal becomes operable at still another position; and means, operative at said third mentioned position whereby said pilot signal becomes operable 10 at said first mentioned position, provided said first mentioned means thereat was operated by said disconnect signal, in which event the operation of said disconnect signal is discontinued; and means at said first mentioned position, operative when a call is being answered and also when said recall signal is operated, whereby said last mentioned pilot signal is not operated but is operated at said first, second or third mentioned positions according to which position first restores said means thereat to its normal condition. 15

126. A telephone exchange system, including telephone lines extending from substations to an exchange switch-board having a 20 line signal individual to each line, a plurality of operators' positions at said switch-board, a line pilot signal individual to an operator's position at said switchboard and operated thereat upon the energization of 25 one or more of the line signals of the lines assigned to said position for answering, link connectors at said position for connecting said lines, a disconnect signal and a recall signal operative when one of said link connectors is connected to a line; means under 30 the control of apparatus at a substation of said line for operating either said disconnect or recall signal; means, operative when a call is being answered at said position and 35 also when said disconnect or recall signal is operated, whereby said pilot signal becomes operable at another operator's position; means, operative at said second mentioned position whereby said pilot signal becomes 40 operable at still another position; and means, operative at said third mentioned position whereby said pilot signal becomes similarly operable at still other positions. 45

127. A telephone exchange system, including telephone lines extending from substations to an exchange switchboard having a line signal individual to each line, a plurality of operator's positions at said switch-board, a line pilot signal individual to one 50 of said operator's positions and operated thereat upon the energization of one or more of the line signals of the lines assigned to said position for answering; means, including means individual to said position, to 55 operate said pilot signal at another operator's position; and means, operative once said signal has begun to be operated at said other position, for maintaining said signal operated independent of said second mentioned means 60 65 means, whereby said signal can only be discontinued at said second mentioned position by the de-energization of said line signal or signals or by the operation of means individual to said second mentioned position. 70

128. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 75 said position for answering; means, including means individual to said position, to operate said pilot signal at another operator's position; means, operative once said signal has begun to be operated at said other position, for maintaining said signal operated independent of said second mentioned means, whereby said signal can only be discontinued at said second mentioned position by the de-energization of said line signal or signals or by the operation of means individual to said second mentioned position. 80

129. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 85 said position for answering; means, including means individual to said position, to operate said pilot signal at another operator's position; and means, operative once said signal has begun to be operated thereat for maintaining said signal operated independent of said fourth mentioned means whereby said signal can only be discontinued by the de-energization of said line signal or signals or by the operation of means individual to 90 said third mentioned position. 95

130. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 100 said position for answering; means, including means individual to said position, to operate said pilot signal at another operator's position; means, operative once said signal has begun to be operated at said other position, for maintaining said signal operated independent of said second mentioned means, whereby said signal can only be discontinued at said second mentioned position by the de-energization of said line signal or signals or by the operation of means individual to said second mentioned position. 105

131. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 110 said position for answering; means, including means individual to said position, to operate said pilot signal at another operator's position; means, operative once said signal has begun to be operated at said other position, for maintaining said signal operated independent of said second mentioned means, whereby said signal can only be discontinued at said second mentioned position by the de-energization of said line signal or signals or by the operation of means individual to said second mentioned position. 115

132. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 120 said position for answering; means, including means individual to said position, to operate said pilot signal at still another operator's position; means, operative once said signal has begun to be operated at said other position, for maintaining said signal operated independent of said fourth mentioned means whereby said signal can only be discontinued at said second mentioned position by the de-energization of said line signal or signals or by the operation of means individual to said second mentioned position. 125

133. A telephone exchange system, including telephone lines extending from substations to an exchange switchboard having a line signal individual to each line, a plurality of operator's positions at said switch-board, a line pilot signal individual to one of said operator's positions and operated thereat upon the energization of one or more of the line signals of the lines assigned to 130 said position for answering; means, including means individual to said position, to operate said pilot signal at still another operator's position; means, operative once said signal has begun to be operated at said other position, for maintaining said signal operated independent of said fourth mentioned means whereby said signal can only be discontinued at said second mentioned position by the de-energization of said line signal or signals or by the operation of means individual to said second mentioned position. 130

tinued by the de-energization of said line signal or signals or by the operation of means individual to said third mentioned position; and similar means at said third mentioned position whereby said signal is similarly operated at still other positions.

120. A telephone exchange system, including telephone lines extending from substations to an exchange switchboard having a line signal individual to each line, a plurality of operator's positions at said switchboard, a line pilot signal individual to one of said operator's positions and operated thereat upon the energization of one or more of the line signals of the lines assigned to said position for answering; means, including means individual to said position, to operate said pilot signal at another operator's position; means, operative when said signal has begun to be operated thereat, whereby it can only be discontinued by the de-energization of said line signal or signals or by the operation of means individual to said second mentioned position, means, including said last mentioned means, to operate said signal at still another operator's position; means, operative when said signal has begun to be operated thereat, whereby it can only be discontinued by the de-energization of said line signal or signals or by the operation of means individual to said third mentioned position; means, including said last mentioned means, to operate said signal at said first mentioned position; and means, operative when said signal has begun to be operated thereat, whereby it can only be discontinued by the de-energization of said line signal or signals or by the operation of means individual to said first mentioned position.
131. A telephone exchange system, including telephone lines extending from substations to an exchange switch-board having a line signal individual to each line, a plurality of operator's positions at said switch-board, a line pilot signal individual to one of said operator's positions and operated thereat upon the energization of one or more of the line signals of the lines assigned to said position for answering; means, including means individual to said position, to operate said pilot signal at another operator's position; means, operative when said signal has begun to be operated thereat, whereby it can only be discontinued by the de-energization of said line signal or signals or by the operation of means individual to said second mentioned position, means, including said last mentioned means, to operate said signal at still another operator's position; means, operative when said signal has begun to be operated thereat, whereby it can only be discontinued by the de-energization of said line signal or signals or by the operation of means individual to said third mentioned position; and means, including said last mentioned means, to operate said signal at said first mentioned position; and means, including said

last mentioned means, whereby said pilot signal is not at once operated at any of said positions but is ultimately operated at said first, second or third mentioned position according to which position first restores said individual means thereat to its normal condition; and means, operative when said signal has begun to be operated at one of said positions, whereby it can only be discontinued by the de-energization of said line signal or signals or by the operation of means individual to the position at which the signal is being operated.

132. A telephone exchange system, including telephone lines extending from substations to an exchange switchboard having a line signal individual to each line; a plurality of operators' positions at said switchboard, a line pilot signal individual to an operator's position at said switchboard and operated by one or more of the line signals of the lines assigned to said position for answering; means operative at said position to operate said pilot signal at another operator's position; means operative at said second mentioned position to operate said signal at still another position; and means operative at said third mentioned position to operate said signal at said first mentioned position.

133. A telephone exchange system, including telephone lines extending from substations to an exchange switchboard having a line signal individual to each line; a plurality of operators' positions at said switchboard, link connectors for each of said positions, a line pilot signal individual to an operator's position at said switchboard and operated by one or more of the line signals of the lines assigned to said position for answering; means operative at said position to operate said pilot signal at another operator's position; means operative at said second mentioned position to operate said signal at still another position; and means comprising apparatus associated with one or more of said link connectors and operative at said third mentioned position whereby said signal is similarly operated at still other positions.

134. A telephone exchange system including telephone lines extending from substations to an exchange switchboard having a line signal individual to each line; a plurality of operators' positions at said switchboard, a line pilot signal individual to an operator's position at said switchboard and operated by one or more of the line signals of the lines assigned to said position for answering; means operative at said position to operate said pilot signal at another operator's position; means operative at said second mentioned position to operate said signal at still another position; means operative at said third mentioned position to operate said signal at said first mentioned position; means operative at said first men-

tioned position, other than said first mentioned means, to prevent the operation thereof of said signal; and means whereby said signal will thereupon be operated at 5 said first, second or third mentioned positions, according to which position first restores to normal the aforementioned means thereat.

135. A telephone exchange system, including telephone lines extending from substations to an exchange switchboard having a line signal individual to each line; a plurality of operators' positions at said switchboard, an audible line pilot signal 15 individual to an operator's position at said switchboard and operated by one or more of the line signals of the lines assigned to said position for answering; means operative at said position to operate said pilot signal at another operator's position; means operative at said second mentioned position to operate said signal at still another position; and means operative at said third mentioned position to operate said signal 25 at said first mentioned position.

136. A telephone exchange system, including telephone lines extending from substations to an exchange switchboard having a line signal individual to each line; a telephone receiver for an operator's position at said switchboard; means common to a group of said line signals to sound an audible signal in said receiver simultaneously with the operation of any line signal in said group, 30 said means including a source of fluctuating current, a signal circuit associated with said receiver and including said source; means at said position to transfer said circuit from association with said receiver to association 35 with a receiver at another operator's position, thereby sounding said signal in said last mentioned receiver instead of in said first mentioned receiver; means at said second mentioned position to transfer said 40 circuit from association with said receiver thereat, to association with a receiver at still another operator's position; and means operative at said third mentioned position to transfer said circuit from association 45 with said receiver thereat, to association again with said receiver at said first mentioned position.

137. A telephone exchange system, including telephone lines extending from substations to an exchange switchboard having a line signal individual to each line, a telephone receiver for an operator's position at said switchboard; means common to a group of said line signals to sound an 55 audible signal in said receiver simultaneously with the operation of any line signal in said group, said means including a source of fluctuating current, a signal circuit associated with said receiver and including 60 said source; means at said position to trans-

fer said circuit from association with said receiver to association with a receiver at another operator's position, thereby sounding said signal in said last mentioned receiver instead of in said first mentioned receiver; 70 means at said second mentioned position to transfer said circuit from association with said receiver thereat, to association with a receiver at still another operator's position; means operative at said third mentioned position to transfer said circuit from association with said receiver thereat to association again with said receiver at said first mentioned position; means operative at said first mentioned position, other than said first 80 mentioned means, to prevent the sounding thereof of said signal; and means whereby said signal will thereupon be sounded in the receiver at said first, second or third mentioned position, according to which position first restores to normal condition the aforementioned means thereat.

138. A telephone exchange system, including telephone lines extending from substations to an exchange switchboard having a line signal individual to each line; a plurality of operators' positions at said switchboard, a telephone receiver for each of said positions, a plurality of said positions having individual numbers assigned 95 to them; means, operative upon the energization of one or more of the line signals of the lines assigned to a position for answering, whereby an audible signal comprising the number assigned to said position is 100 sounded in the receiver thereat; and means for sounding said signal in the receivers at other operators' positions, the number sounded indicating the position to which the signal pertains.

139. A telephone exchange system, including telephone lines extending from substations to an exchange switchboard having a plurality of line signals individual to each line, operators' positions at said switchboard having a plurality of groups of line signals assigned to each position, said groups corresponding in number to said plurality of line signals, said plurality of line signals individual to a line being distributed amongst 110 said positions and located in said groups; means under the control of apparatus at one of said substations to energize all the line signals individual to the line of said substation; means, operative upon the energization of said line signals, whereby a pilot signal is operated at one only of said positions at which said line signals are located; and means whereby all of said plurality of positions at which said line signals are located 115 are at one time or another available for the operation of said pilot signal thereat.

140. A telephone exchange system, including telephone lines extending from substations to an exchange switchboard having a 120

plurality of line signals individual to each line, operators' positions at said switchboard having a plurality of groups of line signals assigned to each position, said groups corresponding in number to said plurality of line signals, said plurality of line signals individual to a line being distributed amongst positions bearing corresponding character designations and located in corresponding groups; means under the control of apparatus at one of said substations to energize all the line signals individual to the line of said substation; means, operative upon the energization of said line signals, whereby 5 a pilot signal distinctive to the groups as well as to the positions at which said line signals are located is operated at one only of said positions at which said line signals are located; means whereby all of said plurality of positions at which said line signals are located are at one time or another available for the operation of said pilot signal thereat; and means whereby the positions adjacent to the positions at which said line signals are located are at one time or another available for the operation of said pilot signal thereat.

141. A telephone exchange system, including telephone lines extending from substations to an exchange switchboard having a plurality of line signals individual to each line, operators' positions at said switchboard having a plurality of groups of line signals assigned to each position, said groups corresponding in number to said plurality of line signals, a telephone receiver for each of said positions, individual character designations assigned to said groups, said plurality of line signals individual to a line being distributed amongst said positions and located in said groups which bear corresponding character designations; means under the control of apparatus at one of said substations to energize all the line signals individual to the line of said substation; means, operative upon the energization of said line signals, whereby an audible pilot signal distinctive to the groups at which said line signals are located is sounded in the receiver at one only of said positions at which said line signals are located; and means whereby all of said plurality of positions at which said line signals are located are at one time or another available for the sounding of said signal in the receivers thereat.

142. A telephone exchange system, including telephone lines extending from substations to an exchange switchboard having a plurality of line signals individual to each line, operators' positions at said switchboard having a plurality of groups of line signals assigned to each position, said groups corresponding in number to said plurality of line signals, a telephone receiver for each

of said positions, individual character designations assigned to said groups and also to a plurality of said positions, said plurality of line signals individual to a line being distributed amongst positions bearing corresponding character designations and located in corresponding groups; means under the control of apparatus at one of said substations to energize all the line signals individual to the line of said substation; means, operative upon the energization of said line signals, whereby an audible pilot signal distinctive to the groups as well as to the positions at which said line signals are located is sounded in the receiver at one only of said positions at which said line signals are located; means whereby all of said plurality of positions at which said line signals are located are at one time or another available for the sounding of said signal in the receivers thereat; and means whereby the positions adjacent to the positions at which said line signals are located are at one time or another available for the sounding of said signal in the receivers thereat.

143. A telephone exchange system, including telephone lines extending from substations to an exchange switchboard having a line signal individual to each line, a plurality of operators' positions for said switchboard, a plurality of electromagnetic pilot signal transferring means individual to a position; means, operative when an operator is on duty at said position, for operating said transferring means; and means, operative when said operator vacates said position, whereby said transferring means are maintained operated.

144. A telephone exchange system, including telephone lines extending from substations to an exchange switchboard having a line signal individual to each line, a plurality of operators' positions for said switchboard, a plurality of pilot signal transferring means individual to a position; means, operative when an operator is on duty at said position, for operating said transferring means; and means, operative when said operator vacates said position, whereby said transferring means are maintained operated, said third mentioned means comprising a relay, an operator's telephone transmitter, an operator's transmitter plug and jack and the primary of an induction coil, a circuit including said relay, transmitter, plug, jack, primary and a source of electricity, so connected and arranged that the withdrawal of said plug from said jack when the position is vacated opens said circuit and de-energizes said relay.

145. A telephone exchange system, including telephone lines extending from substations to an exchange switchboard having a line signal individual to each line, a plu-

rality of operators' positions for said switchboard, link connectors for connecting said substations; means, operative when an operator is on duty at a position, for connecting 5 all of the link connectors at said position to signaling instrumentalities individual to said position; and means, operative when said operator vacates said position, whereby said link connectors are disconnected from 10 said instrumentalities and connected to similar instrumentalities at another operator's position.

146. A telephone exchange system, including telephone lines extending from substations to an exchange switchboard having a line signal individual to each line, a plurality of operator's positions for said switchboard, link connectors for connecting said substations; means, operative when an operator is on duty at a position, for connecting 15 all of the link connectors at said position to signaling instrumentalities individual to said position; means, operative when said operator vacates said position, whereby said link connectors are disconnected from said instrumentalities and connected to similar instrumentalities at another operator's position and said transferring means is maintained operated, means, operative when said second mentioned position is vacated, whereby the link connectors of both of said positions are disconnected from said last mentioned instrumentalities and are connected to similar instrumentalities at still another position; and means for successively and similarly disconnecting and connecting all the 20 link connectors at the remaining positions at said switchboard as they become vacated; said second mentioned means comprising a relay, an operator's telephone transmitter, an operator's transmitter plug and jack and the primary of an induction coil, a circuit including said relay, transmitter, plug, jack, primary and a source of electricity, so connected and arranged that the withdrawal of said plug from said jack when the position 25 is vacated opens said circuit and de-energizes said relay.

147. A telephone exchange system, including telephone lines extending from substations to an exchange switchboard having a line signal individual to each line, a plurality of operators' positions for said switchboard, link connectors for connecting said 30 substations; means, operative when an operator is on duty at a position for connecting all of the link connectors at said position to signaling instrumentalities individual to said position; and means, operative when said operator vacates said position, whereby said link connectors are disconnected from said instrumentalities and connected to similar instrumentalities at another operator's position, said second mentioned means comprising a relay, an operator's telephone transmitter, an operator's transmitter plug and jack and the primary of an induction coil, a circuit including said relay, transmitter, plug, jack, primary and a source 35 of electricity, so connected and arranged that the withdrawal of said plug from said jack when the position is vacated opens said circuit and de-energizes said relay.

148. A telephone exchange system, including telephone lines extending from substations to an exchange switchboard having a line signal individual to each line, a plurality of operators' positions at said switchboard, a pilot signal individual to a position

tions to an exchange switchboard having a line signal individual to each line, a plurality of operators' positions for said switchboard, pilot signal transferring means at said positions, link connectors for connecting 70 said substations; means, operative when an operator is on duty at a position, for connecting all of the link connectors at said position to talking and signaling instrumentalities individual to said position and to operate said 75 transferring means; means, operative when said operator vacates said position, whereby said link connectors are disconnected from said instrumentalities and connected to similar instrumentalities at another operator's position and said transferring means is maintained operated, means, operative when said second mentioned position is vacated, whereby the link connectors of both of said positions are disconnected from said last mentioned instrumentalities and are connected to similar instrumentalities at still another position; and means for successively and similarly disconnecting and connecting all the 80 link connectors at the remaining positions at said switchboard as they become vacated; said second mentioned means comprising a relay, an operator's telephone transmitter, an operator's transmitter plug and jack and the primary of an induction coil, a circuit including said relay, transmitter, plug, jack, primary and a source of electricity, so connected and arranged that the withdrawal of said plug from said jack when the position 85 is vacated opens said circuit and de-energizes said relay.

149. A telephone exchange system, including telephone lines extending from substations to an exchange switchboard having a line signal individual to each line, a plurality of operator's positions at said switchboard, a pilot signal individual to a position and operative thereat when an operator is on duty upon the energization of one or more of the line signals assigned to said position for answering; means for operating pilot signals individual to other positions at each of said positions; means, operative when said operator vacates said position, whereby said pilot signal individual thereto is operated at another of said positions; and means, operative at said second mentioned position, when said pilot signal is operated thereat, whereby the pilot signal individual thereto and said pilot signals individual to other positions are operated at still other positions but said pilot signal of the vacant position is operated only at said second mentioned position.

150. A telephone exchange system, including telephone lines extending from substations to an exchange switchboard having a line signal individual to each line, a plurality of operators' positions at said switchboard, a pilot signal individual to a position

and operative thereat when an operator is on duty upon the energization of one or more of the line signals assigned to said position for answering; means for operating pilot signals individual to other positions at each of said positions; means, operative when said operator vacates said position, whereby said pilot signal individual thereto is operated at another of said positions; and means, operative at said second mentioned position, when said pilot signal is operated thereat, whereby the pilot signal individual thereto and said pilot signals individual to other positions are operated at still other positions but said pilot signal of the vacant position is operated only at said second mentioned position, means operative when said second mentioned position is vacated, whereby the pilot signals individual to both of said positions are similarly operated at still another position; and means for successively and similarly operating the pilot signals individual to the remaining positions at said switchboard as they become vacated.

151. A telephone exchange system, including telephone lines extending from substations to an exchange switchboard having a line signal individual to each line, a plurality of operators' positions at said switchboard, a pilot signal individual to a position and operative thereat when an operator is on duty upon the energization of one or more of the line signals assigned to said position for answering; means for operating pilot signals individual to other positions at each of said positions; means, operative when said operator vacates said position, whereby said pilot signal individual thereto is operated at another of said positions; and means, operative at said second mentioned position, when said pilot signal is operated thereat, whereby the pilot signal individual thereto and said pilot signals individual to other positions are operated at still other positions but said pilot signal of the vacant position is operated only at said second mentioned position, said second mentioned means comprising a relay, an operator's telephone transmitter, an operator's transmitter plug and jack and the primary of an induction coil, a circuit including said relay, transmitter, plug, jack, primary and a source of electricity, so connected and arranged that the withdrawal of said plug from said jack when the position is vacated opens said circuit and de-energizes said relay.

152. A telephone exchange system, including telephone lines extending from substations to an exchange switchboard having a line signal individual to each line, an audible signal producing means comprising an interrupter, a source of electricity, a primary winding connected to said source through said interrupter, an operator's telephone receiver in inductive relation to a

secondary winding associated with said primary winding, link connectors for connecting said lines; means for closing a circuit including said secondary winding when one or more of said line signals at an operator's position are energized, whereby an audible signal is produced by said audible signal means in said receiver; and means operative whenever said receiver is telephonically connected to a substation by way of one of said link connectors, whereby said circuit is maintained open and consequently the sounding of said signal prevented.

153. A telephone exchange system, including telephone lines extending from substations to an exchange switchboard having a line signal individual to each line, an audible signal producing means comprising a source of variable electricity and a circuit therefor, a relay for controlling said circuit, an operator's telephone receiver in inductive relation to said circuit, link connectors for connecting said lines; means for closing said circuit including said source when one or more of said line signals at an operator's position are energized, whereby an audible signal is produced by said audible signal means in said receiver; and means comprising said relay and operative whenever said receiver is telephonically connected to a substation by way of one of said link connectors, whereby said circuit is inductively connected to a similar receiver to said first mentioned receiver, thereby sounding said signal therein instead of said first mentioned receiver.

154. A telephone exchange system, including telephone lines extending from substations to an exchange switchboard having a line signal individual to each line, an induction coil, a telephone receiver connected in circuit with the secondary of said induction coil, a source of variable electricity, link connectors for connecting said lines; relay means for closing a circuit including the primary of said induction coil and said source when one or more of the line signals of the lines assigned to an operator for answering are energized, whereby an alternating current is induced in said secondary and consequently an audible signal sounded in said receiver; and means operative whenever said receiver is telephonically connected to a substation by way of one of said link connectors, whereby said primary circuit is maintained open and consequently the sounding of said signal prevented.

155. A telephone exchange system, including telephone lines extending from substations to an exchange switchboard having a line signal individual to each line, an induction coil, a telephone receiver connected in circuit with the secondary of said induction coil, a source of variable electricity, link connectors for connecting said lines; relay means for closing a circuit including the pri-

mary of said induction coil and said source when one or more of the line signals of the lines assigned to an operator for answering are energized, whereby an alternating current is induced in said secondary and consequently an audible signal sounded in said receiver; and means operative whenever said receiver is telephonically connected to a substation by way of one of said link connectors, whereby a primary of a similar induction coil at another operator's position is substituted for said first mentioned primary, thereby sounding said signal in the receiver at said position instead of in said first mentioned receiver.

156. A telephone exchange system, including telephone lines extending from substations to an exchange switchboard having a line signal individual to each line, a relay, an induction coil, a telephone receiver connected in circuit with the secondary of said induction coil, a source of variable electricity, link connectors for connecting said lines; means, operative upon the energization of one or more of the line signals of the lines assigned to an operator for answering, for closing a circuit including two normally engaged contacts of said relay, the primary of said induction coil and said source, whereby an alternating current is induced in said secondary and an audible signal sounded in said receiver; and means, individual to each of said link connectors, for telephonically connecting said receiver to a substation and for closing a circuit including a winding of said relay, thereby energizing said relay, maintaining said contacts disengaged and consequently preventing the sounding of said signal.

40 157. A telephone exchange system, including telephone lines extending from substations to an exchange switchboard having a line signal individual to each line, a relay, an induction coil, a telephone receiver connected in circuit with the secondary of said induction coil, a source of variable electricity, link connectors for connecting said lines; means, operative upon the energization of one or more of the line signals of the lines assigned to an operator for answering, for closing a circuit including two normally engaged contacts of said relay, the primary of said induction coil and said source, whereby an alternating current is induced in said secondary and an audible signal sounded in said receiver; relay means, individual to each of said link connectors, for automatically telephonically connecting said receiver to a substation and for closing a circuit including a winding of said relay, thereby energizing said relay, maintaining said contacts disengaged and consequently preventing the sounding of said signal; and means whereby said energization of said relay closes a 65 circuit including two abnormally engaged

contacts of said relay and a similar primary and said signal is sounded in another receiver.

158. A telephone exchange system, including telephone lines extending from substations to an exchange, link connectors for connecting said substations, a relay for each of said link connectors, calling signal apparatus at said substations, a source of alternating and a source of direct current, means for controlling the passage of alternating current from said first mentioned source around said relay to a called line, means for momentarily short-circuiting said line between alternations of alternating current as impressed thereon, means for controlling the passage of direct current from said second mentioned source through said relay to said called line, the alternations of the alternating current as impressed on said line being of such rapidity as to continuously operate said calling signal apparatus, the direct current being connected to said line only after said line has been momentarily short-circuited by said second mentioned means and between said alternations of the alternating current as impressed on said line, whereby said relay is never traversed by the alternating current and is operated by the direct current only when apparatus under the control of said called substation is substituted for said calling signal apparatus.

159. A telephone exchange system, including telephone lines extending from substations to an exchange, link connectors for connecting said substations, a relay for each of said link connectors, calling signal apparatus at said substations, a source of alternating and a source of direct current, an interrupter for controlling the passage of alternating current from said first mentioned source around said relay to a called line, an interrupter for controlling the passage of direct current from said second mentioned source through said relay to said called line, and an interrupter for momentarily grounding said called line after each alternation of alternating current is impressed on said line, the alternations of the alternating current as impressed on said line being of such rapidity as to continuously operate said calling signal apparatus, the direct current being connected to said line only between alternations of the alternating current as impressed on said line and after said line has been momentarily grounded, whereby said relay is never traversed by the alternating current, nor can receive static discharges from said line and is operated by the direct current only when apparatus under the control of said called substation is substituted for said calling signal apparatus.

160. A telephone exchange system, including telephone lines extending from substations to an exchange, link connectors for

connecting said substations, a relay for each of said link connectors, calling signal apparatus at said substations, a condenser, a source of alternating and a source of direct current, an interrupter for controlling the passage of alternating current from said first mentioned source around said relay to a called line, an interrupter for controlling the passage of direct current from said second mentioned source through said relay to said called line and for shunting said relay with said condenser, the alternations of the alternating current as impressed on said line being of such rapidity as to continuously operate said calling signal apparatus without any intervals of time between the signals as produced by said calling signal apparatus, the direct current being connected to said line and said relay shunted by said condenser only between alternations of the alternating current as impressed on said line, whereby said relay is never traversed by the alternating current and is operated by the direct current only when apparatus under the control of said called substation is substituted for said calling signal apparatus.

161. A telephone exchange system, including telephone lines extending from substations to an exchange, link connectors for connecting said substations, calling signal and talking apparatus at said substations, a calling signal current disconnecting means for each of said link connectors, a source of alternating and a source of direct current, means for controlling the passage of alternating current from said first mentioned source to a called line by way of said link connectors, means for removing the static electrical charges from said line between alternations of said alternating current as impressed on said line, means for controlling the passage of direct current from said second mentioned source, the alternations of the alternating current as impressed on said line being of such rapidity as to continuously operate said calling signal apparatus, the direct current from said second mentioned source being connected to said line only after it has been cleared of its static electrical charge by said second mentioned means and between said impressed alternations only; whereby neither said alternating current nor said static electrical charges traverse said disconnecting means, but said last mentioned means is traversed by said direct current and becomes operative only when said talking apparatus is connected to said line.

In testimony whereof I affix my signature in presence of two witnesses.

HUBERT S. TURNER.
